PENICILLIN ALDEHYDES

William J. Gottstein and Lee C. Cheney, Fayetteville, N.Y., assignors to Bristol-Myers Company, New York, N.Y., a corporation of Delaware
 No Drawing. Filed Mar. 20, 1964, Ser. No. 353,577
 13 Claims. (Cl. 260—306.7)

This invention relates to novel antibacterial agents and chemical reagents and, more particularly, to 6-substituted-penicillanyl aldehydes and especially to penicillin aldehydes.

The aldehydes of the present invention are effective antibacterial agents in vivo against Gram-positive bacteria and are also effective agents for use in a search for oxidative enzymes.

There is thus provided, according to the present invention, the series of compounds having the formula

wherein R^1 is amino, acylamino, benzyloxycarbonylamino, phthalimido or tritylamino. In these compounds the

moiety may exist in tautomeric equilibrium with the enolic structure

The preferred series of compounds is that of the formula

in which R^2 represents the side chain of any of the known penicillins other than those containing a group which is altered by reaction with Raney nickel at 0° C. to 50° C. as determined by simple test. It is this series which may be named 6-(substituted formamido)penicillanyl aldehydes or, more simply, penicillin aldehydes.

In addition to the well-known, older penicillins produced by the use of precursors in fermentation processes, other known penicillins include those disclosed in U.S. Patents 2,941,995, 2,951,839, 2,985,648, 2,996,501, 3,007,920, 3,025,290, 3,028,379, 3,035,047, 3,040,032, 3,040,033, 3,041,332, 3,041,333, 3,043,831, 3,053,831, 3,071,575, 3,071,576, 3,079,305, 3,079,306, 3,080,356, 3,082,204, 3,093,547, 3,093,633, 3,117,119, 3,118,877, 3,120,512, 3,120,513, 3,120,514; in British patent specifications 874,414, 874,416, 876,516, 876,662, 877,120, 877,323, 877,531, 878,233, 880,042, 880,400, 882,335, 888,110, 888,552, 889,066, 889,069, 889,070, 889,168, 889,231, 890,201, 891,174, 891,279, 891,586, 891,777, 891,938, 893,518, 894,247, 894,457, 894,460, 896,072, 899,199, 900,666, 902,703, 903,785, 904,576, 905,778, 906,383, 908,787, 914,419, 916,097, 916,204, 916,205, 916,488, 918,169, 920,176, 920,177, 920,300, 921,513, 922,278, 924,037, 925,281, 931,567, 932,644, 938,066, 938,321, 939,708, 940,488, 943,608, 944,417; in numerous published Belgian patents, e.g. 593,222, 595,171, 597,859, 602,494, 603,703, 609,039, 616,419, 617,187; and South African patent applications, e.g. 60/2882, 60/3057, 60/3748, 61/1649, R61/2751, 62/54, 62/4920, 63/1612 and 63/2423.

Preferred compounds of the present invention are those of the formulae

nd

wherein R⁴ represents hydrogen, amino, carbobenzoxymino, phenyl, fluoro, chloro, bromo, iodo, hydroxy, or (lower) alkanoyloxy including especially acetoxy or (lower) alkoxy; X represents oxygen or sulfur; R⁵ and R⁶ each represent hydrogen, phenyl, benzyl, phenethyl or (lower) alkyl; R⁷ represents (lower) alkyl; R⁸ and R⁹ each represent (lower) alkyl, (lower) alkylthio, benzylthio, cyclohexyl, cyclopentyl, cycloheptyl, benzyl, phenethyl, phenylpropyl, furyl, thienyl, naphthyl or Ar—; R¹⁰ represents (lower) alkylamino, di(lower) alkylamino, cycloalkylamino having from 3 to 7 carbon atoms inclusive, allylamino, diallylamino, phenyl(lower) alkylamino, morpholino, lower(alkyl)morpholino, di(lower) alkylmorpholino, morpholino(lower) alkylamino, pyrrolidino, (lower) alkylpyrrolidino, di(lower) alkylpyrrolidino, N,N-hexanethylenimino, piperidino, lower(alkyl)piperidino, di(lower) alkylpiperidino, 1,2,5,6 - tetrahydropyridino, N-lower(alkyl)piperazino, N-phenyl-piperazino, N-(lower) alkyl(lower) alkylpiperazino, N-(lower)-alkyl-di(lower) alkylpiperazino, furfurylamino, tetrahydrofurfurylamino, N-(lower) alkyl-N-furfurylamino, N-alkyl-N-anilino or (lower) alkoxy-anilino; Z¹, Z² and Z³ each represent a member selected from the group consisting of (lower) alkyl and Ar—; R¹¹ represents (lower) alkyl, (lower) cycloalkyl, naphthyl, benzyl, phenethyl or

and Ar— represents the monovalent radical of the formula

wherein R¹, R² and R³ are each a member selected from the group consisting of hydrogen, chloro, bromo, iodo, trifluoromethyl, phenyl, (lower) alkyl and (lower) alkoxy, but only one R group may represent phenyl.

The term "(lower)alkyl" as used herein means both straight and branched chain aliphatic hydrocarbon radicals having from one to ten carbon atoms such as methyl, ethyl, propyl, isopropyl, butyl, isobutyl, t-butyl, amyl, hexyl, 2-ethylhexyl, heptyl, decyl, etc. Similarly, where the term "(lower)" is used as part of the description of another group, e.g., "(lower)alkoxy," it refers to the alkyl portion of such group which is therefore as described above in connection with "(lower)alkyl."

Preferred embodiments of the present invention are the restricted series of compounds of the following formulae

wherein R represents (lower) alkyl;

wherein R¹ represents (lower) alkyl and R² and R³ each represent a member selected from the group consisting of hydrogen and chloro;

wherein R¹ is (lower) alkyl and R² is a member selected from the group consisting of hydrogen and chloro;

wherein R represents (lower) alkyl;

30 wherein R is (lower) alkyl; and

wherein R is (lower) alkyl; and the individual compounds of the following formulae

and

The compounds of the present invention are prepared, according to the present invention, by either of two methods, as follows:

METHOD A.—OXIDATION OF PENICILLIN ALCOHOLS

The present penicillin aldehydes are prepared by oxidation of the corresponding penicillin alcohols by the addition of about 2-5 moles of a carbodiimide (e.g. dicyclohexylcarbodiimide, diisopropylcarbodiimide) to a solution of about one mole of the alcohol and 0.1-2.0 mole anhydrous phosphoric acid in dry dimethyl sulfoxide. Tetramethylene sulfoxide may also be used and the sulfoxide may be diluted with up to nine volumes of an inert solvent. The reaction proceeds readily at room temperature. The phosphoric acid functions as a catalyst and may be replaced with phosphorous acid, cyanoacetic acid or pyridinium phosphate, trifluoroacetate, hydrochloride or sulfate. Further details are given in the examples below.

METHOD B.—HYDROGENOLYSIS BY RANEY NICKEL OF PENICILLIN THIOACIDS AND THIOESTERS

The penicillin aldehydes of the present invention are preferably prepared by hydrogenolysis by Raney nickel of a thiopenicillin (also called a penicillin thioacid; e.g. see U.S. Patent 2,751,378) which is preferably in the form of the free acid or of a salt such as an alkali metal salt or an amine salt. The reaction is carried out at 0°-50° C. and preferably at close to 0° C. It is advantageous to use an anhydrous or nearly anhydrous solvent

such as tetrahydrofuran or acetone and to use catalytic amounts of a weak anhydrous acid such as glacial acetic acid as the penicillin aldehydes are very sensitive to bases. It is advantageous to add sufficient water to dissolve the thiopenicillin in the reaction mixture in the event that it is not completely soluble in the anhydrous solvent. The proportions are not critical but it is of course desirable to use enough Raney nickel to assure a high yield in the reaction; it is thus preferred to use a weight of Raney nickel (on a wet basis) equal to at least three times the weight of the thiopenicillin. The activated Raney nickel available commercially is quite suitable for use as is that prepared according to Mozingo et al., J. Amer. Chem. Soc., 65, 1013 (1943). The thiopenicillins can be replaced, if desired, with their esters, e.g. with alkylthio or aralkylthio esters; see J. Amer. Chem. Soc., 75, 3636-3637 (1953), J. Chem. Soc. (London), 3733-3739 (1953) and Chem. Ber., 92, 530-534 (1959).

It is on occasion advantageous, but by no means essential, to conduct the hydrogenolysis in the presence of a "trapping" agent for the aldehyde being produced. By this is meant an N,N'-disubstituted-ethylenediamine or a 1,3-disubstituted-propane-1,3-diamine. These reagents condense with the aldehyde formed during the course of the hydrogenolysis to form the corresponding imidazolidines and hexahydropyrimidines respectively, thus protecting the aldehyde function from further reduction or other reaction. The penicillin aldehyde can be readily regenerated by treatment of these heterocyclic derivatives with an acid, e.g., with p-toluenesulfonic acid monohydrate in a suitable solvent such as acetone-ether.

Examples of preferred diamines for use as the aldehyde trapping agents are those of U.S. Patent 2,739,981 and especially N,N'-dibenzylethylenediamine [W. F. Minor, D. A. Johnson and L. C. Cheney, J. Org. Chem., 21, 528 (1956)], N,N-diphenylethylenediamine [W. Wanzlick and W. Löchel, Chem. Ber., 86, 1463 (1953)]. Other suitable diamines include N,N'-dimethylethylenediamine [A. J. Birch, J. Cymerman Craig and M. Slaytor, Australian J. Chem., 8, 512 (1955)] and N,N'-bis(p-methoxybenzyl)-1,3-diaminopropane [J. H. Billman and J. L. Meisenheimer, J. Med. Chem., 6, 682 (1963)].

The product is easily separated from the Raney nickel by filtration and from unreacted starting thiopenicillin by virtue of the fact that only the latter contains an acidic group and can thus be extracted from an organic solvent, such as ether, into aqueous alkali, e.g. 5% NaHCO₃. Where desired, the penicillin aldehydes may be purified by reaction with 2,4-dinitrophenylhydrazine or N,N'-dibenzylethylenediamine [cf. J. Org. Chem., 21, 528-529 (1956) and U.S. Patents 2,717,893 and 2,767,168] to form the hydrazone or imidazolidine respectively, which can itself be purified as by recrystallization and then treated to regenerate purified penicillin aldehyde, e.g. by acid hydrolysis or aldehyde interchange.

The compounds of the present invention exhibit in vitro antibacterial activity. Thus when the Minimum Inhibitory Concentration (MIC) in mcg./ml. was determined in heart infusion broth (to which 5% pooled human serum had been added) for the compounds having the structures

nd

he following results were obtained:

Organism	MIC in meg./ml.				
	Cpd. I	Cpd. II	Cpd. III	Cpd. IV	Ampicillin
<i>S. pneumoniae</i>	12.5	12.5	25	12.5	0.016
<i>S. pyogenes</i>	1.6	3.1	6.3	6.3	0.016
<i>S. aureus</i> Smith	3.1	12.5	25	12.5	0.062

Despite these low levels of in vitro antibacterial activity, it was surprisingly discovered that these compounds are effective antibacterial agents in vivo, that is, exhibited a minimum curative dose in 50% of the mice tested (CD_{50}) against an overwhelmingly lethal dose of *S. aureus* Smith as follows:

Compound:	CD_{50} in mgm./kg.
I	230
II	$^1 < 500$
III	6.0
IV	3.4
Ampicillin	0.6

¹ Complete protection (zero deaths) at 500 mgm./kg.

oxidative enzymes in the microorganism being examined.

The following examples are presented to illustrate the present invention but not to limit it. All temperatures are given in degrees centigrade.

EXAMPLE 1

10

6-phenoxyacetamidopenicillanal. — Commercial, pyrophoric Raney active nickel catalyst, 125 g. wet weight, was washed three times with 275 ml. portions of absolute ethanol and then with four 275 ml. portions of tetrahydrofuran (THF).

The nickel was then suspended in 500 ml. of THF, 10.5 ml. (0.175 mole) of glacial acetic acid was added and the mixture was stirred and cooled to 4°. A solution of 20.22 g. (0.0500 mole) of the potassium salt of penicillin V thiol acid was prepared by suspending the solid in 200 ml. THF and adding 15 ml. water.

This solution was added to the suspension of nickel and the mixture was stirred at 2° for 30 minutes. The catalyst was removed by filtration through diatomaceous earth (Supercel) which was then washed with five 150 ml. portions of THF. From the combined, reddish filtrates the solvent was removed in vacuo at 33°.

The residue was taken up in 1700 ml. ether which was then extracted with three 250 ml. portions of 5% $NaHCO_3$ solution to remove unchanged starting material; the aqueous extracts were discarded. The ethereal phase was then washed with three 175 ml. portions of water, dried over sodium sulfate, decolorized with charcoal and filtered through Supercel. Complete removal by distillation of the solvent from the filtrate left the product, 6-phenoxyacetamidopenicillanal, as a stiff gum (5.7 g.). It was converted to a white solid by twice dissolving it in about 15 ml. methylene chloride which was then poured into 800 ml. n-pentane to precipitate 4.0 g. of the product as a white solid.

EXAMPLE 2

The compounds of the present invention are useful agents for the detection of microorganisms containing oxidative enzymes, e.g. of the type used to oxidize steroids. Thus, cells of the microorganisms being investigated are grown for about 24 hours in a suitable medium (e.g. heart infusion broth with glucose, yeast-malt medium) on a shaker (e.g. at 28° or 37° C.). The cells from 10 ml. are obtained by centrifugation and added to 2 ml. of substrate solution at each of various pH's such as 5 and 7, e.g. to a solution of 500 mcg./ml. phenoxyethylpenicillin aldehyde (IV) in 20% acetone-80% 0.2 molar pH 5 citrate buffer. That mixture of cells and substrate is then returned to the shaker for a short period of time (e.g. four hours). Aliquots are taken, diluted (e.g. ten-, fifty- and one hundred-fold) and assayed by a typical penicillin assay, e.g. by the disc method on an agar plate seeded with *B. subtilis*; activity in this assay indicates the presence of

Penicillin V Aldehyde (6-Phenoxyacetamidopenicillanal).

(1) 6-phenoxyacetamidopenicillanic thiol acid, *N,N'-di-benzylethylenediamine (DBED) salt*. — A mixture of 38.0 g. (0.985 mole) of penicillin V potassium salt, 20.6 g. of triethylamine hydrochloride (0.15 mole) and 1400 ml. of methylene chloride was stirred for 1/2 hour at 25°. Most of the methylene chloride was then removed under vacuum at 30°. Dimethylformamide (DMF), 500 ml., was then added and the mixture was cooled to -4°. Ethyl chloroformate, 9.38 ml. (0.0985 mole), was added and the temperature immediately rose to +2.5°. The mixture was stirred and cooled down to -5° during the next ten minutes forming the mixed anhydride. A solution of 22 g. (0.2 mole) of sodium hydrosulfide (hydrated) in 350 ml. of DMF was prepared by stirring for ten minutes at room temperature under a nitrogen atmosphere. The solution was a turbid yellow, but all chunks of the salt had disappeared at this time. The solution of sodium hydro-

sulfide was poured into the mixed anhydride solution, and the resulting dark mixture was stirred at +10° to 0° for ten minutes forming the thio acid. The reaction mixture was immediately poured into 3700 ml. of ice water, acidified to pH <2 with ca. 50 ml. of 6 N H₂SO₄, and extracted with two 1500 ml. portions of ice-cold ether. The combined yellow ether extracts were washed twice with 75 ml. portions of ice water, and then extracted with two 200 ml. portions of 4.25% NaHCO₃ solution which carried the yellow color into the aqueous layer. The combined basic extracts were added to a solution of 36 g. (0.1 mole) of N,N'-dibenzylethylenediamine diacetate in 200 ml. of water forming the bis salt of the thio acid. The title compound crystallized when all of the dissolved ether was removed under vacuum. It was filtered off, dried briefly on the filter, then placed in a 2-liter round-bottom flask. Acetone, 100 ml., was added followed by 200 ml. of ethyl acetate and the mixture was flashed to dryness at 33° thereby removing the remaining traces of water. The yellow solid was partly dissolved in 50 ml. of dry acetone, diluted with one liter of dry ether and filtered off and dried under vacuum. Yield, 39.5 g. Its infrared spectrum showed NH (3350), intense β -lactam (1760), amide (1670 and 1495), —COS^g (1510) and phenyl absorptions at 1590, 750 and 695 cm.⁻¹.

(2) 3-(1,3-dibenzyl - 2 - imidazolidinyl)-2,2-dimethyl-6-phenoxyacetamidopenam.—Commercial Raney active nickel catalyst, No. 28, 25 g. (wet weight) was washed three times with 55 ml. portions of absolute ethanol, and then with four 55 ml. portions of tetrahydrofuran (THF). The washing procedure is speeded materially if a bar magnet is used to pull the nickel to the bottom of the breaker after each wash. The nickel was then suspended in 100 ml. of THF and 2.1 ml. (0.035 mole) of glacial acetic acid and 1.2 g. (0.0050 mole) of N,N'-dibenzylethylenediamine (DBED) was added and the suspension was stirred and cooled to 5°. A cooled (5°) solution of 4.86 g. (0.0100 mole) of pen V thiol DBED salt in 40 ml. of THF was added and the mixture was stirred at 2° for 3/4 hour. The yield and quality of product may possibly be substantially improved by reducing this reaction time to about 15 minutes. The mixture was filtered over diatomaceous earth ("Supercel") and the catalyst was washed with four 30 ml. portions of THF. The THF was removed under vacuum at 33° and the dark residue was dissolved in 300 ml. of ether. A considerable amount of gum failed to dissolve. On addition of 50 ml. of water, part of the gum dissolved. In some runs a pink solid separated at this point and was filtered off. The water layer was separated and the ether solution was extracted successively with two 30 ml. portions of 5% acetic acid, 50 ml. of water, three 30 ml. portions of 5% sodium bicarbonate and three 30 ml. portions of water. The ether solution was dried briefly over sodium sulfate, treated with decolorizing carbon and filtered over "Supercel" which gave a nearly colorless filtrate. The solvent was flashed off at 33°, the residue was flashed with two 100 ml. portions of chloroform to remove moisture and then thoroughly dried over phosphorus pentoxide at 0.5 mm. The yield of the titled compound was 2.23 g. of a hard gum.

(A similar procedure yielded the N,N'-diphenylimidazolidinyl analog of the title compound which was obtained as a crystalline solid, M.P. 174-176° sl. dec.)

Analysis.—Calc'd. for C₃₉H₅₂N₄O₅S: C, 68.15; H, 6.10. Found: C, 67.90; H, 6.20.

The infrared spectra of the two imidazolidines were very similar.

(3) 6-phenoxyacetamidopenicillanal.—A solution of 2.23 g. (4.00 millimole) of the above N,N'-dibenzyl-imidazolidine in 15 ml. of dry acetone and 45 ml. of ether was treated all at once with a solution of 1.67 g. (8.80 millimole) of p-toluenesulfonic acid monohydrate in 7.5 ml. of acetone and 22.5 ml. of ether. A heavy pre-

5 cipitate formed instantly. The suspension was stirred for 15 minutes at 25° and then filtered. Addition of 1 ml. of the same toluenesulfonic acid solution to the filtrate produced no further precipitate, so the filtrate was extracted twice with 25 ml. portions of water (the first extract was strongly acidic, the second much less acidic), once with 20 ml. of 2% sodium bicarbonate and again with 20 ml. of water. The ethereal solution was dried over sodium sulfate, treated with decolorizing carbon, and filtered over "Supercel." Removal of the solvent and through drying under vacuum yielded 1.10 g. of the product, 6-phenoxyacetamidopenicillanal, as a very hard, almost glassy gum. Its infrared spectrum (in methylene chloride) showed a weak OH (3500), NH (3370), intense 10 β -lactam (1780), medium —CHO (1730), intense amide (1690 and 1510), phenyl (1595, 1590 and 1490) and phenyl—O—C (1230). Its NMR spectrum (in CDCl₃) showed all of the expected sharp resonance lines.

EXAMPLE 3

6-(3-phenyl-5-methylisoxazole-4-carboxamido)penicillanal.—One hundred grams of wet No. 28 commercial Raney Ni (Raney Co.) was washed three times with 100 ml. portions of absolute ethanol, three times with 100 ml. portions of acetone and finally a fourth portion of 100 ml. of acetone was added and the slurry cooled and stirred at 0° to 5° C. while 7 g. of N,N'-diphenylethylenediamine, 2.4 ml. of glacial acetic acid and a solution of 10 g. of freshly prepared triethylammonium thiol oxacillin [triethylammonium 6-(5-methyl-3-phenylisoxazole-4-carboxamido)thiopenicillanate] in 50 ml. of acetone was added in that order. These were added at such a rate as not to exceed 5° C. The slurry was stirred 1/2 hour at 2° C., filtered and the Raney Ni sludge washed with 4× 50 ml. portions of acetone. The combined filtrates were evaporated to dryness at 25° C. under reduced pressure and the resulting oil dissolved in 500 ml. of dry ether, filtered and the ether washed with 3× 100 ml. of 5% H₃PO₄, 3× 100 ml. H₂O, 3× 100 ml. of 5% NaHCO₃ and 3× 100 ml. water. The ether solution was then dried briefly over Na₂SO₄, filtered and treated with a concentrated solution of p-toluenesulfonic acid in acetone until the solution was strongly acid to moist pH paper after stirring for 5 minutes. The crystalline amine salt was then filtered off and the ether filtrate washed with 3× 100 ml. water, 3× 100 ml. 5% NaHCO₃ and 3× 100 ml. of water. The ether solution was dried over Na₂SO₄ briefly; filtered and stripped to dryness under high vacuum until the product, 6-(3-phenyl-5-methylisoxazole-4-carboxamido)penicillanal, was obtained as a frothy solid which was scraped out of the flask and found to weigh 2.5 g.

Analysis.—Calc'd. for C₁₉H₁₉N₃O₄S: C, 59.25%; H, 4.96%; N, 10.9%. Found: C, 59.70%; H, 5.61%; N, 9.84%.

EXAMPLE 4

Penicillin G aldehyde (6-phenoxyacetamidopenicillanal).—To a precooled, stirred suspension of 13.08 g. (0.03 mole) of penicillin G-triethylammonium salt in 200 ml. of dimethylformamide (DMF) was added 3.24 g. (0.03 mole) of ethyl chloroformate dropwise over a 20-minute period. The resulting nearly clear solution was then treated all at once with 3 g. of NaSH in 50 ml. of DMF which had been previously dissolved by pulverizing in a mortar and stirred and cooled in an ice bath until a cloudy solution had been obtained. The resulting

11

dark green reaction mixture was stirred one-half hour with the ice bath removed and poured into a mixture of 500 ml. benzene, one liter of crushed ice in water and 30 ml. of 40% H_3PO_4 . The benzene extract was washed three times with cold water and partially dried by filtering through sodium sulfate. The benzene was then removed under reduced pressure on the flash evaporator and when the benzene was nearly all removed (avoiding heating) the resulting oil was dissolved in 50 ml. of dry acetone and added immediately, dropwise, to a previously prepared stirred suspension of 100 g. of No. 28 commercial Raney Ni (Raney Co.), [previously washed 3X with absolute ethanol and 4X with dry acetone (200 ml. portions)], 300 ml. of acetone, 10.5 g. of N,N'-diphenylethylenediamine and 3.6 ml. of glacial acetic acid at 2.0° C. The addition took five minutes and the temperature rose to 4° C. After stirring an additional 1/2 hour the Raney Ni was filtered off through "Supercel" filter aid and the Raney Ni sludge was washed 4X with 100 ml. portions of acetone. The combined filtrates were evaporated to an oil on the flash evaporator and dissolved in one liter of ether; a precipitate was then filtered off and the ether solution was extracted 3X with 5% H_3PO_4 (100 ml.), 3X with water (100 ml.), 3X with 5% $NaHCO_3$ (100 ml.) and 3X with water. The ether solution was dried briefly over Na_2SO_4 , filtered and evaporated under reduced pressure to an oil. The oil was then dissolved in 100 ml. of acetone and 900 ml. of ether added. To this solution was added 6 g. of p-toluenesulfonic acid trihydrate dissolved in 50 ml. of acetone and the resulting slurry stirred for ten minutes, filtered and the filtrate washed three times with 200 ml. of water. The ether solution was dried briefly over Na_2SO_4 , filtered, stripped to dryness and dissolved in 300 ml. of CH_2Cl_2 and stripped again followed by pumping at high vacuum (0.1 mm. Hg). The resulting product, penicillin G aldehyde, was thus obtained as a frothy solid which was scraped out, dried over P_2O_5 under vacuum and found to weight 5.6 g.

Alternate procedure.—Same as above except the potassium salt of penicillin G-thiol acid was used; yield, 1 g.

Analysis.—Calc'd. for $C_{16}H_{18}N_2O_3S$: C, 60.3%; H, 5.70%; N, 8.79%. Found: C, 59.8%; H, 6.18%; N, 8.03%.

Alternate procedure.—Same as above except N,N'-dibenzylethylenediamine was used in place of N,N'-diphenylethylenediamine and dilute (2%) acetic acid was used in place of H_3PO_4 in the acid washes. Tetrahydrofuran was used as solvent for the reaction and the DBED salt of the thiol-penicillin G was used. The yield was 27 g. (60%) of the crude dibenzylimidazolidine and the aldehyde was liberated as before with p-toluenesulfonic acid. The aldehyde was the same as in previous runs by infrared spectrum. The yield in this experiment was approximately 50%, an improvement over the methods given above.

EXAMPLE 5

Phenethicillin aldehyde (6 - α - phenoxypropionamido-penicillan or α-phenoxyethylpenicillin aldehyde).—Fifty grams of wet Raney nickel was washed three times with 100 ml. portions of absolute ethanol and three times with 100 ml. portions of dry acetone and finally 100 ml. of dry acetone was added and, while cooling to 0° there was added 4.24 g. (0.02 mole) N,N'-diphenylethylenediamine and 2.4 ml. glacial acetic acid. To this cooled and stirred slurry there was added all at once a cooled partial solution of 9.4 g. (0.02 mole of potassium thio-phenethicillin (potassium 6-α-phenoxypropionamido-thiopenicillanate) in 100 ml. acetone and 2.4 ml. glacial acetic acid. The temperature rose to 6° C. and after stirring 30 minutes at 0° C. the Raney nickel was removed by filtration and

12

washed four times with 50 ml. portions of acetone. The combined filtrates were flash-distilled to dryness under reduced pressure at 20° C. to leave the expected imidazole as a purple oil which was triturated with 500 ml. dry ether and filtered. The ethereal filtrate was washed three times with 100 ml. portions of water, three times with 100 ml. portions of 2% $NaHCO_3$ solution and three times with water and dried over Na_2SO_4 . To the dry ethereal filtrate there was then added a solution of p-toluenesulfonic acid (5 g. in 50 ml. acetone) until the solution was acidic to wet pH paper. The solid p-toluenesulfonic acid salt of N,N'-diphenylethylenediamine which precipitated was removed by filtration and the filtrate was treated as before with the acid repeatedly until no more solid formed upon addition of acid and the ethereal solution was still acidic to wet filter paper after standing ten minutes. The ethereal solution containing the product, phenethicillin aldehyde, was then washed with 2% $NaHCO_3$ and water, dried, filtered and the solvent was removed by distillation to dryness under high vacuum to leave the product as a frothy, amorphous solid weighing 2.9 g. and having an infrared absorption spectrum consistent with the structure given above.

Analysis.—Calc'd. for $C_{17}H_{20}N_2O_4S$: C, 58.6; H, 5.80; N, 8.06. Found: C, 58.9; H, 6.13; N, 7.52.

EXAMPLE 6

Benzylxypenicillin aldehyde (6 - N - carbobenzoyloxy-aminopenicillan).—To 45 g. of previously acetone-washed Raney nickel suspended in 100 ml. of acetone with 3.7 g. (0.0174 mole) N,N'-diphenylethylenediamine and 2.1 ml. of glacial acetic acid, was added 7 g. (0.0174 mole) of benzylxypenicillin thiol (potassium salt) dissolved in 25 ml. of acetone and 3 ml. of glacial acetic acid. The mixture was stirred for one hour in an ice-bath and the mixture was filtered. The filtrate was evaporated to an oil under reduced pressure at 30° and residue was slurried with 100 ml. of ether. The ether was washed twice with dilute sodium bicarbonate and several times with water. The ether was dried over anhydrous magnesium sulfate. The drying agent was separated and the ether solution treated with a solution of p-toluenesulfonic acid in acetone until there was no more turbidity. The N,N'-diphenylethylenediamine toluenesulfonate was collected and the filtrate was washed with water and dried over anhydrous $MgSO_4$. The solvent was evaporated under reduced pressure to yield 1.5 g. of neutral benzylxypenicillin aldehyde.

EXAMPLE 7

6 - phthalimidopenicillin aldehyde (6 - phthalimidopenicillan).—To a solution of 5.0 g. (0.015 mole) of 6-phthalimidopenicillanyl alcohol in 50 ml. of anhydrous dimethylsulfoxide was added 10.0 g. (0.049 mole) of dicyclohexylcarbodiimide and 1.5 g. (0.0075 mole) of pyridinium trifluoracetate. The mixture was swirled in an Erlenmeyer flask for a few seconds, placed in a desiccator under a nitrogen atmosphere, allowed to stand at 25° C. for 17 hours and then filtered and the filtrate thrown into 500 ml. of 50:50 chloroform-water and shaken. The chloroform layer was separated, washed with water and dried over $MgSO_4$ for two hours. The chloroform solution was then filtered and evaporated to

leave an oily liquid whose NMR spectrum showed strong absorption attributed to aldehyde proton in the region of 9.5 τ as well as absorption due to several contaminants including starting materials. The oil was dissolved in chloroform, 100 ml., and 50 ml. portions of petroleum ether were added to precipitate four fractions of solid. The mother liquor was taken and concentrated in vacuo to give the product, 6-phthalimidopenicillan aldehyde (6-phthalimidopenicillan), as a foamy solid. The NMR of this foam showed it to be 80-90% pure aldehyde.

EXAMPLE 8

6-(5 - methyl - 3 - o-chlorophenylisoxazole-4-carboxamido)penicillan [5-methyl-3-o-chlorophenyl - 4 - isoxazolylpenicillin aldehyde.—Twenty-five g. (wet weight) of Raney nickel, No. 28 was washed three times with 55 ml. portions of 100% ethanol, followed by four washings with 55 ml. portions of tetrahydrofuran (THF). The nickel was then suspended in 100 ml. THF and cooled to -4° and to this there was added 2.1 ml. glacial acetic acid. Potassium 6-(5-methyl-3-o-chlorophenylisoxazole-4-carboxamido)thiopenicillanate (4.5 g.) was dissolved completely in 40 ml. THF and added to the Raney nickel. The reaction mixture was stirred below 0° for 15 minutes. The Raney nickel was then filtered through diatomaceous earth and washed five times with 60 ml. portions of THF. The filtrate was evaporated to dryness. The resulting oil was partially dissolved in 350 ml. ether. A pink gum appeared which was carried along with the ether. The ether was then extracted three times with 60 ml. portions of 5% NaHCO₃ and three times with 40 ml. portions of water. The ether layer was then separated from the gum and dried over magnesium sulfate and charcoal. After filtration the ether was evaporated to dryness. The resulting oil could be solidified by dissolving it in methylene chloride or ether and precipitating with n-pentane. The product, 6-(5-methyl-3-o-chlorophenylisoxazole-4-carboxamido)penicillan [5 - methyl-3-o-chlorophenyl-4-isoxazolylpenicillin aldehyde], precipitated as an amorphous solid, yield 150 mgm. Both IR and NMR spectra showed all of the expected absorptions.

EXAMPLE 9

In the procedure of Example 5 the potassium thiopheneticillin is replaced by an equimolar amount of the potassium salt of the acids

- 6-[α -(2-chlorophenoxy)propionamido] thiopenicillanic acid,
- 6-[α -(4-sulfamylphenoxy)-n-butyramido] thiopenicillanic acid,
- 6-[α -(3,4-dimethoxyphenoxy)-n-pentanoamido] thiopenicillanic acid,
- 6-[α -(3-methylphenoxy)isovaleramido] thiopenicillanic acid,
- 6-[α -(4-methylthiophenoxy)propionamido] thiopenicillanic acid,
- 6-[α -(4-dimethylaminophenoxy)-n-hexanoamido] thiopenicillanic acid,
- 6-[α -(2-methoxyphenoxy)-n-decanoamido] thiopenicillanic acid,
- 6-[α -(2,4-dichlorophenoxy)phenylacetamido] thiopenicillanic acid,
- 6-[α -(2-nitrophenoxy)- β -phenylpropionamido] thiopenicillanic acid,
- 6-[α -(2-acetamidophenoxy)- γ -phenylbutyramido] thiopenicillanic acid,
- 6-[α -(2,4-dimethylphenoxy)-n-butyramido] thiopenicillanic acid,
- 6-[α -(4-isopropylphenoxy)propionamido] thiopenicillanic acid,
- 6-[α -(3-bromophenoxy)-n-butyramido] thiopenicillanic acid,
- 6-[α -(2-iodophenoxy)phenylacetamido] thiopenicillanic acid,
- 6-[α -(2-diethylaminophenoxy)isovaleramido] thiopenicillanic acid,
- 6-[α -(3,5-dichlorophenoxy)isohexanoamido] thiopenicillanic acid,
- 6-[α -(4-cyclohexylphenoxy)propionamido] thiopenicillanic acid,
- 6-[α -phenoxy-isovaleramido] thiopenicillanic acid,
- 6-[α -phenoxy-n-decanoamido] thiopenicillanic acid,
- 6-[α -phenoxy- γ -phenylbutyramido] thiopenicillanic acid,
- 6-[α -(2-benzylphenoxy)-n-butyramido] thiopenicillanic acid,
- 6-[α -(2-trifluoromethylphenoxy)propionamido] thiopenicillanic acid, and
- 6-[α -(4-fluorophenoxy)propionamido] thiopenicillanic acid,

14

- 6-[α -(2,4-dimethylphenoxy)-n-butyramido] thiopenicillanic acid,
  - 6-[α -(4-isopropylphenoxy)propionamido] thiopenicillanic acid,
  - 5 6-[α -(3-bromophenoxy)-n-butyramido] thiopenicillanic acid,
  - 6-[α -(2-iodophenoxy)phenylacetamido] thiopenicillanic acid,
  - 6-[α -(2-diethylaminophenoxy)isovaleramido] thiopenicillanic acid,
  - 10 6-[α -(3,5-dichlorophenoxy)isohexanoamido] thiopenicillanic acid,
  - 6-[α -(4-cyclohexylphenoxy)propionamido] thiopenicillanic acid,
  - 15 6-[α -phenoxy-isovaleramido] thiopenicillanic acid,
  - 6-[α -phenoxy-n-decanoamido] thiopenicillanic acid,
  - 6-[α -phenoxy- γ -phenylbutyramido] thiopenicillanic acid,
  - 20 6-[α -(2-benzylphenoxy)-n-butyramido] thiopenicillanic acid,
  - 6-[α -(2-trifluoromethylphenoxy)propionamido] thiopenicillanic acid, and
  - 25 6-[α -(4-fluorophenoxy)propionamido] thiopenicillanic acid,
- respectively, to produce
- 6-[α -(2-chlorophenoxy)propionamido]penicillan,
  - 30 6-[α -(4-sulfamylphenoxy)-n-butyramido]penicillan,
  - 6-[α -(3,4-dimethoxyphenoxy)-n-pentanoamido] penicillan,
  - 6-[α -(3-methylphenoxy)isovaleramido] penicillan,
  - 35 6-[α -(4-methylthiophenoxy)propionamido] penicillan,
  - 6-[α -(4-dimethylaminophenoxy)-n-hexanoamido] penicillan,
  - 40 6-[α -(2-methoxyphenoxy)-n-decanoamido] penicillan,
  - 6-[α -(2,4-dichlorophenoxy)phenylacetamido] penicillan,
  - 6-[α -(2-nitrophenoxy)- β -phenylpropionamido] penicillan,
  - 45 6-[α -(2-acetamidophenoxy)- γ -phenylbutyramido] penicillan,
  - 6-[α -(2,4-dimethylphenoxy)-n-butyramido] penicillan,
  - 6-[α -(4-isopropylphenoxy)propionamido] penicillan,
  - 50 6-[α -(3-bromophenoxy)-n-butyramido] penicillan,
  - 6-[α -(2-iodophenoxy)phenylacetamido] penicillan,
  - 6-[α -(2-diethylaminophenoxy)isovaleramido] penicillan,
  - 55 6-[α -(3,5-dichlorophenoxy)isohexanoamido] penicillan,
  - 6-[α -(4-cyclohexylphenoxy)propionamido] penicillan,
  - 60 6-[α -phenoxy-isovaleramido] penicillan,
  - 6-[α -phenoxy-n-decanoamido] penicillan,
  - 6-[α -phenoxy- γ -phenylbutyramido] penicillan,
  - 65 6-[α -(2-benzylphenoxy)-n-butyramido] penicillan,
  - 6-[α -(2-trifluoromethylphenoxy)propionamido] penicillan, and
  - 70 6-[α -(4-fluorophenoxy)propionamido] penicillan,
- respectively, each of which is isolated as a solid which is converted to an active antibacterial agent upon exposure to an oxidative enzyme system.

15

EXAMPLE 10

In the procedure of Example 5 the potassium thiophenothicillin is replaced by an equimolar amount of the potassium salt of the acids,

5-(α -phenylthiopropionamido)thiopenicillanic acid,
5-(α -paranitrophenylthiopropionamide)thiopenicillanic acid,
5-(α -parachlorophenylthiopropionamido)thiopenicillanic acid,
5-(α -phenylthiobutyramido)thiopenicillanic acid,
6-(α -phenylthiopropanamide)thiopenicillanic acid,
6-(α -phenylthioisovaleramido)thiopenicillanic acid,
6-[α -(4-t-butylphenylthio)propionamido]thiopenicillanic acid,
6-[α -ortho-tolylthiopropionamido]thiopenicillanic acid,
6-(α -ortho-nitrophenylthiopropionamido)thiopenicillanic acid,
6-(α -parachlorophenylthiobutyramido)thiopenicillanic acid,
6-[α -(3,4,5-trichlorophenylthio)propionamide]thiopenicillanic acid,
6-[α -(3-trifluoromethylphenylthio)butyramido]thiopenicillanic acid,
6-(α -parabromophenylthioisovaleramido)thiopenicillanic acid,
6-(α -paraphenylphenylthiopropionamido)thiopenicillanic acid,
6-[α -(4-methoxyphenylthio)caproamido]thiopenicillanic acid,
6-[α -(4-cyclohexylphenylthio)butyramido]thiopenicillanic acid,
6-(α -phenylthio- α -cyclohexylacetamido)thiopenicillanic acid,
6-(α -phenylthio- α -cyclopentylacetamide)thiopenicillanic acid,
6-[α -(2,4-dichlorophenylthio)caproamido]thiopenicillanic acid,
6-[α -(2,4-diisoamylphenylthio)propionamido]thiopenicillanic acid,
6-[α -(4-benzylphenylthio)propionamido]thiopenicillanic acid,
6-[α -(4-sulfamylphenylthio)butyramido]thiopenicillanic acid,
6-[α -(2-allyloxyphenylthio)propionamido]thiopenicillanic acid,
6-[α -(4-allylphenylthio)isovaleramido]thiopenicillanic acid,
6-[α -(4-dimethylaminophenylthio)propionamido]thiopenicillanic acid,
6-[α -(2,5-dichlorophenylthio)butyramido]thiopenicillanic acid,
6-[α -(2-iodophenylthio)propionamido]thiopenicillanic acid,
6-[α -(2-acetamidophenylthio)propionamido]thiopenicillanic acid,
6-[α -(4-diethylaminophenylthio)propionamido]thiopenicillanic acid, and
6-[α -(3-fluorophenylthio)butyramido]thiopenicillanic acid.

respectively, to produce

- 6-(α -phenylthiopropionamido) penicillanal,
- 6-(α -paranitrophenylthiopropionamido) penicillanal,
- 6-(α -parachlorophenylthiopropionamido) penicillanal,
- 6-(α -phenylthiobutyramido) penicillanal,
- 6-(α -phenylthiocaproamido) penicillanal,
- 6-(α -phenylthiovaleramido) penicillanal,
- 6-[α -(4-t-butylphenylthio) propionamido] penicillanal,
- 6-[α -ortho-tolylthiopropionamido] penicillanal,
- 6-(α -ortho-nitrophenylthiopropionamido) penicillanal,
- 6-(α -parachlorophenylthiobutyramido) penicillanal,
- 6-[α -(3,4,5-trichlorophenylthio) propionamido] penicillanal,
- 6-[α -(3-trifluoromethylphenylthio) butyramido] penicillanal,

16

6-(α -parabromophenylthioisovaleramido)penicillanal,
 6-(α -paraphenylphenylthiopropionamido)penicillanal,
 6-[α -(4-methoxyphenylthio)caproamido]penicillanal,
 6-[α -(4-cyclohexylphenylthio)butyramido]penicillanal,
 5 6-(α -phenylthio- α -cyclohexylacetamido)penicillanal,
 6-(α -phenylthio- α -cyclopentylacetamido)penicillanal,
 6-[α -(2,4-dichlorophenylthio)caproamido]penicillanal,
 6-[α -(2,4-disacamylphenylthio)propionamido]
 penicillanal,
 10 6-[α -(4-benzylphenylthio)propionamido]penicillanal,
 6-[α -(4-sulfamylphenylthio)butyramido]penicillanal,
 6-[α -(2-allyloxyphenylthio)propionamido]penicillanal,
 6-[α -(4-allylphenylthio)isovaleramido]penicillanal,
 6-[α -(4-dimethylaminophenylthio)propionamido]
 15 penicillanal,
 6-[α -(2,5-dichlorophenylthio)butyramido]penicillanal,
 6-[α -(2-iodophenylthio)propionamido]penicillanal,
 6-[α -(2-acetamidophenylthio)propionamido]penicillanal,
 6-[α -(4-diethylaminophenylthio)propionamido]
 20 penicillanal, and
 6-[α -(3-fluorophenylthio)butyramido]penicillanal,
 respectively, each of which is isolated as a solid which is
 converted to an active antibacterial agent upon exposure
 to an oxidative enzyme system.
 25

EXAMPLE 11

In the procedure of Example 5 the potassium thio-phenethicillin is replaced by an equimolar amount of the
 30 potassium salt of the acids,

D,L-6-[α -amino-(3-thienyl)acetamido]thiopenicillanic acid,
 6-[α -amino-(5-ethyl-2-thienyl)acetamido]thiopenicillanic acid,
 35 6-[α -amino-(5-methyl-2-thienyl)acetamido]
 thiopenicillanic acid,
 6-[α -amino-(5-t-butyl-2-thienyl)acetamido]
 thiopenicillanic acid,
 40 6-[α -amino-(2,5-dimethyl-3-thienyl)acetamido]
 thiopenicillanic acid,
 6-[α -amino-(5-chloro-2-thienyl)acetamido]
 thiopenicillanic acid,
 45 6-[α -amino-(5-bromo-2-thienyl)acetamido]
 thiopenicillanic acid,
 6-[α -amino-(5-phenyl-3-chloro-2-thienyl)acetamido]
 thiopenicillanic acid,
 6-[α -amino-(3,5-dimethyl-2-thienyl)acetamido]
 thiopenicillanic acid
 50 6-[α -amino-(5-cyclohexyl-2-thienyl)acetamido]
 thiopenicillanic acid,
 6-[α -amino-(5-diethylamino-2-thienyl)acetamido]
 thiopenicillanic acid,
 6-[α -amino-(4-methylsulfonyl-2-thienyl)acetamido]
 thiopenicillanic acid,
 55 6-[α -amino-(3-ethylthio-2-thienyl)acetamido]
 thiopenicillanic acid, and
 6-[α -amino-(4-cycloheptyloxy-2-thienyl)acetamido]
 thiopenicillanic acid,

respectively, to produce

60 D,L-6-[α -amino-(3-thienyl)acetamido]penicillanal,
 6-[α -amino-(5-ethyl-2-thienyl)acetamido]penicillanal,
 6-[α -amino-(5-methyl-2-thienyl)acetamido]penicillanal,
 6-[α -amino-(5-t-butyl-2-thienyl)acetamido]penicil-
 lanal,
 6-[α -amino-(2,5-dimethyl-3-thienyl)acetamido]penicil-
 lanal,
 6-[α -amino-(5-chloro-2-thienyl)acetamido]penicillanal,
 6-[α -amino-(5-bromo-2-thienyl)acetamido]penicillanal,
 70 6-[α -amino-(5-phenyl-3-chloro-2-thienyl)acetamido]
 penicillanal,
 6-[α -amino-(3,5-dimethyl-2-thienyl)acetamido]penicil-
 lanal,
 6-[α -amido-(5-cyclohexyl-2-thienyl)acetamido]penicil-
 lanal,
 75

- 6-[α -amino-(5-diethylamino-2-thienyl)acetamido]penicillanal,
 6-[α -amino-(4-methylsulfonyl-2-thienyl)acetamido]penicillanal,
 6-[α -amino-(3-ethylthio-2-thienyl)acetamido]penicillanal, and
 6-[α -amino-(4-cycloheptyloxy-2-thienyl)acetamido]penicillanal,

respectively, each of which is isolated as a solid which is converted to an active antibacterial agent upon exposure to an oxidative enzyme system.

EXAMPLE 12

In the procedure of Example 5 the potassium thiopenethicillin is replaced by an equimolar amount of the potassium salt of the acids

- 6-(α -amino-p-chlorophenylacetamido)thiopenicillanic acid,
 6-(α -amino-p-methoxyphenylacetamido)thiopenicillanic acid,
 6-[L-(+)- α -aminophenylacetamido]thiopenicillanic acid,
 6-(α -amino-4-diethylaminophenylacetamido)thiopenicillanic acid,
 6-(α -amino-4-trifluoromethylphenylacetamido)thiopenicillanic acid,
 6-(α -amino-2,4-dibromophenylacetamido)thiopenicillanic acid,
 6-(α -amino-2-nitrophenylacetamido)thiopenicillanic acid,
 6-(α -amino-3-methylphenylacetamido)thiopenicillanic acid,
 6-(α -amino-4-sulfamylphenylacetamido)thiopenicillanic acid,
 6-(α -amino-2-iodophenylacetamido)thiopenicillanic acid,
 6-(α -amino-4-t-butylphenylacetamido)thiopenicillanic acid,
 6-(α -amino-2-acetamidophenylacetamido)thiopenicillanic acid,
 6-(α -amino-3-nitrophenylacetamido)thiopenicillanic acid,
 6-(α -amino-3,4-dimethoxyphenylacetamido)thiopenicillanic acid,
 6-(α -amino-4-dimethylaminophenylacetamido)thiopenicillanic acid,
 6-(α -amino-2,4-dichlorophenylacetamido)thiopenicillanic acid,
 6-(α -amino-4-isopropylphenylacetamido)thiopenicillanic acid,
 6-(α -amino-3-bromophenylacetamido)thiopenicillanic acid,
 6-(α -amino-3-iodophenylacetamido)thiopenicillanic acid,
 6-(α -amino-2-diethylaminophenylacetamido)thiopenicillanic acid,
 6-(α -amino-2-trifluoromethylphenylacetamido)thiopenicillanic acid,
 6-(α -amino-4-fluorophenylacetamido)thiopenicillanic acid, and
 6-(α -amino-3,4,5-trifluoromethylphenylacetamido)thiopenicillanic acid,

respectively, to produce

- 6-(α -amino-p-chlorophenylacetamido)penicillanal,
 6-(α -amino-p-methoxyphenylacetamido)penicillanal,
 6-[L-(+)- α -aminophenylacetamido]penicillanal,
 6-(α -amino-4-diethylaminophenylacetamido)penicillanal,
 6-(α -amino-4-trifluoromethylphenylacetamido)penicillanal,
 6-(α -amino-2,4-dibromophenylacetamido)penicillanal,
 6-(α -amino-2-nitrophenylacetamido)penicillanal,
 6-(α -amino-3-methylphenylacetamido)penicillanal,
 6-(α -amino-4-sulfamylphenylacetamido)penicillanal,
 6-(α -amino-2-iodophenylacetamido)penicillanal,
 6-(α -amino-4-t-butylphenylacetamido)penicillanal,
 6-(α -amino-2-acetamidophenylacetamido)penicillanal,
 6-(α -amino-3-nitrophenylacetamido)penicillanal,
 6-(α -amino-3,4-dimethoxyphenylacetamido)penicillanal,
 6-(α -amino-4-dimethylaminophenylacetamido)penicillanal,
 6-(α -amino-2,4-dichlorophenylacetamido)penicillanal,
 6-(α -amino-4-isopropylphenylacetamido)penicillanal,
 6-(α -amino-3-bromophenylacetamido)penicillanal,
 6-(α -amino-3-iodophenylacetamido)penicillanal,
 6-(α -amino-2-diethylaminophenylacetamido)penicillanal,
 6-(α -amino-2-trifluoromethylphenylacetamido)penicillanal,
 6-(α -amino-4-fluorophenylacetamido)penicillanal,
 6-(α -amino-3,4,5-trifluoromethylphenylacetamido)penicillanal,

- 6-(α -amino-3-nitrophenylacetamido)penicillanal,
 6-(α -amino-3,4-dimethoxyphenylacetamido)penicillanal,
 6-(α -amino-4-dimethylaminophenylacetamido)penicillanal,
 6-(α -amino-2,4-dichlorophenylacetamido)penicillanal,
 6-(α -amino-4-isopropylphenylacetamido)penicillanal,
 6-(α -amino-3-bromophenylacetamido)penicillanal,
 6-(α -amino-3-iodophenylacetamido)penicillanal,
 6-(α -amino-2-diethylaminophenylacetamido)penicillanal,
 6-(α -amino-2-trifluoromethylphenylacetamido)penicillanal,
 6-(α -amino-4-fluorophenylacetamido)penicillanal, and
 6-(α -amino-3,4,5-trifluoromethylphenylacetamido)penicillanal,

respectively, each of which is isolated as a solid which is converted to an active antibacterial agent upon exposure to an oxidative enzyme system.

EXAMPLE 13

In the procedure of Example 5 the potassium thiopenethicillin is replaced by an equimolar amount of the potassium salt of the acids

- 6-(n-propylureido)thiopenicillanic acid,
 6-(n-hexylureido)thiopenicillanic acid,
 6-(n-octadecylureido)thiopenicillanic acid,
 6-(cyclohexylureido)thiopenicillanic acid,
 6-(p-chlorophenylureido)thiopenicillanic acid,
 6-(m-methoxyphenylureido)thiopenicillanic acid,
 6-(benzylureido)thiopenicillanic acid,
 6-(cyclopentylureido)thiopenicillanic acid,
 6-(p-tolylureido)thiopenicillanic acid,
 6-(p-dimethylaminophenylureido)thiopenicillanic acid,
 6-(phenylureido)thiopenicillanic acid,
 6-(2-methylphenylureido)thiopenicillanic acid,
 6-(methylureido)thiopenicillanic acid,
 6-(2-nitrophenylureido)thiopenicillanic acid,
 6-(benzoylureido)thiopenicillanic acid,
 6-(4'-nitrobenzoylureido)thiopenicillanic acid,
 6-(2'-chlorobenzoylureido)thiopenicillanic acid,
 6-(2'-methylbenzoylureido)thiopenicillanic acid,
 6-(3',4',5'-trimethoxybenzoylureido)thiopenicillanic acid,
 6-(4'-methylbenzoylureido)thiopenicillanic acid,
 6-(4'-chlorobenzoylureido)thiopenicillanic acid,
 6-(3',4'-dichlorobenzoylureido)thiopenicillanic acid,
 6-(3'-nitrobenzoylureido)thiopenicillanic acid,
 6-(2',4',6'-trimethoxybenzoylureido)thiopenicillanic acid,
 6-(4'-ethoxybenzoylureido)thiopenicillanic acid,
 6-(2',6'-dimethoxybenzoylureido)thiopenicillanic acid,
 6-(2',4',6'-trimethylbenzoylureido)thiopenicillanic acid,
 6-(2',6'-dichlorobenzoylureido)thiopenicillanic acid,
 6-(2',6'-diethoxybenzoylureido)thiopenicillanic acid,
 6-(2',6'-di-n-butoxybenzoylureido)thiopenicillanic acid,
 6-(2',3',6'-trimethoxybenzoylureido)thiopenicillanic acid,
 6-(2',4',6'-tribromobenzoylureido)thiopenicillanic acid,
 6-(2',6'-di-n-propoxybenzoylureido)thiopenicillanic acid,
 6-(2',6'-dimethoxy-4'-methylbenzoylureido)thiopenicillanic acid,
 6-(4',6'-diethyl-2'-methoxybenzoylureido)thiopenicillanic acid,
 6-(2'-ethoxy-6'-methoxybenzoylureido)thiopenicillanic acid,
 6-(2'-phenylbenzoylureido)thiopenicillanic acid,
 6-(2'-methoxybenzoylureido)thiopenicillanic acid,
 6-(2',6'-dimethylbenzoylureido)thiopenicillanic acid,
 6-(2'-chloro-6'-methylbenzoylureido)thiopenicillanic acid,
 6-(2',6'-dimethoxy-3'-nitrobenzoylureido)thiopenicillanic acid,
 6-(3',5'-dichloro-2',6'-dimethoxybenzoylureido)thiopenicillanic acid,
 6-(3',5'-dibromo-2',6'-dimethoxybenzoylureido)thiopenicillanic acid, and
 6-(3'-bromo-2',6'-dimethoxybenzoylureido)thiopenicillanic acid,

-(3'-chloro-2',6'-dimethoxybenzoylureido)thiopenicillanic acid,
 -(3',5'-diido-2',6'-dimethoxybenzoylureido)thiopenicillanic acid,
 -(3'-iodo-2',6'-dimethoxybenzoylureido)thiopenicillanic acid,
 -(4'-trifluoromethylbenzoylureido)thiopenicillanic acid,
 -(4'-isopropylbenzoylureido)thiopenicillanic acid, and
 -(4'-iodobenzoylureido)thiopenicillanic acid,
 respectively, to produce
 -(n-propylureido)penicillanal,
 -(n-hexylureido)penicillanal,
 -(n-octadecylureido)penicillanal,
 -(cyclohexylureido)penicillanal,
 -(p-chlorophenylureido)penicillanal,
 -(m-methoxyphenylureido)penicillanal,
 -(benzylureido)penicillanal,
 -(cyclopentylureido)penicillanal,
 -(p-tolylureido)penicillanal,
 -(p-dimethylaminophenylureido)penicillanal,
 -(phenylureido)penicillanal,
 -(2-methylphenylureido)penicillanal,
 -(methylureido)penicillanal,
 -(2-nitrophenylureido)penicillanal,
 -(benzoylureido)penicillanal,
 -(4'-nitrobenzolureido)penicillanal,
 -(2'-chlorobenzoylureido)penicillanal,
 -(2'-methylbenzoylureido)penicillanal,
 -(3',4',5'-trimethoxybenzoylureido)penicillanal,
 -(4'-methylbenzoylureido)penicillanal,
 -(4'-chlorobenzoylureido)penicillanal,
 -(3',4'-dichlorobenzoylureido)penicillanal,
 -(3'-nitrobenzoylureido)penicillanal,
 -(2',4',6'-trimethoxybenzoylureido)penicillanal,
 -(4'-ethoxybenzoylureido)penicillanal,
 -(2',6'-dimethoxybenzoylureido)penicillanal,
 -(2',4',6'-trimethylbenzoylureido)penicillanal,
 -(2',6'-dichlorobenzoylureido)penicillanal,
 -(2',6'-diethoxybenzoylureido)penicillanal,
 -(2',6'-di-n-butoxybenzoylureido)penicillanal,
 -(2',3',6'-trimethoxybenzoylureido)penicillanal,
 -(2',4',6'-tribromobenzoylureido)penicillanal,
 -(2'-ethoxy-6'-methoxybenzoylureido)penicillanal,
 -(2'-phenylbenzoylureido)penicillanal,
 -(2'-methoxybenzoylureido)penicillanal,
 -(2',6'-dimethylbenzoylureido)penicillanal,
 -(2'-chloro-6'-methylbenzoylureido)penicillanal,
 -(2',6'-dimethoxy-3'-nitrobenzoylureido)penicillanal,
 -(3',5'-dichloro-2',6'-dimethoxybenzoylureido)penicillanal,
 -(3',5'-dibromo-2',6'-dimethoxybenzoylureido)penicillanal,
 -(3'-bromo-2',6'-dimethoxybenzoylureido)penicillanal,
 -(3'-chloro-2',6'-dimethoxybenzoylureido)penicillanal,
 -(3',5'-diido-2',6'-dimethoxybenzoylureido)penicillanal,
 -(3'-iodo-2',6'-dimethoxybenzoylureido)penicillanal,
 -(4'-trifluoromethylbenzoylureido)penicillanal,
 -(4'-isopropylbenzoylureido)penicillanal, and
 -(4'-iodobenzoylureido)penicillanal,

respectively, each of which is isolated as a solid which is converted to an active antibacterial agent upon exposure to an oxidative enzyme system.

EXAMPLE 14

In the procedure of Example 5, the potassium thiophenethicillin is replaced by an equimolar amount of the potassium salt of the acids,

6-(benzamido)thiopenicillanic acid,
 6-(3,5-dinitrobenzamido)thiopenicillanic acid,

6-(2-chlorobenzamido)thiopenicillanic acid,
 6-(2-methylbenzamido)thiopenicillanic acid,
 6-(4-aminobenzamido)thiopenicillanic acid,
 6-(4-nitrobenzamido)thiopenicillanic acid,
 6-(4-hydroxybenzamido)thiopenicillanic acid,
 6-(3,4,5-trimethoxybenzamido)thiopenicillanic acid,
 6-(4-methylbenzamido)thiopenicillanic acid,
 6-(4-chlorobenzamido)thiopenicillanic acid,
 6-(3,4-dichlorobenzamido)thiopenicillanic acid,
 6-(3-nitrobenzamido)thiopenicillanic acid,
 6-(2,4,6-trimethoxybenzamido)thiopenicillanic acid,
 6-(2-hydroxybenzamido)thiopenicillanic acid,
 6-(4-ethoxybenzamido)thiopenicillanic acid,
 6-(2,6-dimethoxybenzamido)thiopenicillanic acid,
 6-(2,4,6-trimethylbenzamido)thiopenicillanic acid,
 6-(2,6-dichlorobenzamido)thiopenicillanic acid,
 6-(2,6-diethoxybenzamido)thiopenicillanic acid,
 6-(2,6-di-n-butoxybenzamido)thiopenicillanic acid,
 6-(2,6-dibenzoyloxybenzamido)thiopenicillanic acid,
 6-(2,3,6-trimethoxybenzamido)thiopenicillanic acid,
 6-(2,4,6-tribromobenzamido)thiopenicillanic acid,
 6-(2,6-di-n-propoxybenzamido)thiopenicillanic acid,
 6-(2,6-dimethoxy-4-methylbenzamido)thiopenicillanic acid,
 6-(4,6-diethyl-2'-methoxybenzoylureido)thiopenicillanic acid,
 6-(2-chloro-3,4,5-trimethoxybenzamido)thiopenicillanic acid,
 6-(4,6-diethyl-2-methoxybenzamido)thiopenicillanic acid,
 6-(6-ethoxy-2-methoxybenzamido)thiopenicillanic acid,
 6-(2-methylthiobenzamido)thiopenicillanic acid,
 6-(2-benzylthiobenzamido)thiopenicillanic acid,
 6-(2-phenoxybenzamido)thiopenicillanic acid,
 6-(pentachlorobenzamido)thiopenicillanic acid,
 6-(2-phenylbenzamido)thiopenicillanic acid,
 6-(2-methoxybenzamido)thiopenicillanic acid,
 6-(4-sulfamylbenzamido)thiopenicillanic acid,
 6-(3,4-dimethoxybenzamido)thiopenicillanic acid,
 6-(4-methoxybenzamido)thiopenicillanic acid,
 6-(3-methylbenzamido)thiopenicillanic acid,
 6-(3-dimethylaminobenzamido)thiopenicillanic acid,
 6-(2-methoxybenzamido)thiopenicillanic acid,
 6-(2-chloro-3,4,5-trimethoxybenzamido)thiopenicillanic acid,
 6-(2,4-dichlorobenzamido)thiopenicillanic acid,
 6-(2-nitrobenzamido)thiopenicillanic acid,
 6-(4-methylaminobenzamido)thiopenicillanic acid,
 6-(2-acetamidobenzamido)thiopenicillanic acid,
 6-(2,4-dimethylbenzamido)thiopenicillanic acid,
 6-(2,4,5-trimethylbenzamido)thiopenicillanic acid,
 6-(4-isopropylbenzamido)thiopenicillanic acid,
 6-(3-bromobenzamido)thiopenicillanic acid,
 6-(2-iodobenzamido)thiopenicillanic acid,
 6-(2-ethylaminobenzamido)thiopenicillanic acid,
 6-(2,5-dihydroxybenzamido)thiopenicillanic acid,
 6-(4-hydroxy-3-methoxybenzamido)thiopenicillanic acid,
 6-(4-allylbenzamido)thiopenicillanic acid,
 6-(4-allyloxybenzamido)thiopenicillanic acid,
 6-(2-trifluoromethylbenzamido)thiopenicillanic acid,
 6-(4-fluorobenzamido)thiopenicillanic acid,
 6-(2-phenylthiobenzamido)thiopenicillanic acid,
 6-(2-benzylbenzamido)thiopenicillanic acid,
 6-(2,6-dihydroxybenzamido)thiopenicillanic acid,
 6-(2,6-diaceetoxybenzamido)thiopenicillanic acid,
 6-(2,6-dimethylthiobenzamido)thiopenicillanic acid,
 6-(2,4,6-trinitrobenzamido)thiopenicillanic acid,
 6-(2,6-diacetamidobenzamido)thiopenicillanic acid,
 6-(2,6-dibromobenzamido)thiopenicillanic acid,
 6-(2,6-dimethylbenzamido)thiopenicillanic acid,
 6-(2,6-diethylbenzamido)thiopenicillanic acid,
 6-(2,6-diisopropylbenzamido)thiopenicillanic acid,
 6-(2,6-diallyloxybenzamido)thiopenicillanic acid,
 6-(3-bromo-2,6-dimethoxybenzamido)thiopenicillanic acid,
 6-(4-chloro-2,6-dimethoxybenzamido)thiopenicillanic acid,
 6-(2-chloro-6-nitrobenzamido)thiopenicillanic acid, and
 6-(2-hydroxy-6-methoxybenzamido)thiopenicillanic acid,

respectively, to produce

- 6-(benzamido)penicillanal,
- 6-(3,5-dinitrobenzamido)penicillanal,
- 6-(2-chlorobenzamido)penicillanal,
- 6-(2-methylbenzamido)penicillanal,
- 6-(4-aminobenzamido)penicillanal,
- 6-(4-nitrobenzamido)penicillanal,
- 6-(4-hydroxybenzamido)penicillanal,
- 6-(3,4,5-trimethoxybenzamido)penicillanal,
- 6-(4-methylbenzamido)penicillanal,
- 6-(4-chlorobenzamido)penicillanal,
- 6-(3,4-dichlorobenzamido)penicillanal,
- 6-(3-nitrobenzamido)penicillanal,
- 6-(2,4,6-trimethoxybenzamido)penicillanal,
- 6-(2-hydroxybenzamido)penicillanal,
- 6-(4-ethoxybenzamido)penicillanal,
- 6-(2,6-dimethoxybenzamido)penicillanal,
- 6-(2,4,6-trimethylbenzamido)penicillanal,
- 6-(2,6-dichlorobenzamido)penicillanal,
- 6-(2,6-diethoxybenzamido)penicillanal,
- 6-(2,6-di-n-butoxybenzamido)penicillanal,
- 6-(2,6-dibenzoyloxybenzamido)penicillanal,
- 6-(2,3,6-trimethoxybenzamido)penicillanal,
- 6-(2,4,6-tribromobenzamido)penicillanal,
- 6-(2,6-di-n-propoxybenzamido)penicillanal,
- 6-(2,6-dimethoxy-4-methylbenzamido)penicillanal,
- 6-(4,6-diethyl-2-methoxybenzamido)penicillanal,
- 6-(6-ethoxy-2-methoxybenzamido)penicillanal,
- 6-(2-methylthiobenzamido)penicillanal,
- 6-(2-benzylthiobenzamido)penicillanal,
- 6-(2-phenoxybenzamido)penicillanal,
- 6-(pentachlorobenzamido)penicillanal,
- 6-(2-phenylbenzamido)penicillanal,
- 6-(2-methoxybenzamido)penicillanal,
- 6-(4-sulfamylbenzamido)penicillanal,
- 6-(3,4-dimethoxybenzamido)penicillanal,
- 6-(4-methoxybenzamido)penicillanal,
- 6-(3-methylbenzamido)penicillanal,
- 6-(3-dimethylaminobenzamido)penicillanal,
- 6-(2-methoxybenzamido)penicillanal,
- 6-(2-chloro-3,4,5-trimethoxybenzamido)penicillanal,
- 6-(2,4-dichlorobenzamido)penicillanal,
- 6-(2-nitrobenzamido)penicillanal,
- 6-(4-methylaminobenzamido)penicillanal,
- 6-(2-acetamidobenzamido)penicillanal,
- 6-(2,4-dimethylbenzamido)penicillanal,
- 6-(2,4,5-trimethylbenzamido)penicillanal,
- 6-(4-isopropylbenzamido)penicillanal,
- 6-(3-bromobenzamido)penicillanal,
- 6-(2-iodobenzamido)penicillanal,
- 6-(2-ethylaminobenzamido)penicillanal,
- 6-(2,5-dihydroxybenzamido)penicillanal,
- 6-(4-hydroxy-3-methoxybenzamido)penicillanal,
- 6-(4-allylbenzamido)penicillanal,
- 6-(4-allyloxybenzamido)penicillanal,
- 6-(2-trifluoromethylbenzamido)penicillanal,
- 6-(4-fluorobenzamido)penicillanal,
- 6-(2-phenylthiobenzamido)penicillanal,
- 6-(2-benzylbenzamido)penicillanal,
- 6-(2,6-dihydroxybenzamido)penicillanal,
- 6-(2,6-diacetoxybenzamido)penicillanal,
- 6-(2,6-dimethylthiobenzamido)penicillanal,
- 6-(2,4,6-trinitrobenzamido)penicillanal,
- 6-(2,6-diacetamidobenzamido)penicillanal,
- 6-(2,6-dibromobenzamido)penicillanal,
- 6-(2,6-dimethylbenzamido)penicillanal,
- 6-(2,6-diethylbenzamido)penicillanal,
- 6-(2,6-diisopropylbenzamido)penicillanal,
- 6-(2,6-diallyloxybenzamido)penicillanal,
- 6-(3-bromo-2,6-dimethoxybenzamido)penicillanal,
- 6-(4-chloro-2,6-dimethoxybenzamido)penicillanal,
- 6-(2-chloro-6-nitrobenzamido)penicillanal, and
- 6-(2-hydroxy-6-methoxybenzamido)penicillanal,

respectively, each of which is isolated as a solid which

is converted to an active antibacterial agent upon exposure to an oxidative enzyme system.

EXAMPLE 15

- 5 In the procedure of Example 5, the potassium thio-phenethicillin is replaced by an equimolar amount of the potassium salt of the acids,
- 6-(N-allyl-N'-phthalamido)thiopenicillanic acid,
  - 6-(N-benzyl-N'-phthalamido)thiopenicillanic acid,
  - 10 6-(N-n-propyl-N'-phthalamido)thiopenicillanic acid,

(N- α -methylphenethyl-N'-phthalamido) penicillanal,
(N-2-methoxyphenyl-N'-phthalamido) penicillanal,
(N-phenyl-N-ethyl-N'-phthalamido) penicillanal,
[N-(2-methyl-5-ethylpiperidino)-N'-phthalamido] penicillanal,
(N-pyrrolidino-N'-phthalamido) penicillanal,
[N-(2-methylpyrrolidino)-N'-phthalamido] penicillanal,
[N-(2,5-dimethylpyrrolidino)-N'-phthalamido] penicillanal,
(N,N-hexamethylene-N'-phthalamido) penicillanal,
[N-(1,1,3,3-tetramethylbutyl)-N'-phthalamido] penicillanal,
(N-cyclohexyl-N'-phthalamido) penicillanal,
[N-(3-morpholinopropyl)-N'-phthalamido] penicillanal,
and
[N-(2-methylpiperidino)-N'-phthalamido] penicillanal,

respectively, each of which is isolated as a solid which is converted to an active antibacterial agent upon exposure to an oxidative enzyme system.

EXAMPLE 16

In the procedure of Example 5, the potassium thio-phenethicillin is replaced by an equimolar amount of the potassium salt of the acids,

5-[α -(2-chlorophenoxy)acetamido]thiopenicillanic acid,
 5-[α -(4-sulfamylphenoxy)acetamido]thiopenicillanic acid,
 5-[α -(3,4-dimethoxyphenoxy)acetamido]thiopenicillanic acid,
 5-[α -(3-methylphenoxy)acetamido]thiopenicillanic acid,
 5-[α -(4-methylthiophenoxy)acetamido]thiopenicillanic acid,
 5-[α -(4-dimethylaminophenoxy)acetamido]thiopenicillanic acid,
 5-[α -(2-methoxyphenoxy)acetamido]thiopenicillanic acid,
 6-[α -(2,4-dichlorophenoxy)phenoxyacetamido]thiopenicillanic acid,
 6-[α -(2-nitrophenoxy)acetamido]thiopenicillanic acid,
 6-[α -(2-acetamidophenoxy)acetamido]thiopenicillanic acid,
 6-[α -(2,4-dimethylphenoxy)acetamido]thiopenicillanic acid,
 6-[α -(4-isopropylphenoxy)acetamido]thiopenicillanic acid,
 6-[α -(3-bromophenoxy)acetamido]thiopenicillanic acid,
 6-[α -(2-iodophenoxy)phenoxyacetamido]thiopenicillanic acid,
 6-[α -(2-diethylaminophenoxy)acetamido]thiopenicillanic acid,
 6-[α -(3,5-dichlorophenoxy)acetamido]thiopenicillanic acid,

6-[α -(4-cyclohexylphenoxy)acetamido]thiopenicillanic acid,
 6-[α -(*o*-phenoxyacetamido)thiopenicillanic acid,
 6-[α -(2-benzylphenoxy)acetamido]thiopenicillanic acid,
 5 6-[α -(2-trifluoromethylphenoxy)acetamido]thiopenicillanic acid,
 6-[α -(4-chlorophenoxy)acetamido]thiopenicillanic acid,
 6-[α -(4-nitrophenoxy)acetamido]thiopenicillanic acid,
 6-[α -(4-bromophenoxy)acetamido]thiopenicillanic acid,
 10 6-[α -(4-*t*-butylphenoxy)acetamido]thiopenicillanic acid,
 6-[α -(4-trifluoromethylphenoxy)acetamido]thiopenicillanic acid,
 6-[α -(3-fluorophenoxy)acetamido]thiopenicillanic acid,
 6-[α -(4-sulfamylphenoxy)acetamido]thiopenicillanic acid,
 15 6-[α -(2-benzylphenoxy)acetamido]thiopenicillanic acid,
 6-[α -(3-methoxyphenoxy)acetamido]thiopenicillanic acid,
 6-[α -(2-iodophenoxy)acetamido]thiopenicillanic acid,
 6-[α -(3-diethylaminophenoxy)acetamido]thiopenicillanic
 20 acid, and
 6-[α -(2,4-diisoamylphenoxy)acetamido]thiopenicillanic acid,

respectively, to produce

25 6-[α -(2-chlorophenoxy)acetamido]penicillanal,
 6-[α -(4-sulfamylphenoxy)acetamido]penicillanal,
 6-[α -(3,4-dimethoxyphenoxy)acetamido]penicillanal,
 6-[α -(3-methylphenoxy)acetamido]penicillanal,
 6-[α -(4-methylthiophenoxy)acetamido]penicillanal,
 30 6-[α -(4-dimethylaminophenoxy)acetamido]penicillanal,
 6-[α -(2-methoxyphenoxy)acetamido]penicillanal,
 6-[α -(2,4-dichlorophenoxy)phenoxyacetamido]penicillanal,
 6-[α -(2-nitrophenoxy)acetamido]penicillanal,
 35 6-[α -(2-acetamidophenoxy)acetamido]penicillanal,
 6-[α -(2,4-dimethylphenoxy)acetamido]penicillanal,
 6-[α -(4-isopropylphenoxy)acetamido]penicillanal,
 6-[α -(3-bromophenoxy)acetamido]penicillanal,
 6-[α -(2-iodophenoxy)phenoxyacetamido]penicillanal,
 40 6-[α -(2-diethylaminophenoxy)acetamido]penicillanal,
 6-[α -(3,5-dichlorophenoxy)acetamido]penicillanal,
 6-[α -(4-cyclohexylphenoxy)acetamido]penicillanal,
 6-(α -phenoxyacetamido)penicillanal,
 6-[α -(2-benzylphenoxy)acetamido]penicillanal,
 45 6-[α -(2-trifluoromethylphenoxy)acetamido]penicillanal,
 6-[α -(1,1,1,1-tetrafluoroethylphenoxy)acetamido]penicillanal

6-[α -(4-chlorophenoxy)acetamido]penicillanal,
 6-[α -(4-nitrophenoxy)acetamido]penicillanal,
 6-[α -(4-bromophenoxy)acetamido]penicillanal,
 6-[α -(4-t-butylphenoxy)acetamido]penicillanal,
 6-[α -(4-trifluoromethylphenoxy)acetamido]penicillanal,
 50 6-[α -(3-fluorophenoxy)acetamido]penicillanal,
 6-[α -(4-sulfamylphenoxy)acetamido]penicillanal,
 6-[α -(2-benzylphenoxy)acetamido]penicillanal,
 6-[α -(3-methoxyphenoxy)acetamido]penicillanal,
 6-[α -(2-iodophenoxy)acetamido]penicillanal,
 55 6-[α -(3-diethylaminophenoxy)acetamido]penicillanal,
 and
 6-[α -(2,4-diisoamylphenoxy)acetamido]penicillanal,

60 respectively, each of which is isolated as a solid which is converted to an active antibacterial agent upon exposure to an oxidative enzyme system.

EXAMPLE 17

65 In the procedure of Example 5, the potassium thiophenethicillin is replaced by an equimolar amount of the potassium salt of the acids,

6-(α -phenylthioacetamido)thiopenicillanic acid,
 70 6-(α -paranitrophenylthioacetamido)thiopenicillanic acid,
 6-(α -parachlorophenylthioacetamido)thiopenicillanic acid,
 6-[α -(4-tertiary-butylphenylthio)acetamido]thiopenicillanic acid,
 75 6-(α -ortho-tolylthioacetamido)thiopenicillanic acid,

6-(α -ortho-nitrophenylthioacetamido)thiopenicillanic acid,
 6-[α -(3,4,5-trichlorophenylthio)acetamido]thiopenicillanic acid,
 6-[α -(3-trifluoromethylphenylthio)acetamido]thiopenicillanic acid,
 6-(α -parabromophenylthioacetamido)thiopenicillanic acid,
 6-(α -paraphenylphenylthioacetamido)thiopenicillanic acid,
 6-[α -(4-methoxyphenylthio)acetamido]thiopenicillanic acid,
 6-[α -(2-iodophenyl)acetamido]thiopenicillanic acid,
 6-[α -(3-diethylaminophenyl)acetamido]thiopenicillanic acid, and
 6-[α -(2,4-diisoamylphenyl)acetamido]thiopenicillanic acid,
 respectively, to produce
 6-(α -phenylthioacetamido)penicillanal,
 6-(α -paranitrophenylthioacetamido)penicillanal,
 6-(α -parachlorophenylthioacetamido)penicillanal,
 6-[α -(4-tertiary-butylphenylthio)acetamido]penicillanal,
 6-(α -ortho-tolylthioacetamido)penicillanal,
 6-(α -ortho-nitrophenylthioacetamido)penicillanal,
 6-[α -(3,4,5-trichlorophenylthio)acetamido]penicillanal,
 6-[α -(3-trifluoromethylphenylthio)acetamido]penicillanal,
 6-(α -parabromophenylthioacetamido)penicillanal,
 6-(α -paraphenylphenylthioacetamido)penicillanal,
 6-[α -(4-methoxyphenylthio)acetamido]penicillanal,
 6-[α -(2,4-dichlorophenylthio)acetamido]penicillanal,
 6-[α -(2,4-diisoamylphenylthio)acetamido]penicillanal,
 6-[α -(4-benzylphenylthio)acetamido]penicillanal,
 6-[α -(4-sulfamylphenylthio)acetamido]penicillanal,
 6-[α -(2-allyloxyphenylthio)acetamido]penicillanal,
 6-[α -(4-allylphenylthio)acetamido]penicillanal,
 6-[α -(2-iodophenylthio)acetamido]penicillanal,
 6-[α -(2-acetamidophenylthio)acetamido]penicillanal, and
 6-[α -(3-fluorophenylthio)acetamido]penicillanal,
 respectively, each of which is isolated as a solid which is converted to an active antibacterial agent upon exposure to an oxidative enzyme system.

EXAMPLE 18

In the procedure of Example 5, the potassium thiophenethicillin is replaced by an equimolar amount of the potassium salt of the acids,

6-[α -(4-nitrophenyl)acetamido]thiopenicillanic acid,
 6-[α -(4-bromophenyl)acetamido]thiopenicillanic acid,
 6-[α -(4-t-butylphenyl)acetamido]thiopenicillanic acid,

26
 6-[α -(4-trifluoromethylphenyl)acetamido]thiopenicillanic acid,
 6-[α -(3-fluorophenyl)acetamido]thiopenicillanic acid,
 6-[α -(4-sulfamylphenyl)acetamido]thiopenicillanic acid,
 5 6-[α -(2-benzylphenyl)acetamido]thiopenicillanic acid,
 6-[α -(3-methoxyphenyl)acetamido]thiopenicillanic acid,
 6-[α -(2-iodophenyl)acetamido]thiopenicillanic acid,
 6-[α -(3-diethylaminophenyl)acetamido]thiopenicillanic acid, and
 10 6-[α -(2,4-diisoamylphenyl)acetamido]thiopenicillanic acid,
 respectively, to produce
 6-[α -(4-nitrophenyl)acetamido]penicillanal,
 15 6-[α -(4-bromophenyl)acetamido]penicillanal,
 6-[α -(4-t-butylphenyl)acetamido]penicillanal,
 6-[α -(4-trifluoromethylphenyl)acetamido]penicillanal,
 6-[α -(3-fluorophenyl)acetamido]penicillanal,
 6-[α -(4-sulfamylphenyl)acetamido]penicillanal,
 20 6-[α -(2-benzylphenyl)acetamido]penicillanal,
 6-[α -(3-methoxyphenyl)acetamido]penicillanal,
 6-[α -(2-iodophenyl)acetamido]penicillanal,
 6-[α -(3-diethylaminophenyl)acetamido]penicillanal, and
 6-[α -(2,4-diisoamylphenyl)acetamido]penicillanal,
 25 respectively, each of which is isolated as a solid which is converted to an active antibacterial agent upon exposure to an oxidative enzyme system.

EXAMPLE 19

30 In the procedure of Example 5, the potassium thiophenethicillin is replaced by an equimolar amount of the potassium salt of the acids,

6-(α -phenylacetamido)thiopenicillanic acid,
 35 6-(α -paranitrophenylacetamido)thiopenicillanic acid,
 6-(α -parachlorophenylacetamido)thiopenicillanic acid,
 6-[α -(4-tertiary-butylphenyl)acetamido]thiopenicillanic acid,
 6-(α -ortho-tolylacetamido)thiopenicillanic acid,
 40 6-(α -ortho-nitrophenylacetamido)thiopenicillanic acid,
 6-[α -(3,4,5-trichlorophenyl)acetamido]thiopenicillanic acid,
 6-[α -(3-trifluoromethylphenyl)acetamido]thiopenicillanic acid,
 45 6-(α -parabromophenylacetamido)thiopenicillanic acid,
 6-(α -paraphenylphenylacetamido)thiopenicillanic acid,
 6-[α -(4-methoxyphenyl)acetamido]thiopenicillanic acid,
 6-[α -(4-cyclohexylphenyl)acetamido]thiopenicillanic acid,
 50 6-[α -(2,4-dichlorophenyl)acetamido]thiopenicillanic acid,
 6-[α -(2,4-diisoamylphenyl)acetamido]thiopenicillanic acid,
 6-[α -(4-benzylphenyl)acetamido]thiopenicillanic acid,
 55 6-[α -(4-sulfamylphenyl)acetamido]thiopenicillanic acid,
 6-[α -(2-allyloxyphenylthio)acetamido]thiopenicillanic acid,
 6-[α -(4-allylphenyl)acetamido]thiopenicillanic acid,
 6-[α -(4-dimethylaminophenylthio)acetamido]thiopenicillanic acid,

 6-[α -(2-iodophenylthio)acetamido]thiopenicillanic acid,
 6-[α -(2-acetamidophenylthio)acetamido]thiopenicillanic acid,
 6-[α -(4-diethylaminophenylthio)acetamido]thiopenicillanic acid, and
 6-[α -(3-fluorophenylthio)acetamido]thiopenicillanic acid,
 65 respectively, each of which is isolated as a solid which is converted to an active antibacterial agent upon exposure to an oxidative enzyme system.

i-[α -(3,4,5-trichlorophenyl)acetamido]penicillanal,
i-[α -(3-trifluoromethylphenyl)acetamido]penicillanal,
i-(α -parabromophenylacetamido)penicillanal,
i-(α -paraphenylphenylacetamido)penicillanal,
i-[α -(4-methoxyphenyl)acetamido]penicillanal,
i-[α -(4-cyclohexylphenyl)acetamido]penicillanal,
i-[α -(2,4-dichlorophenyl)acetamido]penicillanal,
i-[α -(2,4-diisoamylphenyl)acetamido]penicillanal,
i-[α -(4-benzylphenyl)acetamido]penicillanal,
i-[α -(4-sulfamylphenyl)acetamido]penicillanal,
i-[α -2-allyloxyphenyl)acetamido]penicillanal,
i-[α -(4-allylphenyl)acetamido]penicillanal,
i-[α -(4-dimethylaminophenyl)acetamido]penicillanal,
i-[α -(2,5-dichlorophenyl)acetamido]penicillanal,
i-[α -(2-iodophenyl)acetamido]penicillanal,
i-[α -(2-acetamidophenyl)acetamido]penicillanal,
i-[α -(4-diethylaminophenyl)acetamido]penicillanal, and
i-[α -3-fluorophenyl)acetamido]penicillanal,

respectively, each of which is isolated as a solid which is converted to an active anti-bacterial agent upon exposure to an oxidative enzyme system.

EXAMPLE 20

In the procedure of Example 5, the potassium thio-phenethicillin is replaced by an equimolar amount of the potassium salt of the acids,

3-m-chlorophenyl-5-methyl-4-isoxazolylthiopenicillin,
3-(2,4-dichlorophenyl)-5-methyl-4-isoxazolylthiopenicillin,
3-(3,4-dichlorophenyl)-5-methyl-4-isoxazolylthiopenicillin,
3-p-tolyl-5-methyl-4-isoxazolylthiopenicillin,
3-o-nitrophenyl-5-methyl-4-isoxazolylthiopenicillin,
3-m-nitrophenyl-5-methyl-4-isoxazolylthiopenicillin,
3-p-nitrophenyl-5-methyl-4-isoxazolylthiopenicillin,
3-p-bromophenyl-5-methyl-4-isoxazolylthiopenicillin,
3-p-fluorophenyl-5-methyl-4-isoxazolylthiopenicillin,
3-p-methylsulfonylphenyl-5-methyl-4-isoxazolylthiopenicillin,
3-p-methoxyphenyl-5-methyl-4-isoxazolylthiopenicillin,
3-p-trifluoromethylphenyl-5-methyl-4-isoxazolylthiopenicillin,
3-o-methoxyphenyl-5-methyl-4-isoxazolylthiopenicillin,
3-p-ethoxyphenyl-5-methyl-4-isoxazolylthiopenicillin,
3-(3,4-dimethoxyphenyl)-5-methyl-4-isoxazolylthiopenicillin,
3-p-dimethylaminophenyl-5-methyl-4-isoxazolylthiopenicillin,
3- α -naphthyl-5-methyl-4-isoxazolylthiopenicillin,
3- β -naphthyl-5-methyl-4-isoxazolylthiopenicillin,
3-phenyl-5-ethyl-4-isoxazolylthiopenicillin,
3-p-chlorophenyl-5-ethyl-4-isoxazolylthiopenicillin,
3-phenyl-5-isopropyl-4-isoxazolylthiopenicillin,
3-phenyl-5-methylmercapto-4-isoxazolylthiopenicillin,
3-methyl-5-o-chlorophenyl-4-isoxazolylthiopenicillin,
3-methyl-5-p-bromophenyl-4-isoxazolylthiopenicillin,
3-methyl-5-o-iodophenyl-4-isoxazolylthiopenicillin,
3-methyl-5-(2,4-dichlorophenyl)-4-isoxazolylthiopenicillin,
3-methyl-5-m-nitrophenyl-4-isoxazolylthiopenicillin,
3-methyl-5-p-tolyl-4-isoxazolylthiopenicillin,
3-methyl-5-p-nitrophenyl-4-isoxazolylthiopenicillin,
3-methyl-5-p-methoxyphenyl-4-isoxazolylthiopenicillin,
3-methyl-5-p-ethoxyphenyl-4-isoxazolylthiopenicillin,
3-methyl-5-(2,6-dimethoxyphenyl)-4-isoxazolylthiopenicillin,
3-methyl-5-p-methylsulfonylphenyl-4-isoxazolylthiopenicillin,
3-methyl-5-p-fluorophenyl-4-isoxazolylthiopenicillin,
3-methyl-5-p-cyanophenyl-4-isoxazolylthiopenicillin,
3-methyl-5-p-methylmercaptophenyl-4-isoxazolylthiopenicillin,
3-methyl-5-p-dimethylaminophenyl-4-isoxazolylthiopenicillin,
3-methyl-5- α -naphthyl-4-isoxazolylthiopenicillin

3-methyl-5- β -naphthyl-4-isoxazolylthiopenicillin,
3-ethyl-5-phenyl-4-isoxazolylthiopenicillin,
3-ethyl-5-p-chlorophenyl-4-isoxazolylthiopenicillin,
3-isopropyl-5-phenyl-4-isoxazolylthiopenicillin,
5-tert. butyl-5-methyl-4-isoxazolylthiopenicillin,
3-methyl-5-p-trifluoromethylphenyl-4-isoxazolylthiopenicillin,
3-methyl-5-cyclohexyl-4-isoxazolylthiopenicillin,
3-cyclohexyl-5-methyl-4-isoxazolylthiopenicillin,
10 3- α -furyl-5-methyl-4-isoxazolylthiopenicillin, and
3- α -thienyl-5-methyl-4-isoxazolylthiopenicillin,
respectively, to produce
3-m-chlorophenyl-5-methyl-4-isoxazolylthiopenicillin
15 aldehyde,
3-(2,4-dichlorophenyl)-5-methyl-4-isoxazolylpenicillin
aldehyde,
3-(3,4-dichlorophenyl)-5-methyl-4-isoxazolylpenicillin
aldehyde,
20 3-p-tolyl-5-methyl-4-isoxazolylpenicillin aldehyde,
3-o-nitrophenyl-5-methyl-4-isoxazolylpenicillin aldehyde,
3-m-nitrophenyl-5-methyl-4-isoxazolylpenicillin aldehyde,
3-p-nitrophenyl-5-methyl-4-isoxazolylpenicillin aldehyde,
3-p-bromophenyl-5-methyl-4-isoxazolylpenicillin
25 aldehyde,
3-p-fluorophenyl-5-methyl-4-isoxazolylpenicillin
aldehyde,
3-p-methylsulfonylphenyl-5-methyl-4-isoxazolylpenicillin
aldehyde,
30 3-p-methoxyphenyl-5-methyl-4-isoxazolylpenicillin
aldehyde,
3-p-trifluoromethylphenyl-5-methyl-4-isoxazolylpenicillin
aldehyde,
3-o-methoxyphenyl-5-methyl-4-isoxazolylpenicillin
aldehyde,
35 3-p-ethoxyphenyl-5-methyl-4-isoxazolylpenicillin
aldehyde,
3-(3,4-dimethoxyphenyl)-5-methyl-4-isoxazolylpenicillin
aldehyde,
40 3-p-dimethylaminophenyl-5-methyl-4-isoxazolylpenicillin
aldehyde,
3- α -naphthyl-5-methyl-4-isoxazolylpenicillin aldehyde,
3- β -naphthyl-5-methyl-4-isoxazolylpenicillin aldehyde,
3-phenyl-5-ethyl-4-isoxazolylpenicillin aldehyde,
3-p-chlorophenyl-5-ethyl-4-isoxazolylpenicillin aldehyde,
45 3-phenyl-5-isopropyl-4-isoxazolylpenicillin aldehyde,
3-phenyl-5-methylmercapto-4-isoxazolylpenicillin
aldehyde,
3-methyl-5-o-chlorophenyl-4-isoxazolylpenicillin
aldehyde,
50 3-methyl-5-p-bromophenyl-4-isoxazolylpenicillin
aldehyde,
3-methyl-5-o-iodophenyl-4-isoxazolylpenicillin aldehyde,
3-methyl-5-(2,4-dichlorophenyl)-4-isoxazolylpenicillin
aldehyde,
55 3-methyl-5-m-nitrophenyl-4-isoxazolylpenicillin aldehyde,
3-methyl-5-p-tolyl-4-isoxazolylpenicillin aldehyde,
3-methyl-5-p-nitrophenyl-4-isoxazolylpenicillin aldehyde,
3-methyl-5-p-methoxyphenyl-4-isoxazolylpenicillin
aldehyde,
60 3-methyl-5-p-ethoxyphenyl-4-isoxazolylpenicillin
aldehyde,
3-methyl-5-(2,6-dimethoxyphenyl)-4-isoxazolylpenicillin
aldehyde,
3-methyl-5-p-methylsulfonylphenyl-4-isoxazolylpenicillin
aldehyde,
65 3-methyl-5-p-fluorophenyl-4-isoxazolylpenicillin aldehyde,
3-methyl-5-p-cyanophenyl-4-isoxazolylpenicillin aldehyde,
3-methyl-5-p-methylmercaptophenyl-4-isoxazolylpenicillin
aldehyde,
70 3-methyl-5-p-dimethylaminophenyl-4-isoxazolylpenicillin
aldehyde,
3-methyl-5- α -naphthyl-4-isoxazolylpenicillin aldehyde,
3-methyl-5- β -naphthyl-4-isoxazolylpenicillin aldehyde,
3-ethyl-5-phenyl-4-isoxazolylpenicillin aldehyde,
75 3-ethyl-5-p-chlorophenyl-4-isoxazolylpenicillin aldehyde,

3-isopropyl-5-phenyl-4-isoxazolylpenicillin aldehyde, 3-tert. butyl-5-methyl-4-isoxazolylpenicillin aldehyde, 3-methyl-5-p-trifluoromethylphenyl-4-isoxazolylpenicillin aldehyde, 3-methyl-5-cyclohexyl-4-isoxazolylpenicillin aldehyde, 3-cyclohexyl-5-methyl-4-isoxazolylpenicillin aldehyde, 3- α -furyl-5-methyl-4-isoxazolylpenicillin aldehyde, and 3- α -thienyl-5-methyl-4-isoxazolylpenicillin aldehyde,

respectively, each of which is isolated as a solid which is converted to an active antibacterial agent upon exposure to an oxidative enzyme system.

EXAMPLE 21

In the procedure of Example 5, the potassium thio-penicillin is replaced by an equimolar amount of the potassium salt of the acids,

3,5-diphenyl-4-isoxazolylthiopenicillin, 3-methyl-5-phenyl-4-isoxazolylthiopenicillin, 3,5-dimethyl-4-isoxazolylthiopenicillin, 5-benzyl-3-methyl-4-isoxazolylthiopenicillin, 3-methyl-5-styryl-4-isoxazolylthiopenicillin, 5-tert. butyl-3-phenyl-4-isoxazolylthiopenicillin, 5-(2-furyl)-3-methyl-4-isoxazolylthiopenicillin, 3-methyl-5-(3',5'-dimethyl-4'-isoxazolyl)-4-isoxazolylthiopenicillin, 3-methyl-5-(2-thienyl)-4-isoxazolylthiopenicillin, 3-(p-chlorophenyl)-5-methyl-4-isoxazolylthiopenicillin, 3-methyl-5-methylmercapto-4-isoxazolylthiopenicillin, 5-(p-chlorophenyl)-3-methyl-4-isoxazolylthiopenicillin, 3-methyl-5-(o-nitrophenyl)-4-isoxazolylthiopenicillin, 5-isopropyl-3-methyl-4-isoxazolylthiopenicillin and 5-methyl-3-(p-chlorophenyl)-4-isoxazolylthiopenicillin,

respectively, to produce,

3,5-diphenyl-4-isoxazolylpenicillin aldehyde, 3-methyl-5-phenyl-4-isoxazolylpenicillin aldehyde, 3,5-dimethyl-4-isoxazolylpenicillin aldehyde, 5-benzyl-3-methyl-4-isoxazolylpenicillin aldehyde, 3-methyl-5-styryl-4-isoxazolylpenicillin aldehyde, 5-tert. butyl-3-phenyl-4-isoxazolylpenicillin aldehyde, 5-(2-furyl)-3-methyl-4-isoxazolylpenicillin aldehyde, 3-methyl-5-(3',5'-dimethyl-4'-isoxazolyl)-4-isoxazolylpenicillin aldehyde, 3-methyl-5-(2-thienyl)-4-isoxazolylpenicillin aldehyde, 3-(p-chlorophenyl)-5-methyl-4-isoxazolylpenicillin aldehyde, 3-methyl-5-methylmercapto-4-isoxazolylpenicillin aldehyde, 5-(p-chlorophenyl)-3-methyl-4-isoxazolylpenicillin aldehyde, 3-methyl-5-(o-nitrophenyl)-4-isoxazolylpenicillin aldehyde, 5-isopropyl-3-methyl-4-isoxazolylpenicillin and 5-methyl-3-(p-chlorophenyl)-4-isoxazolylpenicillin aldehyde,

respectively, each of which is isolated as a solid which is converted to an active antibacterial agent upon exposure to an oxidative enzyme system.

EXAMPLE 22

(1) *6-phenoxyacetamidopenicillanic thiol acid potassium salts*.—A solution containing 35.04 g. (0.100 mole) of penicillin V (phenoxyethylpenicillin) 14.02 ml. (0.10 mole) of dry triethylamine, and 508 ml. of pure, dry DMF (dimethylformamide) was stirred and cooled to -3° C. Ethyl chloroformate (9.51 ml.; 0.10 mole) was added and the resulting solution was stirred at 0° for 10 minutes. A solution of 22.0 g. (0.2 mole) of sodium hydrosulfide (hydrated) in 358 ml. of pure, dry DMF was prepared by stirring at 25° C. under a nitrogen atmosphere for 10 minutes. This turbid yellow solution was added to the mixed anhydride solution all at once and the cooling bath was removed. After stirring for 10 minutes,

the reaction mixture was poured into 3.0 liters of ice water. The solution was acidified to pH 2.0 with 6 N sulfuric acid and extracted with three one-liter portions of cold ether. The combined ether solutions were washed twice with 500 ml. portions of ice water, dried very briefly over sodium sulfate and filtered. Addition of 20.5 ml. of an 85% by weight solution of potassium-2-ethylhexanoate (KEH) in dry n-butanol (diluted to 40 ml. with dry ether) precipitated the product, which was collected by filtration, washed with dry ether and dried, yield 32.7 g. (81%). The product was recrystallized by dissolving in a minimum of cold water (ca. 40 ml.), adding ca. 500 ml. of n-butanol, and removing the water-butanol azeotrope in vacuo at 33° C. until the solution was entirely dry. The purified yield was 28.2 g. (70%). The infrared absorption spectrum was identical to that of the original sample of this material for which excellent analytical data had already been obtained.

(2) *3 - (1,3 - diphenyl-2-imidazolidinyl)-2,2-dimethyl-6-phenoxyacetamidopenam*.—A suspension of 52.0 g. of Raney active nickel No. 28 (washed by decantation three times with 105 ml. portions of absolute ethanol and then four times with 105 ml. portions of THF) in 160 ml. of tetrahydrofuran (THF) containing 3.20 ml. of glacial acetic acid, 5.00 g. (0.0235 mole) of N,N'-diphenylethylenediamine, and 15.0 ml. of water was cooled to 0° C. To this vigorously stirred solution was added a solution of 6.35 g. (0.0157 mole) of 6-phenoxyacetamidopenicillanic thiol acid potassium salt in 60 ml. of THF containing 6.25 ml. of water. An effervescence was noted, which subsided after about one minute. The mixture was stirred at 6-0° C. for 15 minutes. The catalyst was then filtered off over diatomaceous earth ("Supercel"), and the nickel was washed on the filter with five 50 ml. portions of THF. The solvent was removed in vacuo from the pale yellow filtrate, and the residue was flash-distilled with two 100 ml. portions of dry ethyl acetate at 33° C. to remove traces of moisture. Five hundred ml. of anhydrous ether was added and the turbid solution was refluxed for one-half hour. During this period of reflux, a white, crystalline precipitate formed. At the end of the reflux period, the warm solution was filtered, and the solids and filtrate were worked up separately.

The solids were boiled briefly with 100 ml. of ethyl acetate and the hot mixture was filtered. On thorough cooling, the filtrate yielded 2.70 g. of white crystals, M.P. 174-175° C. Then the filtrate from this portion of the product was freed of solvent in vacuo and the residue was treated with 15 ml. of dry ether, a further quantity of the product, 1.42 g., was obtained as a highly crystalline but slightly tan solid, M.P. 167-170° C.

The filtrate was extracted with 20 ml. of 10% phosphoric acid, which caused N,N'-diphenylethylenediamine phosphate to crystallize. It was filtered off, the aqueous phase was separated, and the ether solution was again extracted with 20 ml. of 10% phosphoric acid and washed with three 100 ml. portions of water. It was dried over sodium sulfate, filtered, flushed dry and flushed with ethyl acetate. The addition of 10 ml. of dry ether to the small residue caused 0.25 g. of product to crystallize, M.P. 164-168° C.

The total yield was 4.37 g. (52.5%) of the title compound.

(3) *6 - phenoxyacetamidopenicillanal*.—A solution of 10.5 g. of pure 3-(1,3-diphenyl-2-imidazolidinyl)-2,2-dimethyl-6-phenoxyacetamidopenam (0.189 mole) was prepared in 98.5 ml. dry acetone, 98.5 ml. of methylene chloride and 298 ml. of anhydrous ether. To this solution was added a solution of 7.11 g. (0.374 mole) of p-toluenesulfonic acid monohydrate in a mixture of 50 ml. of CH_2Cl_2 , 50 ml. of dry acetone, 150 ml. of anhydrous ether, and 1.3 ml. of water. A heavy precipitate formed instantly, and the slurry was stirred mechanically at 25° for $\frac{1}{2}$ hour. It was then diluted with 1.1 liter of ether and filtered over "Supercel." The clear filtrate was ex-

31

acted with two 100 ml. portions of water, dried over sodium sulfate, filtered and flushed dry at 33° C. Fifty ml. of dry ether was added and the solution cooled in ice for at least 15 minutes. The product crystallized and filtration yielded 2.08 g. of white needles, M.P. 106–108° C. The filtrate was allowed to evaporate with 1.5 ml. of H₂O added at 20° C. for 24 hours. The crystals were filtered and the yield was 3.90 g. of white needles, M.P. 105–104° C. The total yield was 5.98 g. (94.5%).

The infrared absorption spectrum was quite sharp, showing NH 3380 cm.⁻¹, β -lactam 1780, aldehyde 1740, amide 1670 and 1525 cm.⁻¹. All of the bands noted were of equal intensity. The aldehyde may be recrystallized again at 33° C. Water (a few ml.) and ordinary ether acetate (three parts per 100 ml.) and flushing off the solvent at 33° C. Water (a few ml.) and ordinary ether one part per 100 ml.) are added and the resulting solution is allowed to stand at 20° C. for 24 hours. The product will slowly crystallize.

Analysis.—Calc'd for C₁₆H₁₈N₂O₄S·½H₂O: C, 55.96; H, 5.57; N, 8.16; S, 9.34. Found: C, 55.40, 55.25; H, 5.63, 5.72; N, 8.08; S, 9.12.

(4) 2,2-dimethyl-3-acetoxymethylene-6-phenoxyacetimidopenam.—A mixture of 2.07 g. (0.00604 mole) of penicillin V aldehyde hemihydrate, 200 ml. of acetic anhydride, and 3.0 ml. of pyridine was stirred at 25° under a nitrogen atmosphere for 16 hours. The acetic anhydride and excess pyridine were removed in vacuo at 50° C. The dark residue was dissolved as far as possible in 150 ml. of carbon tetrachloride and the solution was stirred with ca. 4 g. of decolorizing charcoal for 45 minutes. The solution was filtered over "Supercel" and the filtrate was flushed dry at 50° C. In order to codistill most of the remaining traces of acetic anhydride, 75 ml. of carbon tetrachloride was added and the flushing was repeated. The light orange residue was dissolved in a few ml. of methylene chloride, flushed to an oil and dried to a friable fluff in high vacuum at 25° C. The yield was 1.11 g. (49%) of light orange foam. The infrared spectrum (5% in CCl₄) shows NH at 3400 cm.⁻¹, β -lactam 1800, enol acetate carbonyl 1762, amide 1700 and 1510 and C—O—C bands at 1230, 1190, and 1090 cm.⁻¹. A weak band at 1640 cm.⁻¹ is ascribed to

The NMR spectrum is in full agreement with the enol acetate structure and shows further that the product is a mixture of approximately equal amounts of cis and trans isomers.

Analysis.—Calc'd for C₁₈H₂₀N₂O₅S: C, 57.43; H, 5.63. Found: C, 57.20; H, 5.37.

PREPARATION OF STARTING MATERIALS— PENICILLIN THIOACIDS

Another series of starting materials used to prepare the compounds of the present invention comprises the series of compounds of the formula

wherein R¹ is amino, acylamino, benzyloxycarbonyl-amino, phthalimido or trityl-amino and, particularly, the so-called penicillin thioacids or thiopenicillins of the formula

in which R² represents the side chain of any of the known penicillins other than those containing a group which is altered by reaction with Raney nickel above 0°

32

C. These compounds are usually used in the form of salts, e.g. sodium, potassium.

These compounds exist in tautomeric forms, i.e. the —COSH group may be in the thiol form as

or in the thione form as

Such thiopenicillins are prepared from penicillins by the methods described below or in U.S. Patent 2,751,378. In general, to prepare a thiopenicillin, an active acylating derivative of the starting penicillin such as an anhydride or a mixed anhydride (such as the mixed anhydride with a lower alkyl ester of ethoxy- or isobutoxy-carbonic acid) or an acid chloride is prepared and reacted with a source of sulphydryl groups, e.g. hydrogen sulfide or sodium hydrosulfide or potassium hydrosulfide.

Additional examples of the preparation of thiopenicillins are as follows:

Preparation 11.—Preparation of potassium 6-(DL- α -phenoxypropionamido)thiopenicillanate

Dilute sulfuric acid is added to a solution of potassium 6-(DL- α -phenoxypropionamido)penicillanate (10 gm., 0.025 mole), dissolved in water (100 ml.) until a pH of 2 is attained. The penicillin acid is extracted from this solution into ether, washed with water, and dried over anhydrous magnesium sulfate. The ether is evaporated under reduced pressure to leave a residual oil which is azeotroped three times with ethyl acetate to remove all traces of water. The residue is dissolved in dimethylformamide (125 ml.) and cooled to 5° C. in an ice bath. 2,6-lutidine (2.7 gm., 0.0254 mole) is added, followed by the dropwise addition of ethyl chloroformate (2.7 gm., 0.0254 mole). The mixture is stirred for 15 minutes and a suspension of sodium hydrosulfide (5.6 gm., 0.06 mole) in dimethylformamide (100 ml.) is added all at once. The solution is stirred for one hour, and turns dark brown. The solution is poured into water (one liter) and acidified to pH 2 with dilute sulfuric acid. The 6-(DL- α -phenoxypropionamido)thiopenicillanic acid is extracted into ether, washed with water, and dried over anhydrous magnesium sulfate. Potassium 2-ethylhexanoate (5 gm.) is added and the crystalline precipitate is collected and weighs 4.5 gm. Recrystallization from water and acetone yields 1.1 gm. of the product, potassium 6-(DL- α -phenoxypropionamido)thiopenicillanate, as colorless plates which are found to contain the β -lactam ring as shown by infrared analysis, to have a melting point of greater than 240° C. with decomposition and the following elemental analysis:

Calculated for C₁₇H₁₉N₂O₄S₂K·½H₂O: C, 47.8%; H, 4.74%; S, 14.9%. Found: C, 48.2%; H, 4.52%; S, 13.8%.

Preparation 12

In procedure of Preparation 11, the potassium 6-(α -phenoxypropionamido)penicillanate is replaced by 0.025 mole of the potassium salt of the acids

- 6-[α -(2-chlorophenoxy)propionamido]penicillanic acid,
- 6-[α -(4-sulfamylphenoxy)-n-butyramido]penicillanic acid,
- 6-[α -(3,4-dimethoxyphenoxy)-n-pentanoamido]penicillanic acid,
- 6-[α -(3-methylphenoxy)isovaleramido]penicillanic acid,
- 6-[α -(4-methylthiophenoxy)propionamido]penicillanic acid,
- 6-[α -(4-dimethylaminophenoxy)-n-hexanoamido]penicillanic acid,

- 6 - [α - (2 - methoxyphenoxy) - n - decanoamido]penicillanic acid,
 6 - [α - (2,4 - dichlorophenoxy)phenylacetamido]penicillanic acid,
 6 - [α - (2 - nitrophenoxy) - β - phenylpropionamido] 5 penicillanic acid,
 6 - [α - (2 - acetamidophenoxy) - γ - phenylbutyramido] penicillanic acid,
 6 - [α - (2,4 - dimethylphenoxy) - n - butyramido]penicillanic acid,
 6 - [α - (4 - isopropylphenoxy)propionamido]penicillanic acid,
 6 - [α - (3 - bromophenoxy) - n - butyramido]penicillanic acid,
 6 - [α - (2 - iodophenoxy)phenylacetamido]penicillanic 15 acid,
 6 - [α - (2 - diethylaminophenoxy)isovaleramido]penicillanic acid,
 6 - [α - (3,5 - dichlorophenoxy)isohexanoamido]penicillanic acid,
 6 - [α - (4 - cyclohexyphenoxy)propionamido]penicillanic acid,
 6 - [α - phenoxy - isovaleramido]penicillanic acid,
 6 - [α -phenoxy-n-decanoamido]penicillanic acid,
 6 - [α -phenoxy- γ -phenylbutyramido]penicillanic acid,
 5 - [α - (2 - benzylphenoxy) - n - butyramido]penicillanic acid,
 6 - [α - (2-trifluoromethylphenoxy)propionamido]penicillanic acid, and
 6 - [α - (4-fluorophenoxy)propionamido]penicillanic acid,
 to produce the potassium salts of
 6 - [α - (2-chlorophenoxy)propionamido]thiopenicillanic acid,
 6 - [α - (4-sulfamylphenoxy) - n - butyramido]thiopenicillanic acid,
 6 - [α - (3,4-dimethoxyphenoxy) - n - pentanoamido] 35 thiopenicillanic acid,
 6 - [α - (3-methylphenoxy)isovaleramido]thiopenicillanic acid,
 6 - [α - (4-methylthiophenoxy)propionamido] thiopenicillanic acid,
 6 - [α - (4-dimethylaminophenoxy) - n - hexanoamido] thiopenicillanic acid,
 6 - [α - (2-methoxyphenoxy) - n - decanoamido] 40 thiopenicillanic acid,
 6 - [α - (2,4-dichlorophenoxy)phenylacetamido] thiopenicillanic acid,
 6 - [α - (2-nitrophenoxy) - β - phenylpropionamido] thiopenicillanic acid,
 6 - [α - (2-acetamidophenoxy) - γ - phenylbutyramido] 45 thiopenicillanic acid,
 6 - [α - (2,4-dimethylphenoxy) - n - butyramido] thiopenicillanic acid,
 6 - [α - (4-isopropylphenoxy)propionamido]thiopenicillanic acid,
 6 - [α - (3-bromophenoxy) - n - butyramido]thiopenicillanic acid,
 6 - [α - (2-iodophenoxy)phenylacetamido]thiopenicillanic 55 acid,
 6 - [α - (2-diethylaminophenoxy)isovaleramido] thiopenicillanic acid,
 6 - [α - (3,5-dichlorophenoxy)isohexanoamido] thiopenicillanic acid,
 6 - [α - (4-cyclohexylphenoxy)propionamido] 60 thiopenicillanic acid,
 6 - [α - phenoxy-isovaleramido]thiopenicillanic acid,
 6 - [α -phenoxy-n-decanoamido]thiopenicillanic acid,
 6 - [α -phenoxy- γ -phenylbutyramido]thiopenicillanic acid,
 6 - [α - (2-benzylphenoxy) - n - butyramido]thiopenicillanic acid,
 6 - [α - (2-trifluoromethylphenoxy)propionamido]thiopenicillanic 65 acid, and
 6 - [α - (4-fluorophenoxy)propionamido]thiopenicillanic acid,

respectively, each of which is isolated as its solid, water-soluble potassium salt.

Preparation 13.—Preparation of potassium 6-(D- α -phenoxypropionamido)thiopenicillanate

Dilute sulfuric acid is added to a solution of potassium 6-(D- α -phenoxypropionamido)penicillanate (5 gm., 0.0125 mole) in water (150 ml.) until a pH of 2 is attained. The penicillin acid is extracted from this solution into ethyl acetate (200 ml.), washed with water, and dried over anhydrous magnesium sulfate. The ethyl acetate is evaporated at 35° C. The residue is dissolved in dimethylformamide (150 ml.) and cooled to 5° C. in an ice bath. 2,6-lutidine (1.33 gm., 0.0125 mole) is added, followed by the dropwise addition of ethyl chloroformate (1.33 gm., 0.0125 mole). The mixture is stirred for 15 minutes and a suspension of sodium hydrosulfide (2.5 gm., 0.0447 mole) in dimethylformamide (100 ml.) is added all at once. The solution is stirred for 20 minutes and then poured into water (one liter) and acidified to pH 2 with dilute sulfuric acid. The 6-(D- α -phenoxypropionamido)thiopenicillanic acid that forms is extracted into ether, washed with water, and dried over anhydrous magnesium sulfate. Potassium 2-ethylhexanoate (3 gm.) is added and the crystalline precipitate is collected. Recrystallization from water and n-butanol yields 1.7 gm. of the product, potassium 6-(D- α -phenoxypropionamido)thiopenicillanate, which is found to contain the β -lactam ring as shown by infrared analysis, to have a melting point of greater than 195° C. with decomposition and the following elemental analysis:

Calculated for $C_{17}H_{19}N_2O_4S_2K$: C, 48.78%; H, 4.58%; N, 6.7%; S, 15.4%. Found: C, 49.25%; H, 4.68%; N, 6.84%; S, 14.52%.

Preparation 14.—Preparation of potassium 6-(L- α -phenoxypropionamido)thiopenicillanate

Dilute sulfuric acid is added to a solution of potassium 6 - (L- α -phenoxypropionamido)penicillanate (5 gm., 0.0125 mole) in water (150 ml.) until a pH of 2 is attained. The penicillin acid is extracted from this solution into ethyl acetate (200 ml.), washed with water, and dried over anhydrous magnesium sulfate. The ethyl acetate is evaporated at 35° C. The residue is dissolved in dimethylformamide (150 ml.) and cooled to 5° C. in an ice bath. 2,6-lutidine (1.33 gm., 0.0125 mole) is added, followed by the dropwise addition of ethyl chloroformate (1.33 gm., 0.0125 mole). The mixture is stirred for 15 minutes and a suspension of sodium hydrosulfide (2.5 gm., 0.0447 mole) in dimethylformamide (100 ml.) is added all at once. The solution is stirred for 20 minutes and then poured into water (one liter) and acidified to pH 2 with dilute sulfuric acid. The 6-(L- α -phenoxypropionamido)thiopenicillanic acid is extracted into ether, washed with water, and dried over anhydrous magnesium sulfate. Potassium 2-ethylhexanoate (3 gm.) is added and the crystalline precipitate is collected. Recrystallization from water and n-butanol yields 2.5 gm. of the product, potassium 6-(L- α -phenoxypropionamido)thiopenicillanate which is found to have a melting point of greater than 215° C. with decomposition and the following elemental analysis:

Calculated for $C_{17}H_{19}N_2O_4S_2K$: C, 48.78%; H, 4.58%; N, 6.7%; S, 15.4%. Found: C, 50.22%; H, 4.98%; N, 6.77%; S, 14.18%.

Preparation 15.—Preparation of potassium 6-(α -isopropyl- α -phenoxyacetamido)thiopenicillanate

Dilute sulfuric acid is added to a solution of potassium 6-(α -isopropyl- α -phenoxyacetamido)thiopenicillanate (5.3 gm., 0.0125 mole) in water (150 ml.) until a pH of 2 is attained. The penicillin acid is extracted from this solution into ethyl acetate (200 ml.) washed with water, and dried over anhydrous magnesium sulfate. The ethyl acetate is evaporated at 35° C. The residue is dis-

olved in dimethylformamide (150 ml.) and cooled to 5° C. in an ice bath. 2,6-lutidine (1.33 gm., 0.0125 mole) is added, followed by the dropwise addition of ethyl chloroformate (1.33 gm., 0.0125 mole). The mixture is stirred for 15 minutes and a suspension of sodium hydroxide (2.5 gm., 0.0447 mole) in dimethylformamide (100 ml.) is added all at once. The solution is stirred for 20 minutes and then poured into water (one liter) and acidified to pH 2 with dilute sulfuric acid. The 6-(α -isopropyl- α -phenoxyacetamido)thiopenicillanic acid is extracted into ether, washed with water, and dried over anhydrous magnesium sulfate. Potassium 2-ethylhexanoate (3 gm.) is added and the crystalline precipitate is collected. Recrystallization from ethyl acetate and Skellysolve yields 2.3 gm. of the product potassium 6-(α -isopropyl- α -phenoxyacetamido)thiopenicillanate, which is found to contain the β -lactam ring as shown by infrared analysis and to have a melting point of greater than 170° C. with decomposition.

Preparation 16.—Preparation of potassium 6-[L(—)- α -phenoxybutyramido]thiopenicillanate

Potassium 6-[L(—)- α -phenoxybutyramido]penicillanate (2.08 gm., 0.005 mole) is dissolved in water (30 ml.) and layered with ethyl acetate. After cooling to 5° C., dilute phosphoric acid (40%) is added until a pH of 2 is attained. The penicillin acid is extracted into the ethyl acetate and a further extraction with fresh ethyl acetate is made. The combined extracts are washed with ice-water, dried over anhydrous magnesium sulfate, and evaporated to dryness. The residue is dissolved in dimethylformamide (30 ml.) and cooled to 0° C. in an ice bath. 2,6-lutidine (0.53 gm., 0.005 mole) is added, followed by the dropwise addition of ethyl chloroformate (0.52 gm., 0.005 mole) forming a precipitate. The mixture is stirred for 10 minutes at 0° C. and a solution of sodium hydroxide trihydrate (1.1 gm., 0.01 mole) in dimethylformamide (30 ml.) is added in one portion. The resulting green solution is stirred for 25 minutes and poured into a precooled (5°–10° C.) mixture of water (150 ml.), acidified to pH 1.5 with dilute phosphoric acid (40%) and benzene (100 ml.) with vigorous stirring. The 6-[L(—)- α -phenoxybutyramido]thiopenicillanic acid is extracted into benzene and a further extraction with fresh benzene is made. The combined extracts are washed and dried. Potassium 2-ethylhexanoate (0.005 mole) is added as a 50% solution of potassium 2-ethylhexanoate in butanol. Skellysolve B (a petroleum ether fraction having a boiling point range of from about 60° to about 68° C. consisting essentially of n-hexane) is added to the solution with cooling and shaking until the solution becomes cloudy, and an oil separates. The solution is decanted and flashed to dryness. The residue is triturated with ether, and a white solid forms which is removed by filtration, washed with dry ether, and dried in vacuo. The product, potassium 6-[L(—)- α -phenoxybutyramido]thiopenicillanate is found to weigh 2 grams, to have a melting point of 145°–149° C. with decomposition and the structure is confirmed by infrared analysis.

Preparation 17

In the procedure of Preparation 11, the potassium 6-(α -phenoxypropionamido)penicillanate is replaced by 0.025 mole of the potassium salt of

6-(α -phenoxy- α -benzylpropionamido)penicillanic acid, 6-(α -phenylthio- α -benzylpropionamido)penicillanic acid, 6-(α -phenoxy- α -methylpropionamido)penicillanic acid, 6-(α -phenylthio- α -methylpropionamido)penicillenic acid, 6-[α -(2,4-dichlorophenoxy)- α -ethylpropionamido] penicillanic acid, 6-[α -(2-chlorophenoxy)- α -methylbutyramido] penicillanic acid, 6-[α -(4-nitrophenoxy)- α -methyl-n-butyrarnido] penicillanic acid, 6-[α -(4-bromophenoxy)- α -phenyl-n-valeramido] penicillanic acid, 6-[α -(3-fluorophenoxy)- α -benzyl-n-valeramido] penicillanic acid, 6-[α -(4-sulfamylphenoxy)- α -methylpropionamido] penicillanic acid, 6-[α -(2-benzylphenoxy)- α -methyl-n-butyrarnido] penicillanic acid, 6-[α -(3-methoxyphenoxy)- α -methyldecanoamido] penicillanic acid, 6-[α -(2-iodophenoxy)- α -phenylpropionamido] penicillanic acid, 6-[α -(3-diethylaminophenoxy)- α -methyl-n-butyrarnido] penicillanic acid, 6-[α -(2,4-diisoamylphenoxy)- α -methyl-n-butyrarnido] penicillanic acid,

- 6-[α -(4-bromophenoxy)- α -phenyl-n-valeramido] penicillanic acid, 6-[α -(4-t-butylphenoxy)- α -benzyl-n-butyrarnido] penicillanic acid, 6-[α -(4-trifluoromethylphenoxy)- α -phenyl-n-butyrarnido] penicillanic acid, 6-[α -(3-fluorophenoxy)- α -benzyl-n-valeramido] penicillanic acid, 6-[α -(4-sulfamylphenoxy)- α -methylpropionamido] penicillanic acid, 6-[α -(2-benzylphenoxy)- α -methyl-n-butyrarnido] penicillanic acid, 6-[α -(3-methoxyphenoxy)- α -methyldecanoamido] penicillanic acid, 6-[α -(2-iodophenoxy)- α -phenylpropionamido] penicillanic acid, 6-[α -(3-diethylaminophenoxy)- α -methyl-n-butyrarnido] penicillanic acid, 6-[α -(2,4-diisoamylphenoxy)- α -methyl-n-butyrarnido] penicillanic acid, to produce the potassium salts of 6-(α -phenoxy- α -benzylpropionamido)thiopenicillanic acid, 6-(α -phenylthio- α -benzylpropionamido)thiopenicillanic acid, 6-(α -phenoxy- α -methylpropionamido)thiopenicillanic acid, 6-(α -phenylthio- α -methylpropionamido)thiopenicillanic acid, 6-[α -(2,4-dichlorophenoxy)- α -ethylpropionamido] thiopenicillanic acid, 6-[α -(2-chlorophenoxy)- α -methylbutyramido] thiopenicillanic acid, 6-[α -(4-nitrophenoxy)- α -methyl-n-butyrarnido] thiopenicillanic acid, 6-[α -(4-bromophenoxy)- α -phenyl-n-valeramido] thiopenicillanic acid, 6-[α -(3-fluorophenoxy)- α -benzyl-n-valeramido] thiopenicillanic acid, 6-[α -(4-sulfamylphenoxy)- α -methylpropionamido] thiopenicillanic acid, 6-[α -(2-benzylphenoxy)- α -methyl-n-butyrarnido] thiopenicillanic acid, 6-[α -(3-methoxyphenoxy)- α -methyldecanoamido] thiopenicillanic acid, 6-[α -(2-iodophenoxy)- α -phenylpropionamido] thiopenicillanic acid, 6-[α -(3-diethylaminophenoxy)- α -methyl-n-butyrarnido] thiopenicillanic acid, 6-[α -(2,4-diisoamylphenoxy)- α -methyl-n-butyrarnido] thiopenicillanic acid, respectively, each of which is isolated as its solid, water-soluble potassium salt.

Preparation 18

- 60 In the procedure of Preparation 11, the potassium 6-(α -phenoxypropionamido)penicillanate is replaced by 0.025 mole of the potassium salt of
- 65 6-(α -phenylthiopropionamido) penicillanic acid, 6-(α -paranitrophenylthiopropionamido) penicillanic acid, 6-(α -parachlorophenylthiopropionamido) penicillanic acid, 6-(α -phenylthiobutyramido) penicillanic acid, 6-(α -phenylthiopropanoamido) penicillanic acid, 70 6-(α -phenylthioisovaleramido) penicillanic acid, 6-[α -(4-t-butylphenylthio)propionamido] penicillanic acid, 6-[α -ortho-tolylthiopropionamido] penicillanic acid, 6-[α -ortho-nitrophenylthiopropionamido] penicillanic acid, 75 6-(α -parachlorophenylthiobutyramido) penicillanic acid,

6-[α -(3,4,5-trichlorophenylthio)propionamido] penicillanic acid,
 6-[α -(3-trifluoromethylphenylthio)butyramido] penicillanic acid,
 6-(α -parabromophenylthioisovaleramido) penicillanic acid,
 6-(α -paraphenylphenylthiopropionamido) penicillanic acid,
 6-[α -(4-methoxyphenylthio)caproamido] penicillanic acid,
 6-[α -(4-cyclohexylphenylthio)butyramido] penicillanic acid,
 6-(α -phenylthio- α -cyclohexylacetamido) penicillanic acid,
 6-(α -phenylthio- α -cyclopentylacetamido) penicillanic acid,
 6-[α -(2,4-dichlorophenylthio)caproamido] penicillanic acid,
 6-[α -(2,4-diisoamylphenylthio)propionamido] penicillanic acid,
 6-[α -(4-benzylphenylthio)propionamido] penicillanic acid,
 6-[α -(4-sulfamylphenylthio)butyramido] penicillanic acid,
 6-[α -(2-allyloxyphenylthio)propionamido] penicillanic acid,
 6-[α -(2-iodophenylthio)propionamido] penicillanic acid,
 6-[α -(2-acetamidophenylthio)propionamido] penicillanic acid,
 6-[α -(4-diethylaminophenylthio)propionamido] penicillanic acid, and
 6-[α -(3-fluorophenylthio)butyramido] penicillanic acid,
 to produce the potassium salts of
 6-(α -phenylthiopropionamido)thiopenicillanic acid,
 6-(α -paranitrophenylthiopropionamido) thiopenicillanic acid,
 6-(α -parachlorophenylthiopropionamido) thiopenicillanic acid,
 6-(α -phenylthiobutyramido)thiopenicillanic acid,
 6-(α -phenylthiopropanoamido)thiopenicillanic acid,
 6-[α -(3,4,5-trichlorophenylthio)propionamido] thiopenicillanic acid,
 6-[α -(3-trifluoromethylphenylthio)butyramido] thiopenicillanic acid,
 6-(α -parabromophenylthioisovaleramido) thiopenicillanic acid,
 6-(α -paraphenylphenylthiopropionamido) thiopenicillanic acid,
 6-[α -(4-methoxyphenylthio)caproamido] thiopenicillanic acid,
 6-[α -(4-cyclohexylphenylthio)butyramido] thiopenicillanic acid,
 6-(α -phenylthio- α -cyclohexylacetamido) thiopenicillanic acid,
 6-(α -phenylthio- α -cyclopentylacetamido) thiopenicillanic acid,
 6-[α -(2,4-dichlorophenylthio)caproamido] thiopenicillanic acid,
 6-[α -(2,4-diisoamylphenylthio)propionamido] thiopenicillanic acid,
 6-[α -(4-benzylphenylthio)propionamido] thiopenicillanic acid,
 6-[α -(4-sulfamylphenylthio)butyramido] thiopenicillanic acid,
 6-[α -(2-allyloxyphenylthio)propionamido] thiopenicillanic acid,
 6-[α -(2-iodophenylthio)propionamido] thiopenicillanic acid,
 6-[α -(2-acetamidophenylthio)propionamido] thiopenicillanic acid,
 6-[α -(4-diethylaminophenylthio)propionamido] thiopenicillanic acid, and
 6-[α -(3-fluorophenylthio)butyramido] thiopenicillanic acid,

6-[α -(2,4-diisoamylphenylthio)propionamido] thiopenicillanic acid,
 6-[α -(4-benzylphenylthio)propionamido] thiopenicillanic acid,
 5 6-[α -(4-sulfamylphenylthio)butyramido] thiopenicillanic acid,
 6-[α -(2-allyloxyphenylthio)propionamido] thiopenicillanic acid,
 6-[α -(4-allylphenylthio)isovaleramido] thiopenicillanic acid,
 10 6-[α -(4-dimethylaminophenylthio)propionamido] thiopenicillanic acid,
 6-[α -(2,5-dichlorophenylthio)butyramido] thiopenicillanic acid,
 15 6-[α -(2-iodophenylthio)propionamido] thiopenicillanic acid,
 6-[α -(2-acetamidophenylthio)propionamido] thiopenicillanic acid,
 6-[α -(4-diethylaminophenylthio)propionamido] thiopenicillanic acid, and
 20 6-[α -(3-fluorophenylthio)butyramido] thiopenicillanic acid,
 respectively, each of which is isolated as its solid water-soluble potassium salt.

25

Preparation 19

In the procedure of Preparation 16 the 2.08 gm. of potassium 6-[L(-)- α -phenoxybutyramido]penicillanic acid is replaced by 8.32 grams of the same acid to produce in the first crop 4.0 grams of the desired product, potassium 6-[L(-)- α -phenoxybutyramido]thiopenicillanic acid in crystalline form, having purity of about 95% (as shown by NMR studies), a specific rotation of $[\alpha]_D^{26} +177^\circ$ (c. = $\frac{1}{2}$ % H₂O) and a melting point range of from 155° to 160° C. with decomposition.

Preparation 20.—Preparation of potassium 6-[D(+)- α -phenoxybutyramido]thiopenicillanate

40

Potassium 6-[D(+)- α -phenoxybutyramido]penicillanate (3.0 gm.) is dissolved in water (30 ml.) and layered with ethyl acetate. After cooling to 5° C., dilute phosphoric acid (40%) is added until a pH of 2 is attained. The penicillin acid is extracted into the ethyl acetate and a further extraction with fresh ethyl acetate is made. The combined extracts are washed with ice-water, dried over anhydrous magnesium sulfate, and evaporated to dryness. The residue is dissolved in dimethylformamide (30 ml.) and cooled to 0° C. in an ice bath. 2,6-lutidine (0.53 gm., 0.005 mole) is added, followed by the drop-wise addition of ethyl chloroformate (0.52 gm., 0.005 mole) forming a precipitate. The mixture is stirred for 10 minutes at 0° C. and a solution of sodium hydrosulfide trihydrate (1.1 gm., 0.01 mole) in dimethylformamide (30 ml.) is added in one portion. The resulting green solution is stirred for 25 minutes and poured into a precooled (5°–10° C.) mixture of water (150 ml.), acidified to pH 1.5 with dilute phosphoric acid (40%) and benzene (100 ml.) with vigorous stirring. The 6-[D(+)- α -phenoxybutyramido]thiopenicillanic acid is extracted into benzene and a further extraction with fresh benzene is made. The combined extracts are washed and dried. Potassium 2-ethylhexanoate (0.005 mole) is added as a 50% solution of potassium 2-ethylhexanoate in butanol. Skellysolve B is added to the solution with cooling and shaking until the solution becomes cloudy, and an oil separates. The solution is decanted and flashed to dryness. The residue is triturated with ether, and a white solid forms which is removed by filtration, washed with dry ether, dried in vacuo and found to weigh 2.5 gm. The product, potassium 6-[D(+)- α -phenoxybutyramido]thiopenicillanate, is found to have a melting point of 140°–145° C. with decomposition, and the structure is confirmed by infrared analysis.

Preparation 21.—Preparation of potassium 6-[D,L- α -phenoxypropionamido]thiopenicillanate

Potassium 6-[D,L- α -phenoxypropionamido]penicillanate (30.0 gm.) is dissolved in a mixture of 100 ml. ice water and 100 ml. trichlorethylene. After cooling the mixture to 5° C., 6 N hydrochloric acid is added with stirring until a pH of 2 is attained. The trichlorethylene phase is separated and maintained at 5° C. The aqueous phase is extracted again with 50 ml. of trichlorethylene and the trichlorethylene extracts are combined, mixed with 40 ml. of anhydrous magnesium sulfate and stirred in an ice bath for 30 minutes. The combined extracts are then filtered and the filter cake is washed with 50 ml. of trichlorethylene. The filtrates are placed together with 250 ml. of dimethylformamide in a one-liter 3-necked flask with a drying tube vent and cooled to -3° C. in an ice-acetone bath. To the chilled filtrates is then added 10.2 ml. of 2,6-lutidine and then ethylchloroformate (8.7 ml.) over a five-minute period after which the resulting solution of mixed anhydride is stirred in the ice bath for 30 minutes. An anhydrous solution of 16.8 gm. of sodium hydrosulfide trihydrate in 150 ml. of dimethylformamide is mixed with the mixed anhydride solution over a period of five minutes and the resulting slurry is stirred for one hour at 0° C. The slurry is then slowly decanted into 1500 ml. of ice water having a pH of 1.9. The pH of the mixture is maintained at about 2 by adjustment with 6 N hydrochloric acid. The aqueous solution of 6-[D,L- α -phenoxypropionamido]thiopenicillanic acid is extracted and re-extracted with trichlorethylene. The combined trichlorethylene extracts are dried over anhydrous magnesium sulfate in an ice bath and placed under vacuum for 30 minutes to remove hydrogen sulfide. The magnesium sulfate is then filtered off and washed on the filter with trichlorethylene. To the combined filtrates is added 70 ml. of a 22% solution of potassium ethylhexanoate in methyl isobutyl ketone whereupon the product, potassium 6-[D,L- α -phenoxypropionamido]thiopenicillanate, crystallizes out of solution. The slurry is stirred for 20 minutes at room temperature and thereafter in an ice bath for 75 minutes while the product crystallizes. The product is collected by filtration, washed with trichlorethylene, vacuum dried over P₂O₅ for 18 hours and thereafter found to weigh 23.9 gm.

Preparation 22.—Preparation of potassium 6-[D,L- α -phenoxybutyramido]thiopenicillanate

Potassium 6-[D,L- α -phenoxybutyramido]penicillanate (30.0 gm.) is dissolved in a mixture of 100 ml. ice water and 100 ml. trichlorethylene. After cooling the mixture to 5° C., 6 N hydrochloric acid is added with stirring until a pH of 2 is attained. The trichlorethylene phase is separated and maintained at 5° C. The aqueous phase is extracted again with 50 ml. of trichlorethylene and the trichlorethylene extracts are combined, mixed with 40 gm. of anhydrous magnesium sulfate and stirred in an ice bath for 30 minutes. The combined extracts are then filtered, and the filter cake is washed with 50 ml. trichlorethylene. The filtrates are placed together with 250 ml. dimethylformamide in a one-liter 3-necked flask with a drying tube vent and cooled to -3° C. in an ice-acetone bath. To the chilled filtrates is then added 10.2 ml. 2,6-lutidine and then ethylchloroformate, 8.7 ml. over a five-minute period after which the resulting solution of mixed anhydride is stirred in the ice bath for 30 minutes. An anhydrous solution of 16.8 gm. of sodium hydrosulfide trihydrate in 150 ml. of dimethylformamide is mixed with the mixed anhydride solution over a period of five minutes and the resulting slurry is stirred for one hour at 0° C. The slurry is then slowly decanted into 1500 ml. of ice water having a pH of 1.9. The pH of the mixture is maintained at about two by adjustment with 6 N hydrochloric acid. The aqueous solution of 6-[D,L- α -phenoxybutyramido]thiopenicillanic acid is extracted with trichlorethylene. The combined trichlorethylene extracts are dried over an-

hydrous magnesium sulfate on an ice bath and placed under vacuum for 30 minutes to remove hydrogen sulfide. The magnesium sulfate is then filtered off and washed on the filter with trichlorethylene. To the combined filtrates is added 70 ml. of a 22% solution of potassium ethylhexanoate in methyl isobutyl ketone whereupon the product, potassium 6-[D,L- α -phenoxybutyramido]thiopenicillanate, crystallizes out of solution. The slurry is stirred for 20 minutes at room temperature and thereafter in an ice bath for 75 minutes while the product crystallizes. The product is collected by filtration, washed with trichlorethylene, vacuum-dried over P₂O₅ for 18 hours, and thereafter the structure is confirmed by nuclear magnetic resonance and infrared absorption data.

Preparation 23.—Preparation of 6-aminothiopenicillanic acid

A fermentation broth is prepared by the fermentation of *Escherichia coli* under submerged aerobic conditions according to conventional procedures and found to contain 5,270 penicillin amidase units per ml.

A solution of 2.5 gm. calcium nitrate dihydrate dissolved in 6 ml. of water is added to one liter of such fermentation broth. After mixing, the broth is filtered, and the filtered mat washed with 150 ml. water. The filtered mat is then suspended in 200 ml. of water to which is added 5 ml. of toluene, and the suspension is stirred for three hours. After stirring, the suspension is filtered and the collected solid materials washed with 100 ml. of water. The filtrate is stirred with 1 gm. activated carbon (Darco KB) and 1.2 ml. of "Quaternary Ammonium Salt Mixture No. I." "Quaternary Ammonium Salt Mixture No. I" is commercially available from Armour & Company of Chicago, Ill., under the trademark of "Arquad 16-50" and is a liquid quaternary ammonium salt mixture containing, by weight, about 45% hexadecyltrimethylammonium chloride, about 3% octadecyltrimethylammonium chloride, about 2% octadecenyltrimethylammonium chloride, about 35% isopropanol, about 14% water, and about 1% sodium chloride.

After thorough mixing, all solid materials are removed from the mixture by filtration, and there is obtained 280 ml. of an essentially pure aqueous solution of penicillin amidase assaying 1950 penicillin amidase units per ml. and containing about 10% of the penicillin amidase originally present in the broth.

Benzylthiopenicillin (8 gm.) is prepared by the procedure described in United States Patent No. 2,751,378 and added to 400 ml. of penicillin amidase solution, prepared according to the procedure described above. This suspension is maintained at pH 8.0 and 35° C. for four hours, during which time the enzyme brings about the enzymatic hydrolysis of the benzylthiopenicillin. The benzylthiopenicillin and phenylacetate (produced during the hydrolysis) are removed at pH 2 and 5° C. with methyl isobutyl ketone. After extraction, a portion of the liquor (250 ml.) is adjusted to pH 7 with sodium hydroxide and vacuum concentrated to 20 ml. The concentrate is adjusted to pH 4 with hydrochloric acid (6 N) and cooled to 5° C. and allowed to stand for 20 hours at 5° C. during which time crystallization occurs. The crystals are filtered, washed with water (10 ml.) and then dry acetone. The 6-aminothiopenicillanic acid is recovered, weighs 0.29 gm. and the presence of the

group and β -lactam ring is confirmed by infrared analysis.

Preparation 24.—Preparation of 6-(α -aminophenylacetamido)-thiopenicillanic acid

6-(α -carboxybenzoyloxyaminophenylacetamido)penicillanic acid which is obtained by the reaction of equivalent quantities of 6-(α -aminophenylacetamido)penicillanic acid and benzyl chlorocarbonate in aqueous sodium hy-

dioxide is dissolved in dimethylformamide (125 ml.) and cooled to 5° C. 2,6-lutidine (2.2 gm.) and ethyl chloroformate (2.2 gm.) are added dropwise to the solution. After stirring for 15 minutes, a mixture of sodium hydrosulfide (4.5 gm.) in dimethylformamide (50 ml.) is added in one portion. The solution turns brown and is stirred for 30 minutes and then is poured into water (1000 ml.). The pH is adjusted to 2 with dilute sulfuric acid. The 6-(α -carbobenzoyloxyaminophenylacetamido)thiopenicillanic acid is extracted into ether and dried over anhydrous magnesium sulfate. Potassium 2-ethylhexanoate (4 gm.) is added and potassium 6-(α -carbobenzoyloxyaminophenylacetamido)penicillanate precipitates. The salt is dissolved in ethyl acetate and all traces of water are removed. The residue is slurried with Skellysolve B, filtered, and dried. The potassium 6-(α -carbobenzoyloxyaminophenylacetamido)thiopenicillanate weighs 3 gm., is found to have a melting point of greater than 100° C. with decomposition, and to contain the β -lactam ring as shown by infrared analysis.

Potassium 6-(α -carbobenzylaminophenylacetamido)thiopenicillanate (5 gm.) is dissolved in water (75 ml.). Palladium (5 gm. of 30%) is added and the mixture hydrogenated at 50 p.s.i. for 30 minutes. The pH is adjusted to 2 with dilute sulfuric acid, and the palladium collected by filtration. Sodium hydroxide (10%) is added to the filtrate until the pH is adjusted to 5. The 6-(α -aminophenylacetamido)thiopenicillanic acid is recovered and found to contain the β -lactam ring as shown by infrared analysis.

Preparation 25.—Preparation of D,L-6-[α -amino-(2-thienyl)acetamido]thiopenicillanic acid

α -(2-thienyl)glycine [5.0 gm., 0.032 mole, obtained by the method disclosed in Ber. 19, 2115 (1886)] is suspended in 35 ml. of methylene chloride and cooled to -7° C. with stirring and in the presence of calcium chloride dessicant. Phosphorus pentachloride (10 gm., 0.048 mole) is added in one portion causing the temperature to rise to -3° C. The mixture is stirred for one-half hour while maintaining the temperature at -5° C. to 0° C., 15 ml. of methylene chloride is added, and stirring at -5° C. is continued for another one-half hour. Then, 10 drops of dimethyl formamide is added and another 20 ml. of methylene chloride is added to thin the mixture. The mixture is stirred rapidly and a purple slurry results. The product, D,L- α -(2-thienyl)glycyl chloride hydrochloride, is collected by filtration under reduced pressure, washed three times with methylene chloride and dried in vacuo over P_2O_5 . The weight of the product is 5.9 gm. which represents a 72% yield.

The pH of a solution of 6-aminothiopenicillanic acid (0.019 mole) in 80 ml. of water is adjusted to 6.3 by the addition of a 10% by weight solution of NaOH with stirring. The solution is then diluted with 340 ml. of acetone and cooled to -5° C. The pH of the solution is then adjusted quickly to 2.5 by the addition of 6 N HCl to the well-stirred mixture. To this solution is added D,L- α -(2-thienyl)glycyl chloride hydrochloride (5.9 gm., 0.028 mole) over a 20-minute period, the pH being kept at 2 to 2.5 by intermittent additions of 10% NaOH. The solution is stirred for 5 minutes after completion of the addition of the chloride hydrochloride and the pH is then adjusted to 4.8 by the addition of 10% NaOH. The acetone is removed under reduced pressure at 30° to 34° C. and the solution is filtered to remove insoluble material. The filtrate, having a pH of 4, is cooled to 5° C., adjustable to a pH of 7 by the addition of 10% NaOH, layered with 20 ml. of methyl isobutyl ketone and acidified to pH 2 with 20% H_2SO_4 . Upon removal of the methyl isobutyl ketone layer, the color of the remaining aqueous layer clarifies. This aqueous layer is extracted again with 20 ml. of methyl isobutyl ketone and the extracts are discarded. The aqueous layer is then cooled to 0° C. and extracted at pH 2 with a 10% solution containing dioctyl sodium

sulfosuccinate (5.3 gm., 0.012 mole) in methyl isobutyl ketone. The methyl isobutyl ketone extract is separated by decanting, filtered through anhydrous Na_2SO_4 and concentrated slightly by evaporation under reduced pressure at 30° C. It is then neutralized to pH 5.3 by the addition of triethylamine. The solid product which forms is collected by filtration under reduced pressure, slurried with ether, refiltered and dried in vacuo over P_2O_5 . The product, D,L-6-[α -amino-(2-thienyl)acetamido]thiopenicillanic acid is found to contain the β -lactam structure as shown by infrared analysis.

Preparation 26

In the general procedure of Preparation 25, the α -(2-thienyl)-glycine is replaced by 0.032 mole of

α -(3-thienyl)glycine,
 α -(5-ethyl-2-thienyl)glycine,
 α -(5-methyl-2-thienyl)glycine,
 α -(5-t-butyl-2-thienyl)glycine,
 α -(2,5-dimethyl-3-thienyl)glycine,
 α -(5-chloro-2-thienyl)glycine,
 α -(5-bromo-2-thienyl)glycine,
 α -(5-phenyl-3-chloro-2-thienyl)glycine,
 α -(3,5-dimethyl-2-thienyl)glycine,
 α -(5-cyclohexyl-2-thienyl)glycine,
 α -(5-diethylamino-2-thienyl)glycine,
 α -(4-methylsulfonyl-2-thienyl)glycine,
 α -(3-ethylthio-2-thienyl)glycine, and
 α -(4-cycloheptyloxy-2-thienyl)glycine,

respectively, to produce

D,L-6-[α -amino-(3-thienyl)acetamido]thiopenicillanic acid,
6-[α -amino-(5-ethyl-2-thienyl)acetamido]thiopenicillanic acid,
6-[α -amino-(5-methyl-2-thienyl)acetamido]thiopenicillanic acid,
6-[α -amino-(5-t-butyl-2-thienyl)acetamido]thiopenicillanic acid,
6-[α -amino-(2,5-dimethyl-3-thienyl)acetamido]thiopenicillanic acid,
6-[α -amino-(5-chloro-2-thienyl)acetamido]thiopenicillanic acid,
6-[α -amino-(5-bromo-2-thienyl)acetamido]thiopenicillanic acid,
6-[α -amino-(5-phenyl-3-chloro-2-thienyl)acetamido]thiopenicillanic acid,
6-[α -amino-(3,5-dimethyl-2-thienyl)acetamido]thiopenicillanic acid,
6-[α -amino-(5-cyclohexyl-2-thienyl)acetamido]thiopenicillanic acid,
6-[α -amino-(5-diethylamino-2-thienyl)acetamido]thiopenicillanic acid,
6-[α -amino-(4-methylsulfonyl-2-thienyl)acetamido]thiopenicillanic acid,
6-[α -amino-(3-ethylthio-2-thienyl)acetamido]thiopenicillanic acid and
6-[α -amino-(4-cycloheptyloxy-2-thienyl)acetamido]thiopenicillanic acid,

respectively, which are isolated and found to contain the β -lactam ring as shown by infrared analysis.

Preparation 27.—Preparation of 6-(α -aminophenylacetamido)thiopenicillanic acid

D(-)- α -phenylglycine (25.0 gm., 0.165 mole $[\alpha]_D = -153^\circ$) is suspended in methylene dichloride (500 ml.) and phosphorus pentachloride (63.0 gm., 0.30 mole) is added to the suspension at 3° C. After 10 minutes, dimethylformamide (2 ml.) is added to the reaction mixture which is then stirred for 10 minutes in an ice-bath and thereafter for 2 hours at room temperature. The resulting product, D(-)- α -phenylglycylchloride hydrochloride, is collected by filtration, washed with methylene dichloride and ether, dried in vacuo over P_2O_5 for 2 hours and thereafter found to weigh 19.6 gm.

6-aminothiopenicillanic acid (0.019 mole) is dissolved in water (80 ml.) and the pH of the solution is adjusted to 6.3 by the addition of a 10% by weight solution of sodium hydroxide with stirring. The solution is then diluted with acetone (340 ml.) and cooled to -5° C. The pH of the solution is then adjusted quickly to 2.5 by the addition of 6 N hydrochloric acid to the well-stirred mixture. To this solution is added D(—)- α -phenylglycylchloride hydrochloride (0.028 mole) over a 20-minute period, the pH being kept at 2 to 2.5 by intermittent additions of 10% sodium hydroxide. The solution is stirred for 5 minutes after completion of the addition of the chloride hydrochloride and the pH is then adjusted to 4.8 by the addition of 10% sodium hydroxide. The acetone is removed under reduced pressure at $30\text{--}34^{\circ}$ C. and the solution is filtered to remove insoluble material. The filtrate, having a pH of 4, is cooled to 5° C., adjusted to a pH of 7 by the addition of 10% sodium hydroxide, layered with methyl isobutyl ketone (20 ml.), and acidified to pH 2 with 20% sulfuric acid. Upon removal of the methyl isobutyl ketone layer, the color of the remaining aqueous layer clarifies. This aqueous layer is extracted again with methyl isobutyl ketone (20 ml.) and the extracts are discarded. The aqueous layer is then cooled to 0° C. and extracted at pH 2 with a 10% solution containing dioctyl sodium sulfosuccinate (5.3 gm., 0.012 mole) in methyl isobutyl ketone. The methyl isobutyl ketone extract is separated by decanting, filtered through anhydrous sodium sulfate and concentrated slightly by evaporation under reduced pressure at 30° C. It is then neutralized to pH 5.3 by the addition of triethylamine. The solid product which forms is collected by filtration under reduced pressure, slurried with ether, re-filtered, and dried in vacuo over phosphorus pentoxide. The product, 6-(α -aminophenylacetamido)thiopenicillanic acid, is found to contain the β -lactam ring as shown by infrared analysis.

Preparation 28

In the general procedure of Preparation 27, the D(—)- α -phenylglycine is replaced by 0.165 mole of

α -p-chlorophenylglycine,
 α -p-methoxyphenylglycine,
L(+)— α -phenylglycine,
 α -4-diethylaminophenylglycine,
 α -4-trifluoromethylphenylglycine,
 α -2,4-dibromophenylglycine,
 α -2-nitrophenylglycine,
 α -3-methylphenylglycine,
 α -4-sulfamylphenylglycine,
 α -2-iodophenylglycine,
 α -4-t-butylphenylglycine,
 α -2-acetamidophenylglycine,
 α -3-nitrophenylglycine,
 α -3,4-dimethoxyphenylglycine,
 α -4-dimethylaminophenylglycine,
 α -2,4-dichlorophenylglycine,
 α -4-isopropylphenylglycine,
 α -3-bromophenylglycine,
 α -3-iodophenylglycine,
 α -2-diethylaminophenylglycine,
 α -2-trifluoromethylphenylglycine,
 α -4-fluorophenylglycine, and
 α -3,4,5-trifluoromethylphenylglycine,

respectively, to produce

6-(α -amino-p-chlorophenylacetamido)thiopenicillanic acid,
6-(α -amino-p-methoxyphenylacetamido)thiopenicillanic acid,
6-[L(+)— α -aminophenylacetamido]thiopenicillanic acid,
6-(α -amino-4-diethylaminophenylacetamido)thiopenicillanic acid,
6-(α -amino-4-trifluoromethylphenylacetamido)thiopenicillanic acid,

44
6-(α -amino-2,4-dibromophenylacetamido)thiopenicillanic acid,
6-(α -amino-2-nitrophenylacetamido)thiopenicillanic acid,
6-(α -amino-3-methylphenylacetamido)thiopenicillanic acid,
6-(α -amino-4-t-butylphenylacetamido)thiopenicillanic acid,
6-(α -amino-2-acetamidophenylacetamido)thiopenicillanic acid,
6-(α -amino-3-nitrophenylacetamido)thiopenicillanic acid,
6-(α -amino-3,4-dimethoxyphenylacetamido)thiopenicillanic acid,
6-(α -amino-4-dimethylaminophenylacetamido)thiopenicillanic acid,
6-(α -amino-2,4-dichlorophenylacetamido)thiopenicillanic acid,
6-(α -amino-4-isopropylphenylacetamido)thiopenicillanic acid,
6-(α -amino-3-bromophenylacetamido)thiopenicillanic acid,
6-(α -amino-3-iodophenylacetamido)thiopenicillanic acid,
6-(α -amino-diethylaminophenylacetamido)thiopenicillanic acid,
6-(α -amino-2-trifluoromethylphenylacetamido)thiopenicillanic acid,
6-(α -amino-4-fluorophenylacetamido)thiopenicillanic acid, and
6-(α -amino-3,4,5-trifluoromethylphenylacetamido)thiopenicillanic acid,

35 respectively, which are isolated and found to contain the β -lactam ring as shown by infrared analysis.

Preparation 29

In the general procedure of Preparation 27, the D(—)- α -phenylglycine is replaced by 0.165 mole of

α -(1-naphthyl)glycine,
 α -(2-naphthyl)glycine,
 α -(1-chloro-2-naphthyl)glycine,
 α -(2-methyl-7-naphthyl)glycine,
 α -(6-nitro-1-naphthyl)glycine,
 α -(2,7-dibromo-3-naphthyl)glycine,
 α -(4-trifluoromethyl-1-naphthyl)glycine,
 α -(8-iodo-1-naphthyl)glycine,
 α -(1-methoxy-2-naphthyl)glycine, and
 α -(4-acetamido-1-naphthyl)glycine,

55 respectively, to produce

6-[α -amino-(1-naphthyl)acetamido]thiopenicillanic acid,
6-[α -amino-(2-naphthyl)acetamido]thiopenicillanic acid,
6-[α -amino-(1-chloro-2-naphthyl)acetamido]thiopenicillanic acid,
6-[α -amino-(2-methyl-7-naphthyl)acetamido]thiopenicillanic acid,
6-[α -amino-(6-nitro-1-naphthyl)acetamido]thiopenicillanic acid,
6-[α -amino-(2,7-dibromo-3-naphthyl)acetamido]thiopenicillanic acid,
6-[α -amino-(4-trifluoromethyl-1-naphthyl)acetamido]thiopenicillanic acid,
6-[α -amino-(8-iodo-1-naphthyl)acetamido]thiopenicillanic acid,
6-[α -amino-(1-methoxy-2-naphthyl)acetamido]thiopenicillanic acid,
6-[α -amino-(4-acetamido-1-naphthyl)acetamido]thiopenicillanic acid,

75 respectively, which are isolated and found to contain the β -lactam ring as shown by infrared analysis.

*Preparation 30.—Preparation of sodium and *N,N'*-dibenzylethylenediamine salts of 5-methyl-3-phenyl-4-isoxazolylthiopenicillin*

Ethyl chloroformate (2.65 gm., 0.025 mole) is added to a solution of triethylamine salt of 5-methyl-3-phenyl-4-isoxazolylpenicillin (11.9 gm., 0.025 mole) in dimethylformamide (125 ml.) at 5° C. Sodium hydrosulfide (5.6 gm., 0.1 mole) is added to the mixture after stirring for 10 minutes. The mixture is stirred for 20 minutes and turns green and then dark brown. Water (1000 ml.) is added and the mixture acidified to pH 2 with dilute sulfuric acid. The 5-methyl-3-phenyl-4-isoxazolylthiopenicillin is extracted into ether and dried over anhydrous magnesium sulfate. The drying agent is separated and a solution of sodium 2-ethylhexanoate in n-butanol is added. A crystalline product, sodium salt of 5-methyl-3-phenyl-4-isoxazolylthiopenicillin forms and infrared analysis confirms the structure. 3.1 gm. of the sodium salt is dissolved in water (15 ml.) and a solution of *N,N'*-dibenzylethylenediamine acetate (1 gm.) in water is added. A gum forms and is dissolved in acetone (20 ml.). The solution is cooled and crystals of the product, *N,N'*-dibenzylethylenediamine salt of 5-methyl-3-phenyl-4-isoxazolylthiopenicillin, form and are collected by filtration and dried. The product is found to contain the β -lactam ring by infrared analysis, have a melting point of 850–90° C. with decomposition and have the following elemental analysis:

Calculated for $C_{27}H_{19}N_3O_4S_2 \cdot 1\frac{1}{2}H_2O$: C, 57.6%; H, 5.73%; S, 11.35%. Found: C, 57.5%; H, 5.4%; S, 10.9%.

*Preparation 31.—Preparation of *N,N'*-dibenzylethylenediamine salt of 3-(o-chlorophenyl) - 5 - methyl-5-isoxazolylthiopenicillin*

Phosphoric acid (40%) is added to a solution of the sodium salt 3-(o-chlorophenyl)-5-methyl-4-isoxazolylthiopenicillin (9.14 gm., 0.02 mole) dissolved in cold water (50 ml.) until at pH of 2 is attained. The penicillin acid is extracted from this solution into ethyl acetate, washed with water, and dried over anhydrous magnesium sulfate. The ethyl acetate is evaporated under reduced pressure to leave a residue. The residue is dissolved in dimethylformamide (20 ml.) and cooled to 0° C. 2,6-lutidine (2.14 gm., 0.02 mole) is added (followed by the dropwise addition of ethyl chloroformate (2.16 gm., 0.02 mole). The mixture is stirred for 10 minutes and a suspension of sodium hydrosulfide trihydrate (4.6 g., 0.04 mole) in dimethylformamide (70 ml.) is added all at once. The solution is stirred for 25 minutes at 0° C. and turns blue. The mixture is poured into water (600 ml.), layered with ethyl acetate, and acidified to pH 2 with phosphoric acid (40%) with vigorous stirring. The 3-(o-chlorophenyl)-5-methyl-4-isoxazolylthiopenicillin is extracted into ethyl acetate, washed with water, and then extracted into a solution of sodium bicarbonate (2 gm.) in water (40 ml.) followed by an extraction employing water (40 ml.) *N,N'*-dibenzylethylenediamine acetate (3.64 gm., 0.01 mole) in water (30 ml.) is added to the combined extracts and the precipitate is filtered, washed with water, and dried by suction. The solid weighs 10 gm. and is treated with methanol and collected by filtration and dried in *vacuo* over phosphorus pentoxide. The crystalline product, *N,N'*-dibenzylethylenediamine salt of 3-(o-chlorophenyl)-5-methyl-4-isoxazolylthiopenicillin, weighs 3 gm. and is found to have a melting point of 131°–133° C. with decomposition and an infrared spectrum that confirms the structure.

Preparation 32

The following compounds are prepared according to the general procedure of Preparations 30 and 31 above

using a salt of the corresponding penicillin as the starting material:

- 3-m-chlorophenyl-5-methyl-4-isoxazolylthiopenicillin,
 3-(2,4-dichlorophenyl)-5-methyl-4-isoxazolylthiopenicillin,
 3-(3,4-dichlorophenyl)-5-methyl-4-isoxazolylthiopenicillin,
 3-p-tolyl-5-methyl-4-isoxazolylthiopenicillin,
 3-o-nitrophenyl-5-methyl-4-isoxazolylthiopenicillin,
 3-m-nitrophenyl-5-methyl-4-isoxazolylthiopenicillin,
 3-p-nitrophenyl-5-methyl-4-isoxazolylthiopenicillin,
 3-p-bromophenyl-5-methyl-4-isoxazolylthiopenicillin,
 3-p-fluorophenyl-5-methyl-4-isoxazolylthiopenicillin,
 3-p-methylsulfonylphenyl-5-methyl-4-isoxazolylthiopenicillin,
 3-p-methoxyphenyl-5-methyl-4-isoxazolylthiopenicillin,
 3-p-trifluoromethylphenyl-5-methyl-4-isoxazolylthiopenicillin,
 3-o-methoxyphenyl-5-methyl-4-isoxazolylthiopenicillin,
 3-p-ethoxyphenyl-5-methyl-4-isoxazolylthiopenicillin,
 3-(3,4-dimethoxyphenyl)-5-methyl-4-isoxazolylthiopenicillin,
 3-p-dimethylaminophenyl-5-methyl-4-isoxazolylthiopenicillin,
 3- α -naphthyl-5-methyl-4-isoxazolylthiopenicillin,
 3- β -naphthyl-5-methyl-4-isoxazolylthiopenicillin,
 3-phenyl-5-ethyl-4-isoxazolylthiopenicillin,
 3-p-chlorophenyl-5-ethyl-4-isoxazolylthiopenicillin,
 3-phenyl-5-isopropyl-4-isoxazolylthiopenicillin,
 3-phenyl-5-methylmercapto-4-isoxazolylthiopenicillin,
 3-methyl-5-o-chlorophenyl-4-isoxazolylthiopenicillin,
 3-methyl-5-p-bromophenyl-4-isoxazolylthiopenicillin,
 3-methyl-5-o-iodophenyl-4-isoxazolylthiopenicillin,
 3-methyl-5-(2,4-dichlorophenyl)-4-isoxazolylthiopenicillin,
 3-methyl-5-m-nitrophenyl-4-isoxazolylthiopenicillin,
 3-methyl-5-p-tolyl-4-isoxazolylthiopenicillin,
 3-methyl-5-p-nitrophenyl-4-isoxazolylthiopenicillin,
 3-methyl-5-p-methoxyphenyl-4-isoxazolylthiopenicillin,
 3-methyl-5-p-ethoxyphenyl-4-isoxazolylthiopenicillin,
 3-methyl-5-(2,6-dimethoxyphenyl)-4-isoxazolylthiopenicillin,
 3-methyl-5-p-methylsulfonylphenyl-4-isoxazolylthiopenicillin,
 3-methyl-5-p-fluorophenyl-4-isoxazolylthiopenicillin,
 3-methyl-5-p-cyanophenyl-4-isoxazolylthiopenicillin,
 3-methyl-5-p-methylmercaptophenyl-4-isoxazolylthiopenicillin,
 3-methyl-5-p-dimethylaminophenyl-4-isoxazolylthiopenicillin,
 3-methyl-5- α -naphthyl-4-isoxazolylthiopenicillin,
 3-methyl-5- β -naphthyl-4-isoxazolylthiopenicillin,
 3-ethyl-5-phenyl-4-isoxazolylthiopenicillin,
 3-ethyl-5-p-chlorophenyl-4-isoxazolylthiopenicillin,
 3-isopropyl-5-phenyl-4-isoxazolylthiopenicillin,
 3-tert. butyl-5-methyl-4-isoxazolylthiopenicillin,
 3-methyl-5-p-trifluoromethylphenyl-4-isoxazolylthiopenicillin,
 3-methyl-5-cyclohexyl-4-isoxazolylthiopenicillin,
 3-cyclohexyl-5-methyl-4-isoxazolylthiopenicillin,
 3- α -furyl-5-methyl-4-isoxazolylthiopenicillin,
 3- α -thienyl-5-methyl-4-isoxazolylthiopenicillin,
 respectively, which are isolated as their solid water-soluble sodium salts.

Preparation 33

In the procedure of Preparation 31, the sodium salt of 3-(o-chlorophenyl)-5-methyl-4-isoxazolylpenicillin is replaced by 0.02 mole of the sodium salt of

- 3,5-diphenyl-4-isoxazolylpenicillin,
 3-methyl-5-phenyl-4-isoxazolylpenicillin,
 3,5-dimethyl-4-isoxazolylpenicillin,
 5-benzyl-3-methyl-4-isoxazolylpenicillin,
 3-methyl-5-styryl-4-isoxazolylpenicillin,

5-tert. butyl-3-phenyl-4-isoxazolylpenicillin,
 5-(2-furyl)-3-methyl-4-isoxazolylpenicillin,
 3-methyl-5-(3',5'-dimethyl-4'-isoxazolyl)-4-isoxazolyl-
 penicillin,
 3-methyl-5-(2-thienyl)-4-isoxazolylpenicillin,
 3-(p-chlorophenyl)-5-methyl-4-isoxazolylpenicillin,
 3-methyl-5-methylmercapto-4-isoxazolylpenicillin,
 5-(p-chlorophenyl)-3-methyl-4-isoxazolylpenicillin,
 3-methyl-5-(o-nitrophenyl)-4-isoxazolylpenicillin,
 5-isopropyl-3-methyl-4-isoxazolylpenicillin, and
 5-methyl-3-(p-chlorophenyl)-4-isoxazolylpenicillin,

to produce the sodium salt of

3,5-diphenyl-4-isoxazolylthiopenicillin,
 3-methyl-5-phenyl-4-isoxazolylthiopenicillin,
 3,5-dimethyl-4-isoxazolylthiopenicillin,
 5-benzyl-3-methyl-4-isoxazolylthiopenicillin,
 3-methyl-5-styryl-4-isoxazolylthiopenicillin,
 5-tert. butyl-3-phenyl-4-isoxazolylthiopenicillin,
 5-(2-furyl)-3-methyl-4-isoxazolylthiopenicillin,
 3-methyl-5-(3',5'-dimethyl-4'-isoxazolyl)-4-isoxazolyl-
 thiopenicillin,
 3-methyl-5-(2-thienyl)-4-isoxazolylthiopenicillin,
 3-(p-chlorophenyl)-5-methyl-4-isoxazolylthiopenicillin,
 3-methyl-5-methylmercapto-4-isoxazolylthiopenicillin,
 5-(p-chlorophenyl)-3-methyl-4-isoxazolylthiopenicillin,
 3-methyl-5-(o-nitrophenyl)-4-isoxazolylthiopenicillin,
 5-isopropyl-3-methyl-4-isoxazolylthiopenicillin, and
 5-methyl-3-(p-chlorophenyl)-4-isoxazolylthiopenicillin,
 respectively, which are isolated as their solid, water-
 soluble sodium salts.

*Preparation 34.—Preparation of potassium
 6-(benzoylureido)thiopenicillanate*

Dilute sulfuric acid (20%) is added to an ice-cold solution of sodium 6-(benzoylureido)penicillanate (11.7 gm., 0.03 mole) dissolved in water until a pH of 2 is attained. The penicillin acid is extracted from this solution into chilled ethyl acetate three times, washed with chilled water and a saturated aqueous solution of sodium chloride and filtered through anhydrous magnesium sulfate. The ethyl acetate is evaporated under reduced pressure at 25° to 30° C. to leave a residual white solid. The residue is dissolved in dimethylformamide (150 ml.) and cooled to -5° C. Triethylamine (4.2 ml., 0.03 mole) is added, followed by the addition of ethyl chloroformate (2.7 ml., 0.03 mole) in one portion. The mixture is stirred for 30 minutes at -10° to -5° C. and a chilled solution of sodium hydrosulfide trihydrate (6.6 gm., 0.06 mole) in dimethylformamide (120 ml.) is added in one portion. The solution is stirred at -5° C. for 30 minutes and poured into ice water (1100 ml.). The pH is adjusted to 2 with cold dilute sulfuric acid (20%), giving a pale yellow precipitate. The precipitate is collected by suction and found to be soluble in ethyl acetate and methyl isobutyl ketone but not very soluble in ether. The precipitate, 6-(benzoylureido)thiopenicillanate acid is dissolved in ethyl acetate, the aqueous layer separated and the solution washed with saturated sodium chloride solution and dried at 5° to 10° C. over anhydrous magnesium sulfate. Potassium 2-ethylhexanoate (10.9 gm., 0.03 mole) is added as a 50% solution of potassium 2-ethylhexanoate in n-butanol. A yellow solid precipitates and after brief cooling is collected by suction. The solid is hygroscopic and is triturated with anhydrous ether. The product, potassium 6-(benzoylureido)thiopenicillanate weighs 3.5 gm. and is found to have a melting point of 70° to 85° C. with decomposition and an infrared spectrum consistent with the structure.

The ethyl acetate mother liquor is diluted to 500 ml. with anhydrous ether and a solid precipitates. The solid, potassium 6-(benzoylureido)thiopenicillanate, weighs 1.5 gm. and is found to have a melting point of 142° to 164° C. with decomposition, an infrared spectrum consistent

with the structure, and the following elemental analysis:

Calculated (C₁₆H₁₈N₃O₄S₂K): C, 46.00%; H, 3.86%; S, 15.4%. Found: C, 43.52%; H, 4.25%; S, 12.2%.

Starting materials of the type of the formula

10 wherein R¹, R², R³ and R⁴ are each a member selected from the group consisting of hydrogen, chloro, bromo, fluoro, iodo, nitro, sulfamyl, trifluoromethyl, (lower) alkyl, (lower)alkoxy, (lower)alkylthio, di(lower)alkylamino, (lower)alkanoyl, (lower)alkylsulfonyl, cycloalkyl radicals having from 5 to 7 carbon atoms inclusive, cycloalkoxy radicals having from 5 to 7 carbon atoms inclusive and radicals of the formulae

wherein n is a whole integer from 0 to 6 inclusive, wherein 25 X is a member selected from the group consisting of sulfur and oxygen and wherein R⁵, R⁶ and R⁷ are each a member selected from the group consisting of hydrogen, chloro, bromo, fluoro, iodo, nitro, (lower)alkyl, (lower)alkoxy, (lower)alkylthio, di(lower)alkylamino, (lower)alkanoyl, (lower)alkylsulfonyl, cycloalkyl radicals having from 5 to 7 carbon atoms inclusive, phenyl, benzyl, phenethyl and trifluoromethyl 30 are prepared by the reaction of the appropriate benzoylisocyanate, i.e., a compound having the formula

40 wherein R¹, R², R³ and R⁴ have the meaning set forth above, with 6-aminopenicillanic acid, preferably in the form of an easily hydrolyzed ester or of a salt of an alkali or alkaline earth metal or of a tertiary amine, e.g., a tertiary aliphatic amine such as triethylamine. The 45 conduct of the reaction is facilitated by the presence of an unreactive, anhydrous organic solvent, such as dimethylacetamide or methylene chloride; it is also convenient to use an excess of triethylamine as the solvent. An unreactive solvent is one which provides no active hydrogen. 50 Low temperatures, e.g., about 0° C. or room temperature, are preferred but not essential. Roughly equimolecular quantities of the two reagents are used. When formed as the triethylamine salt, the product is converted to the 55 free acid form and thence to other salts in the manner used with benzylpenicillin and other penicillins.

Preparation 35

In the procedure of Preparation 34, the sodium 6-(benzoylureido)penicillanate is replaced by 0.03 mole of the 60 potassium salt of the acids

6-(n-propylureido)penicillanic acid,
 6-(n-hexylureido)penicillanic acid,
 6-(n-octadecylureido)penicillanic acid,
 6-(cyclohexylureido)penicillanic acid,
 6-(p-chlorophenylureido)penicillanic acid,
 6-(m-methoxyphenylureido)penicillanic acid,
 6-(benzylureido)penicillanic acid,
 6-(cyclopentylureido)penicillanic acid,
 6-(p-tolylureido)penicillanic acid,
 6-(p-dimethylaminophenylureido)penicillanic acid,
 6-(phenylureido)penicillanic acid,
 6-(2-methylphenylureido)penicillanic acid,
 6-(methylureido)penicillanic acid,
 6-(2-nitrophenylureido)penicillanic acid,

6-(benzoylureido)penicillanic acid,
 6-(4'-nitrobenzoylureido)penicillanic acid,
 6-(2'-chlorobenzoylureido)penicillanic acid,
 6-(2'-methylbenzoylureido)penicillanic acid,
 6-(3',4',5'-trimethoxybenzoylureido)penicillanic acid,
 6-(4'-methylbenzoylureido)penicillanic acid,
 6-(4'-chlorobenzoylureido)penicillanic acid,
 6-(3',4'-dichlorobenzoylureido)penicillanic acid,
 6-(3'-nitrobenzoylureido)penicillanic acid,
 6-(2',4',6'-trimethoxybenzoylureido)penicillanic acid,
 6-(4'-ethoxybenzoylureido)penicillanic acid,
 6-(2',6'-dimethoxybenzoylureido)penicillanic acid,
 6-(2',4',6'-trimethylbenzoylureido)penicillanic acid,
 6-(2',6'-dichlorobenzoylureido)penicillanic acid,
 6-(2',6'-diethoxybenzoylureido)penicillanic acid,
 6-(2',6'-di-n-butoxybenzoylureido)penicillanic acid,
 6-(2',3',6'-trimethoxybenzoylureido)penicillanic acid,
 6-(2',4',6'-tribromobenzoylureido)penicillanic acid,
 6-(2',6'-di-n-propoxybenzoylureido)penicillanic acid,
 6-(2',6'-dimethoxy-4'-methylbenzoylureido)penicillanic acid,
 6-(4',6'-diethyl-2'-methoxybenzoylureido)penicillanic acid,
 6-(2'-ethoxy-6'-methoxybenzoylureido)penicillanic acid,
 6-(2'-phenylbenzoylureido)penicillanic acid,
 6-(2'-methoxybenzoylureido)penicillanic acid,
 6-(2',6'-dimethylbenzoylureido)penicillanic acid,
 6-(2'-chloro-6'-methylbenzoylureido)penicillanic acid,
 6-(2',6'-dimethoxy-3'-nitrobenzoylureido)penicillanic acid,
 6-(3',5'-dichloro-2',6'-dimethoxybenzoylureido)penicillanic acid,
 6-(3',5'-dibromo-2',6'-dimethoxybenzoylureido)penicillanic acid,
 6-(3'-bromo-2',6'-dimethoxybenzoylureido)penicillanic acid,
 6-(3'-chloro-2',6'-dimethoxybenzoylureido)penicillanic acid,
 6-(3',5'-diido-2',6'-dimethoxybenzoylureido)penicillanic acid,
 6-(3'-iodo-2',6'-dimethoxybenzoylureido)penicillanic acid,
 6-(4'-trifluoromethylbenzoylureido)penicillanic acid,
 6-(4'-isopropylbenzoylureido)penicillanic acid,
 6-(4'-iodobenzoylureido)penicillanic acid,
 respectively, to produce the potassium salts of
 6-(n-propylureido)thiopenicillanic acid,
 6-(n-hexylureido)thiopenicillanic acid,
 6-(n-octadecylureido)thiopenicillanic acid,
 6-(cyclohexylureido)thiopenicillanic acid,
 6-(p-chlorophenylureido)thiopenicillanic acid,
 6-(m-methoxyphenylureido)thiopenicillanic acid,
 6-(benzylureido)thiopenicillanic acid,
 6-(cyclopentylureido)thiopenicillanic acid,
 6-(p-tolylureido)thiopenicillanic acid,
 6-(p-dimethylaminophenylureido)thiopenicillanic acid,
 6-(phenylureido)thiopenicillanic acid,
 6-(2-methylphenylureido)thiopenicillanic acid,
 6-(methylureido)thiopenicillanic acid,
 6-(2-nitrophenylureido)thiopenicillanic acid,
 6-(benzoylureido)thiopenicillanic acid,
 6-(4'-nitrobenzoylureido)thiopenicillanic acid,
 6-(2'-chlorobenzoylureido)thiopenicillanic acid,
 6-(2'-methylbenzoylureido)thiopenicillanic acid,
 6-(3',4',5'-trimethoxybenzoylureido)thiopenicillanic acid,
 6-(4'-methylbenzoylureido)thiopenicillanic acid,
 6-(4'-chlorobenzoylureido)thiopenicillanic acid,
 6-(3',4'-dichlorobenzoylureido)thiopenicillanic acid,
 6-(3'-nitrobenzoylureido)thiopenicillanic acid,
 6-(2',4',6'-trimethoxybenzoylureido)thiopenicillanic acid,
 6-(4'-ethoxybenzoylureido)thiopenicillanic acid,
 6-(2',6'-dimethoxybenzoylureido)thiopenicillanic acid,

6-(2',4',6'-trimethylbenzoylureido)thiopenicillanic acid,
 6-(2',6'-dichlorobenzoylureido)thiopenicillanic acid,
 6-(2',6'-diethoxybenzoylureido)thiopenicillanic acid,
 6-(2',6'-di-n-butoxybenzoylureido)thiopenicillanic acid,
 5 6-(2',3',6'-trimethoxybenzoylureido)thiopenicillanic acid,
 6-(2',4',6'-tribromobenzoylureido)thiopenicillanic acid,
 6-(2',6'-di-n-propoxybenzoylureido)thiopenicillanic acid,
 6-(2',6'-dimethoxy-4'-methylbenzoylureido)thiopenicillanic acid,
 10 6-(4',6'-diethyl-2'-methoxybenzoylureido)thiopenicillanic acid,
 6-(2'-ethoxy-6'-methoxybenzoylureido)thiopenicillanic acid,
 15 6-(2'-phenylbenzoylureido)thiopenicillanic acid,
 6-(2'-methoxybenzoylureido)thiopenicillanic acid,
 6-(2',6'-dimethylbenzoylureido)thiopenicillanic acid,
 6-(2'-chloro-6'-methylbenzoylureido)thiopenicillanic acid,
 20 6-(2',6'-dimethoxy-3'-nitrobenzoylureido)thiopenicillanic acid,
 6-(3',5'-dichloro-2',6'-dimethoxybenzoylureido)thiopenicillanic acid,
 6-(3',5'-dibromo-2',6'-dimethoxybenzoylureido)thiopenicillanic acid,
 25 6-(3'-bromo-2',6'-dimethoxybenzoylureido)thiopenicillanic acid,
 6-(3'-chloro-2',6'-dimethoxybenzoylureido)thiopenicillanic acid,
 30 6-(3',5'-diido-2',6'-dimethoxybenzoylureido)thiopenicillanic acid,
 6-(3'-iodo-2',6'-dimethoxybenzoylureido)thiopenicillanic acid,
 35 6-(4'-trifluoromethylbenzoylureido)thiopenicillanic acid,
 6-(4'-isopropylbenzoylureido)thiopenicillanic acid, and
 6-(4'-iodobenzoylureido)thiopenicillanic acid,

respectively, each of which is isolated as its solid, water-soluble potassium salt and found to contain the β -lactam ring structure as shown by infrared analysis.

Preparation 36.—Preparation of N,N'-dibenzylethylene-diammonium - bis - 6-(2,6-dimethoxybenzamido)-thiopenicillanate

45 Sodium 6 - (2,6 - dimethoxybenzamido)penicillanate (21.0 gm., 0.05 mole) and triethylamine hydrochloride (13.7 gm., 0.10 mole) are suspended in methylene chloride (600 ml.) and stirred for one hour at room temperature. The methylene chloride is evaporated under reduced pressure leaving residual oil. The residue is slurried in dimethylformamide (300 ml.) at -10° C. and isobutyl chloroformate (6.8 gm., 0.05 mole) is added dropwise. The mixture is stirred for ten minutes and a suspension of sodium hydrosulfide trihydrate (20 gm.) in dimethylformamide (300 ml.) is added all at once. Stirring is continued for 30 minutes. The slurry is poured into ice-water (1500 ml.) and acidified to pH 2.0 with dilute sulfuric acid. The 6-(2,6-dimethoxybenzamido)thiopenicillanic acid is extracted into ether, washed with water, and back-extracted with a solution of sodium bicarbonate (0.05 mole) in water (200 ml.). The solution is filtered and N,N'-dibenzylethylenediamine acetate (0.025 mole) is added. The oil which separates is treated with methanol and a solid is obtained weighing 0.500 gm. Recrystallization from acetone and methanol yields 200 mg. of the product N,N'-dibenzylethylene-diammonium-bis - 6 - (2,6-dimethoxybenzamido)thiopenicillanate which is found to have a melting point of 125° C. with decomposition; the structure is confirmed by infrared analysis, and has the following elemental analysis:

Calc'd. for $C_{50}H_{60}N_6O_{10}S_4$: C, 56.20%; H, 5.60%; N, 7.86%; S, 12.10%. Found: C, 56.95%; H, 5.65%; N, 7.88%; S, 12.1%.

Preparation 37.—Preparation of potassium 6-(N-t-butylphthalamido) thiopenicillanate

Potassium 6-(N-t-butylphthalamido)penicillanate (23.5 gm., 0.05 mole) and triethylamine hydrochloride (13.7 gm., 0.10 mole) are suspended in methylene chloride (600 ml.) and stirred for one hour at room temperature. The methylene chloride is evaporated under reduced pressure leaving residual oil. The residue is slurried in dimethylformamide (250 ml.) at -10° C. and isobutyl chloroformate (7 gm., 0.05 mole) is added dropwise. The mixture is stirred for ten minutes and a suspension of sodium hydrosulfide trihydrate (10 gm.) in dimethylformamide (500 ml.) is added all at once. Stirring is continued for 30 minutes. The slurry is poured into ice-water (1500 ml.) and acidified to pH 2.0 with dilute sulfuric acid. The 6-(N-t-butylphthalamido)thiopenicillanic acid is extracted in methyl isobutyl ketone, washed with water, and dried over anhydrous sodium sulfate. 25 ml. of a 40% potassium 2-ethylhexanoate solution in 1-butanol is added and a precipitate forms. The water is removed by azeotropic distillation at reduced pressure and the slurry filtered and diluted with dry ether (2000 ml.). The product, potassium 6-(N-t-butylphthalamido) thiopenicillanate weighs 5 gm.; the structure is confirmed by infrared analysis, and is found to have a melting point of greater than 100° C. with decomposition, and the following elemental analysis:

Calculated for $C_{20}H_{24}KN_3O_4S_2$: C, 50.80%; H, 5.10%; S, 13.55%. Found: C, 49.62%; H, 5.45%; S, 11.90%.

Preparation 38.—Preparation of potassium 6-(2-ethoxy-1-naphthamido)thiopenicillanate and N,N'-dibenzylethylene-diammonium-bis-6-(2-ethoxy-1-naphthamido) thiopenicillanate

Triethylammonium 6-(2-ethoxy-1-naphthamido)penicillanate (12.4 gm., 0.03 mole) is dissolved in dimethylformamide (150 ml.) and cooled to -5° C. Ethyl chloroformate (2.7 gm., 0.03 mole) is added in one portion and the mixture stirred for 30 minutes at -5° C. A chilled solution of sodium hydrosulfide trihydrate (6.6 gm., 0.06 mole) in dimethylformamide (150 ml.) is added in one portion. The mixture is stirred for 30 minutes at -5° C. to 0° C. and poured into ice-water (1200 ml.). The pH is adjusted to 2 with chilled dilute sulfuric acid (20%), giving a white precipitate. The 6-(2-ethoxy-1-naphthamido)thiopenicillanic acid is extracted into ether and ethyl acetate. The combined ether and ethyl acetate extracts are washed, dried over anhydrous magnesium sulfate and filtered. Potassium 2-ethylhexanoate is added as a 50% solution of potassium 2-ethylhexanoate in ether. The gummy solid product which separates is slowly solidified by trituration with dry ether. The solid potassium 6-(2-ethoxy-1-naphthamido)thiopenicillanate is dried in vacuo over phosphorus pentoxide and weighs 8.5 gm.

A portion of the product is dissolved in water and treated with an aqueous solution of N,N'-dibenzylethylene-diamine diacetate, forming a gummy solid. Trituration with methanol gives a white solid. The product, N,N'-dibenzylethylene-diammonium-bis-6-(2-ethoxy-1-naphthamido)thiopenicillanate, is dried in vacuo over phosphorus pentoxide and weighs 0.7 gm. The structure is confirmed by infrared analysis.

Potassium 6-(2-ethoxy-1-naphthamido)thiopenicillanate is recrystallized from acetone, washed with ether, dried in vacuo over phosphorus pentoxide for three hours, and is found to weigh 1.9 gm., to have a melting point of 88°-95° C., and to have an infrared spectrum that confirms the structure, and to have the following elemental analysis:

Calculated for $C_{21}H_{21}KN_2O_4S_2 \cdot 1\frac{1}{2}H_2O$: C, 50.9%; H, 4.86%; S, 12.9%. Found: C, 50.4%; H, 4.72%; S, 11.32%.

Preparation 39.—Preparation of N,N'-dibenzylethylene-diammonium-bis-6-(2-biphenylcarboxamido)thiopenicillanate

Dilute sulfuric acid (20%) is added to an ice-cold solution of sodium 6-(2-biphenylcarboxamido)penicillanate monohydrate (17.5 gm., 0.04 mole) dissolved in water until a pH of 2 is attained. The penicillin acid is extracted from this solution into chilled ethyl acetate three times, washed with chilled water and a saturated aqueous solution of sodium chloride and filtered through anhydrous magnesium sulfate. The ethyl acetate is evaporated under reduced pressure at 25°-30° C. to leave a residual gum. The residue is dissolved in dimethylformamide (150 ml.) and cooled to -5° C. Triethylamine (4.1 gm., 10.04 mole) is added, followed by the addition of ethyl chloroformate (4.35 gm., 0.04 mole) in one portion. The mixture is stirred for 30 minutes at -10° to -5° C. and a chilled solution of sodium hydrosulfide trihydrate (8.8 gm., 0.08 mole) in dimethylformamide (140 ml.) is added in one portion. The solution is stirred at -5° C. for 30 minutes and poured into ice-water (1500 ml.) giving a clear yellow solution. The pH is adjusted to 2 with cold dilute sulfuric acid (20%), giving a heavy white precipitate. A 200 mg. sample is collected and found to be 6-(2-biphenylcarboxamido)thiopenicillanic acid shown by infrared analysis and nuclear magnetic resonance.

The remaining solid [6-(2-biphenylcarboxamido)-thiopenicillanic acid] is extracted into ether, washed with water, and dried over anhydrous magnesium sulfate. The ether is extracted with aqueous sodium bicarbonate solution (5%). An aqueous solution of N,N'-dibenzylethylene-diamine diacetate (5.4 gm., 0.015 mole) is added and a gum precipitates. After decantation of the aqueous layer, the precipitate is solidified by trituration with methanol, dried in vacuo over phosphorus pentoxide and weighs 4.3 gm. The solid is found to have a melting point of 109°-112° C. with decomposition and to be N,N'-dibenzylethylene-diammonium-bis-6-(2-biphenylcarboxamido)thiopenicillanate as shown by infrared analysis. Recrystallization from acetone (12 ml.) and methanol (95 ml.) yields 2.0 gm. of the product, N,N'-dibenzylethylene-diammonium-bis-6-(2-biphenylcarboxamido)thiopenicillanate which is found to have a melting point of 114°-117° C. with decomposition and the structure is confirmed by infrared analysis and has the following elemental analysis:

Calculated for $C_{58}H_{60}N_6O_8S_4$: C, 65.5%; H, 5.68%; S, 12.05%. Found: C, 65.58%; H, 5.67%; S, 11.45%.

Preparation 40

In the procedure of Preparation 36, the sodium 6-(2,6-dimethoxybenzamido) penicillanate is replaced by 0.05 mole of the potassium salt of the acids

- 55 6-(benzamido) penicillanic acid,
- 60 6-(3,5-dinitrobenzamido) penicillanic acid,
- 65 6-(2-chlorobenzamido) penicillanic acid,
- 70 6-(2-methylbenzamido) penicillanic acid,
- 75 6-(4-aminobenzamido) penicillanic acid,
- 6-(4-nitrobenzamido) penicillanic acid,
- 6-(4-hydroxybenzamido) penicillanic acid,
- 6-(3,4,5-trimethoxybenzamido) penicillanic acid,
- 6-(4-methylbenzamido) penicillanic acid,
- 6-(4-chlorobenzamido) penicillanic acid,
- 6-(3,4-dichlorobenzamido) penicillanic acid,
- 6-(3-nitrobenzamido) penicillanic acid,
- 6-(2,4,6-trimethoxybenzamido) penicillanic acid,
- 6-(2-hydroxybenzamido) penicillanic acid,
- 6-(4-ethoxybenzamido) penicillanic acid,
- 6-(2,6-dimethoxybenzamido) penicillanic acid,
- 6-(2,4,6-trimethylbenzamido) penicillanic acid,
- 6-(2,6-dichlorobenzamido) penicillanic acid,
- 6-(2,6-diethoxybenzamido) penicillanic acid,
- 6-(2,6-di-n-butoxybenzamido) penicillanic acid,

6-(2,6-dibenzylxybenzamido) penicillanic acid,
 6-(2,3,6-trimethoxybenzamido) penicillanic acid,
 6-(2,4,6-tribromobenzamido) penicillanic acid,
 6-(2,6-di-n-propoxybenzamido) penicillanic acid,
 6-(2,6-dimethoxy-4-methylbenzamido) penicillanic acid,
 6-(4,6-diethyl-2-methoxybenzamido) penicillanic acid,
 6-(6-ethoxy-2-methoxybenzamido) penicillanic acid,
 6-(2-methylthiobenzamido) penicillanic acid,
 6-(2-benzylthiobenzamido) penicillanic acid,
 6-(2-phenoxybenzamido) penicillanic acid,
 6-(pentachlorobenzamido) penicillanic acid,
 6-(2-phenylbenzamido) penicillanic acid, and
 6-(2-methoxybenzamido) penicillanic acid,

to produce the potassium salts of

6-(benzamido) thiopenicillanic acid,
 6-(3,5-dinitrobenzamido) thiopenicillanic acid,
 6-(2-chlorobenzamido) thiopenicillanic acid,
 6-(2-methylbenzamido) thiopenicillanic acid,
 6-(4-aminobenzamido) thiopenicillanic acid,
 6-(4-nitrobenzamido) thiopenicillanic acid,
 6-(4-hydroxybenzamido) thiopenicillanic acid,
 6-(3,4,5-trimethoxybenzamido) thiopenicillanic acid,
 6-(4-methylbenzamido) thiopenicillanic acid,
 6-(4-chlorobenzamido) thiopenicillanic acid,
 6-(3,4-dichlorobenzamido) thiopenicillanic acid,
 6-(3-nitrobenzamido) thiopenicillanic acid,
 6-(2,4,6-trimethoxybenzamido) thiopenicillanic acid,
 6-(2-hydroxybenzamido) thiopenicillanic acid,
 6-(4-ethoxybenzamido) thiopenicillanic acid,
 6-(2,6-dimethoxybenzamido) thiopenicillanic acid,
 6-(2,4,6-trimethylbenzamido) thiopenicillanic acid,
 6-(2,6-dichlorobenzamido) thiopenicillanic acid,
 6-(2,6-diethoxybenzamido) thiopenicillanic acid,
 6-(2,6-di-n-butoxybenzamido) thiopenicillanic acid,
 6-(2,6-dibenzylxybenzamido) thiopenicillanic acid,
 6-(2,3,6-trimethoxybenzamido) thiopenicillanic acid,
 6-(2,4,6-tribromobenzamido) thiopenicillanic acid,
 6-(2,6-di-n-propoxybenzamido) thiopenicillanic acid,
 6-(2,6-dimethoxy-4-methylbenzamido)-
 thiopenicillanic acid
 6-(4,6-diethyl-2-methoxybenzamido)-
 thiopenicillanic acid
 6-(6-ethoxy-2-methoxybenzamido) thiopenicillanic acid,
 6-(2-methylthiobenzamido) thiopenicillanic acid,
 6-(2-benzylthiobenzamido) thiopenicillanic acid,
 6-(2-phenoxybenzamido) thiopenicillanic acid,
 6-(pentachlorobenzamido) thiopenicillanic acid,
 6-(2-phenylbenzamido) thiopenicillanic acid, and
 6-(2-methoxybenzamido) thiopenicillanic acid,

respectively, each of which is isolated as its solid, water-soluble potassium salt.

Preparation 41

In the procedure of Preparation 36, the sodium 6-(2,6-dimethoxybenzamido) penicillanate is replaced by 0.05 mole of the potassium salt of the acids,

6-(4-sulfamylbenzamido) penicillanic acid,
 6-(3,4-dimethoxybenzamido) penicillanic acid,
 6-(4-methoxybenzamido) penicillanic acid,
 6-(3-methylbenzamido) penicillanic acid,
 6-(3-dimethylaminobenzamido) penicillanic acid,
 6-(2-methoxybenzamido) penicillanic acid,
 6-(2-chloro-3,4,5-trimethoxybenzamido) penicillanic acid,
 6-(2,4-dichlorobenzamido) penicillanic acid,
 6-(2-nitrobenzamido) penicillanic acid,
 6-(4-methylaminobenzamido) penicillanic acid,
 6-(2-acetamidobenzamido) penicillanic acid,
 6-(2,4-dimethylbenzamido) penicillanic acid,
 6-(4,5-trimethylbenzamido) penicillanic acid,
 6-(4-isopropylbenzamido) penicillanic acid,
 6-(3-bromobenzamido) penicillanic acid,
 6-(2-iodobenzamido) penicillanic acid,
 6-(2-ethylaminobenzamido) penicillanic acid,
 6-(2,5-dihydroxybenzamido) penicillanic acid,
 6-(4-hydroxy-3-methoxybenzamido) penicillanic acid,
 6-(4-allylbenzamido) penicillanic acid,
 6-(4-allyloxybenzamido) penicillanic acid,
 6-(2-trifluoromethylbenzamido) penicillanic acid,
 6-(4-fluorobenzamido) penicillanic acid,
 6-(2-phenylthiobenzamido) penicillanic acid,
 6-(2-benzylbenzamido) penicillanic acid,
 6-(2,6-dihydroxybenzamido) penicillanic acid,
 6-(2,6-diacetoxybenzamido) penicillanic acid,
 6-(2,6-dimethylthiobenzamido) penicillanic acid,
 6-(2,4,6-trinitrobenzamido) penicillanic acid,
 6-(2,6-diacetamidobenzamido) penicillanic acid,
 6-(2,6-dibromobenzamido) penicillanic acid,
 6-(2,6-dimethylbenzamido) penicillanic acid,
 6-(2,6-diisopropylbenzamido) penicillanic acid,
 6-(2,6-diallyloxybenzamido) penicillanic acid,
 6-(3-bromo-2,6-dimethoxybenzamido) penicillanic acid,
 6-(4-chloro-2,6-dimethoxybenzamido) penicillanic acid,
 6-(2-chloro-6-nitrobenzamido) penicillanic acid, and
 6-(2-hydroxy-6-methoxybenzamido) penicillanic acid,

respectively, each of which is isolated as its solid, water-soluble potassium salt.

Preparation 42

In the procedure of Preparation 36, the sodium 6-(2,6-dimethoxybenzamido) penicillanate is replaced by 0.05 mole of the potassium salt of the acids,

6-(N-allyl-N'-phthalamido) penicillanic acid,
 6-(N-benzyl-N'-phthalamido) penicillanic acid,

75

-(N-n-propyl-N'-phthalamido) penicillanic acid,
 -(N-n-amyI-N'-phthalamido) penicillanic acid,
 -(N-furfuryl-N'-phthalamido) penicillanic acid,
 -(N-1,2,5,6-tetrahydropyridyl-N'-phthalamido) penicillanic acid,
 -(N,N-tetramethylene-N'-phthalamido) penicillanic acid,
 -[N-(2-phenylethyl)-N'-phthalamido] penicillanic acid,
 -(N,N-pentamethylene-N'-phthalamido) penicillanic acid,
 -(N-isopropyl-N'-phthalamido) penicillanic acid,
 -(N- α -methylbenzyl-N'-phthalamido) penicillanic acid,
 -(N-hexamethylene-N'-phthalamido) penicillanic acid,
 -(N-tetrahydrofurfuryl-N'-phthalamido) penicillanic acid,
 -(N-morpholino-N'-phthalamido) penicillanic acid,
 -[N-(2,6-dimethylmorpholino)-N'-phthalamido] penicillanic acid,
 -(N,N-di-n-butylphthalamido) penicillanic acid,
 -[o-(2-methyl-1,2,3,4-tetrahydroquinolyl-carbonyl) benzamido] penicillanic acid,
 -(N,N-diallyl-N'-phthalamido) penicillanic acid,
 -(N,N-diisopropyl-N'-phthalamido) penicillanic acid,
 -(N,N-diethyl-N'-phthalamido) penicillanic acid,
 -(N,N-dimethyl-N'-phthalamido) penicillanic acid,
 -(N-dodecyl-N'-phthalamido) penicillanic acid,
 -(N-t-butyl-N'-phthalamido) penicillanic acid,
 -(N-methyl-N'-phthalamido) penicillanic acid,
 -(N-ethyl-N'-phthalamido) penicillanic acid,
 -(N-isobutylphthalamido) penicillanic acid,
 -(N- α -methylpropylphthalamido) penicillanic acid,
 -(N- α -methylphenethyl-N'-phthalamido) penicillanic acid,
 -(N-2-methoxyphenyl-N'-phthalamido) penicillanic acid,
 -(N-phenyl-N-ethyl-N'-phthalamido) penicillanic acid,
 -[N-(2-methyl-5-ethylpiperidino)-N'-phthalamido] penicillanic acid,
 -[N-(2,5-dimethylpyrrolidino)-N'-phthalamido] penicillanic acid,
 -[N-(2-methylpyrrolidino)-N'-phthalamido] penicillanic acid,
 -[N-(2,5-dimethylpyrrolidino)-N'-phthalamido] penicillanic acid,
 -[N-(1,1,3,3-tetramethylbutyl)-N'-phthalamido] penicillanic acid,
 -[N-(3-morpholinopropyl)-N'-phthalamido] penicillanic acid, and
 -[N-(2-methylpiperidino)-N'-phthalamido] penicillanic acid,

to produce the potassium salts of

6-(N-allyl-N'-phthalamido) thiopenicillanic acid,
 6-(N-benzyl-N'-phthalamido) thiopenicillanic acid,
 6-(N-n-propyl-N'-phthalamido) thiopenicillanic acid,
 6-(N-n-amyI-N'-phthalamido) thiopenicillanic acid,
 6-(N-furfuryl-N'-phthalamido) thiopenicillanic acid,
 6-(N-1,2,5,6-tetrahydropyridyl-N'-phthalamido) thiopenicillanic acid,
 6-(N,N-tetramethylene-N'-phthalamido) thiopenicillanic acid,
 -[N-(2-phenylethyl)-N'-phthalamido] thiopenicillanic acid,
 -(N,N-pentamethylene-N'-phthalamido) thiopenicillanic acid,
 -(N-isopropyl-N'-phthalamido) thiopenicillanic acid,
 -(N- α -methylbenzyl-N'-phthalamido) thiopenicillanic acid,
 -(N-hexamethylene-N'-phthalamido) thiopenicillanic acid,
 -(N-tetrahydrofurfuryl-N'-phthalamido) thiopenicillanic acid,
 -(N-morpholino-N'-phthalamido) thiopenicillanic acid,
 -[N-(2,6-dimethylmorpholino)-N'-phthalamido] thiopenicillanic acid,
 -(N,N-di-n-butylphthalamido) thiopenicillanic acid,

6-[o-(2-methyl-1,2,3,4-tetrahydroquinolyl-carbonyl) benzamido] thiopenicillanic acid,
 6-(N,N-diallyl-N'-phthalamido) thiopenicillanic acid,
 6-(N,N-diisopropyl-N'-phthalamido) thiopenicillanic acid,
 5 6-(N,N-diethyl-N'-phthalamido) thiopenicillanic acid,
 6-(N,N-dimethyl-N'-phthalamido) thiopenicillanic acid,
 6-(N-dodecyl-N'-phthalamido) thiopenicillanic acid,
 6-(N-t-butyl-N'-phthalamido) thiopenicillanic acid,
 6-(N-methyl-N'-phthalamido) thiopenicillanic acid,
 10 6-(N-ethyl-N'-phthalamido) thiopenicillanic acid,
 6-(N-isobutylphthalamido) thiopenicillanic acid,
 6-(N- α -methylpropylphthalamido) thiopenicillanic acid,
 6-(N- α -methylphenethyl-N'-phthalamido) thiopenicillanic acid,
 15 6-(N-2-methoxyphenyl-N'-phthalamido) thiopenicillanic acid,
 6-(N-phenyl-N-ethyl-N'-phthalamido) thiopenicillanic acid,
 6-[N-(2-methyl-5-ethylpiperidino)-N'-phthalamido] thiopenicillanic acid,
 20 6-(N-pyrrolidino-N'-phthalamido) thiopenicillanic acid,
 6-[N-(2-methylpyrrolidino)-N'-phthalamido] thiopenicillanic acid,
 6-[N-(2,5-dimethylpyrrolidino)-N'-phthalamido] thiopenicillanic acid,
 25 6-(N,N-hexamethylene-N'-phthalamido) thiopenicillanic acid,
 6-[N-(1,1,3,3-tetramethylbutyl)-N'-phthalamido] thiopenicillanic acid,
 30 6-(N-cyclohexyl-N'-phthalamido) thiopenicillanic acid,
 6-[N-(3-morpholinopropyl)-N'-phthalamido] thiopenicillanic acid, and
 6-[N-(2-methylpiperidino)-N'-phthalamido] thiopenicillanic acid,
 35 respectively, each of which is isolated as its solid, water-soluble potassium salt.

Preparation 43.—Preparation of potassium 6-(phenylmercaptoacetamido) thiopenicillanate

40 A solution of potassium 6-(phenylmercaptoacetamido) penicillanate (12.13 gm., 0.0300 mole) and triethylamine hydrochloride (6.17 gm., 0.0450 mole) in methylene chloride (420 ml.) is stirred for one-half hour at 25° C. A fine precipitate of potassium chloride forms. The 45 methylene chloride is evaporated under reduced pressure leaving residual oil. The residue is dissolved in dimethylformamide (150 ml.) and cooled to 0° to -5° C. Ethyl chloroformate (3.25 gm., 0.0300 mole) is added all at once. The mixture is stirred for 10 minutes and a suspension of sodium hydrosulfide trihydrate (6.7 gm., 0.06 mole) in dimethylformamide (100 ml.) is added all at once. Stirring is continued for 25 minutes and the solution turns dark green-brown. The solution is poured into water (1100 ml.) and acidified to pH 2 with dilute sulfuric acid. The 6-(phenylmercaptoacetamido) thiopenicillanic acid is extracted into ether, washed with water and dried over anhydrous sodium sulfate. Potassium 2-ethylhexanoate (0.03 mole) is added as a 50% solution of potassium 2-ethylhexanoate in ether. A crystalline 50 precipitate forms and is collected, washed with acetone and ether, and dried. The product, potassium 6-(phenylmercaptoacetamido) thiopenicillanate weighs 6.99 gm., is found to have a melting point of 220° to 225° C. with decomposition, the structure is confirmed by infrared analysis and has the following elemental analysis:

Calc'd. for $C_{16}H_{17}N_2O_3S_3K$: C, 45.68%; H, 4.08%; N, 6.66%; S, 22.8%. Found: C, 45.88%; H, 4.02%; N, 6.45%; S, 22.36%.

Preparation 44

70 In the procedure of Preparation 43, the potassium 6-(α -phenylmercaptoacetamido) penicillanate is replaced by 0.03 mole of the potassium salt of the acids
 6-[α -(2-chlorophenoxy)acetamido] penicillanic acid,
 75 6-[α -(4-sulfamylphenoxy)acetamido] penicillanic acid,

6-[α -(3,4-dimethoxyphenoxy)acetamido]penicillanic acid,
 6-[α -(3methylphenoxy)acetamido]penicillanic acid,
 6-[α -(4-methylthiophenoxy)acetamido]penicillanic acid,
 6-[α -(4-dimethylaminophenoxy)acetamido]penicillanic acid,
 6-[α -(2-methoxyphenoxy)acetamido]penicillanic acid,
 6-[α -(2,4-dichlorophenoxy)phenoxyacetamido]penicillanic acid,
 6-[α -(2-nitrophenoxy)acetamido]penicillanic acid,
 6-[α -(2-acetamidophenoxy)acetamido]penicillanic acid,
 6-[α -(2,4-dimethylphenoxy)acetamido]penicillanic acid,
 6-[α -(4-isopropylphenoxy)acetamido]penicillanic acid,
 6-[α -(3-bromophenoxy)acetamido]penicillanic acid,
 6-[α -(2-iodophenoxy)phenoxyacetamido]penicillanic acid,
 6-[α -(2-diethylaminophenoxy)acetamido]penicillanic acid,
 6-[α -(3,5-dichlorophenoxy)acetamido]penicillanic acid,
 6-[α -(4-cyclohexylphenoxy)acetamido]penicillanic acid,
 6-[α -(α -phenoxyacetamido)penicillanic acid,
 6-[α -(2-benzylphenoxy)acetamido]penicillanic acid,
 6-[α -(2-trifluoromethylphenoxy)acetamido]penicillanic acid,
 6-[α -(4-chlorophenoxy)acetamido]penicillanic acid,
 respectively, to produce the potassium salts of
 6-[α -(2-chlorophenoxy)acetamido]thiopenicillanic acid,
 6-[α -(4-sulamylphenoxy)acetamido]thiopenicillanic acid,
 6-[α -(3,4-dimethoxyphenoxy)acetamido]thiopenicillanic acid,
 6-[α -(3-methylphenoxy)acetamido]thiopenicillanic acid,
 6-[α -(4-methylthiophenoxy)acetamido]thiopenicillanic acid,
 6-[α -(4-dimethylaminophenoxy)acetamido]thiopenicillanic acid,
 6-[α -(2-methoxyphenoxy)acetamido]thiopenicillanic acid,
 6-[α -(2,4-dichlorophenoxy)phenoxyacetamido]thiopenicillanic acid,
 6-[α -(2-nitrophenoxy)acetamido]thiopenicillanic acid,
 6-[α -(2-acetamidophenoxy)acetamido]thiopenicillanic acid,
 6-[α -(2,4-dimethylphenoxy)acetamido]thiopenicillanic acid,
 6-[α -(4-isopropylphenoxy)acetamido]thiopenicillanic acid,
 6-[α -(3-bromophenoxy)acetamido]thiopenicillanic acid,
 6-[α -(2-iodophenoxy)phenoxyacetamido]thiopenicillanic acid,
 6-[α -(2-diethylaminophenoxy)acetamido]thiopenicillanic acid,
 6-[α -(3,5-dichlorophenoxy)acetamido]thiopenicillanic acid,
 6-[α -(4-cyclohexylphenoxy)acetamido]thiopenicillanic acid,
 6-[α -(α -phenoxyacetamido)thiopenicillanic acid,
 6-[α -(2-benzylphenoxy)acetamido]thiopenicillanic acid,
 6-[α -(2-trifluoromethylphenoxy)acetamido]thiopenicillanic acid,
 6-[α -(4-chlorophenoxy)acetamido]thiopenicillanic acid,
 respectively, each of which is isolated as its solid, water-soluble potassium salt.

Preparation 45.—Preparation of potassium 6-(4-methoxyphenylthioacetamido)thiopenicillanate

A solution of sodium 6-(4-methoxyphenylthioacetamido)penicillanate (5.71 gm., 0.01365 mole) and triethylamine hydrochloride (2.82 gm., 0.0205 mole) in methylene chloride (190 ml.) is stirred for one-half hour at 25° C. The methylene chloride is evaporated under reduced pressure leaving residual oil. The residue is dissolved in dimethylformamide (68 ml.) and cooled to -7° C. Ethyl chloroformate (1.62 gm., 0.0136 mole) is added all at once. The mixture is stirred for ten minutes at -2° C. and a suspension of sodium hydrosulfide trihydrate (3.00 gm., 0.0273 mole) in dimethylformamide (45 ml.) is added all

at once. Stirring is continued for 25 minutes at 0 to -5° C. Water (500 ml.) is added to the solution and then acidified to pH 2.1 with dilute sulfuric acid giving heavy turbidity. The 6-(4-methoxyphenylthioacetamido)thiopenicillanic acid is extracted into ether, washed with water, and dried over anhydrous sodium sulfate. Potassium 2-ethylhexanoate (0.015 mole) is added as a 50% solution of potassium 2-ethylhexanoate in ether. A crystalline precipitate forms and is collected, washed with acetone and dried. The product, potassium 6-(4-methylphenylthioacetamido)thiopenicillanate weighs 1.36 gm., is found to have a melting point of 210-212° C. with decomposition, the structure is confirmed by infrared analysis and has the following elemental analysis:
 5 Calculated for $C_{19}H_{19}N_2O_4S_2K \cdot H_2O$: C, 43.56%; H, 4.52%; S, 20.53%. Found: C, 43.50%; H, 3.98%; S, 19.85%.

Preparation 46.—Potassium 6-(phenoxyacetamido)thiopenicillanate

Potassium 6-(phenoxyacetamido)penicillanate (47.6 gm.) and triethylamine hydrochloride (25.4 gm.) are suspended in methylene chloride (1740 ml.) and stirred for one-half hour at room temperature. The methylene chloride is evaporated under reduced pressure leaving residual oil. The residue is dissolved in dimethylformamide (617 ml.) and cooled to -5° C. Ethyl chloroformate (11.8 ml.) is added all at once. The mixture is stirred for ten minutes and a suspension of sodium hydrosulfide trihydrate (27.2 gm.) in dimethylformamide (427 ml.) is added all at once. Stirring is continued for 25 minutes. The mixture is poured into ice water (4500 ml.) and acidified to pH 2.0 with dilute sulfuric acid. The 6-(phenoxyacetamido)thiopenicillanic acid is extracted into ether, washed with water and dried over anhydrous sodium sulfate. Forty-nine ml. of a 50% solution of potassium 2-ethylhexanoate in ether is added. A crystalline precipitate forms and is collected, washed with acetone and dried. The product, potassium 6-(phenoxyacetamido)thiopenicillanate weighs 15.4 gm. and is found to contain the β -lactam ring as shown by infrared analysis, to have a melting point of 196-207° C. with decomposition after recrystallization with water and n-butanol and the following elemental analysis:
 45 Calculated for $C_{16}H_{17}N_2O_4S_2$: C, 47.51%; H, 4.24%; N, 6.93%. Found: C, 47.59%; H, 4.18%; N, 7.14%.

Preparation 47

In the procedure of Preparation 43, the potassium 6-(α -phenylmercaptoacetamido)penicillanic acid is replaced by 0.03 mole of the potassium salt of
 50 6-[α -(4-nitrophenoxy)acetamido]penicillanic acid,
 6-[α -(4-bromophenoxy)acetamido]penicillanic acid,
 6-[α -(4-t-butylphenoxy)acetamido]penicillanic acid,
 6-[α -(4-trifluoromethylphenoxy)acetamido]penicillanic acid,
 6-[α -(3-fluorophenoxy)acetamido]penicillanic acid,
 6-[α -(4-sulfamylphenoxy)acetamido]penicillanic acid,
 6-[α -(2-benzylphenoxy)acetamido]penicillanic acid,
 6-[α -(3-methoxyphenoxy)acetamido]penicillanic acid,
 6-[α -(2-iodophenoxy)acetamido]penicillanic acid,
 6-[α -(3-diethylaminophenoxy)acetamido]penicillanic acid,
 6-[α -(2,4-diisooamylphenoxy)acetamido]penicillanic acid,
 65 respectively, to produce the potassium salts of
 6-[α -(4-nitrophenoxy)acetamido]thiopenicillanic acid,
 6-[α -(4-bromophenoxy)acetamido]thiopenicillanic acid,
 6-[α -(4-t-butylphenoxy)acetamido]thiopenicillanic acid,
 70 6-[α -(4-trifluoromethylphenoxy)acetamido]thiopenicillanic acid,
 6-[α -(3-fluorophenoxy)acetamido]thiopenicillanic acid,
 6-[α -(4-sulfamylphenoxy)acetamido]thiopenicillanic acid,
 6-[α -(2-benzylphenoxy)acetamido]thiopenicillanic acid,
 75 6-[α -(2-benzylphenoxy)acetamido]thiopenicillanic acid,

5-[α -(3-methoxyphenoxy)acetamido]thiopenicillanic acid,
6-[α -(2-iodophenoxy)acetamido]thiopenicillanic acid,
6-[α -(3-diethylaminophenoxy)acetamido]thiopenicillanic acid, and
6-[α -(2,4-diisoamylphenoxy)acetamido]thiopenicillanic acid,

respectively, each of which is isolated as its solid, water-soluble potassium salt.

Preparation 48

In the procedure of Preparation 43, the potassium 6-(α -phenylmercaptoacetamido)penicillanic acid is replaced by 0.03 mole of the potassium salt of

6-(α -phenylthioacetamido)penicillanic acid,
6-(α -paranitrophenylthioacetamido)penicillanic acid,
6-(α -parachlorophenylthioacetamido)penicillanic acid,
6-[α -(4-tertairy-butylphenylthio)acetamido]penicillanic acid,
6-(α -ortho-tolylthioacetamido)penicillanic acid,
6-(α -ortho-nitrophenylthioacetamido)penicillanic acid,
6-[α -(3,4,5-trichlorophenylthio)acetamido]penicillanic acid,
6-[α -(3-trifluoromethylphenylthio)acetamido]penicillanic acid,
6-(α -parabromophenylthioacetamido)penicillanic acid,
6-(α -paraphenylphenylthioacetamido)penicillanic acid,
6-[α -(4-methoxyphenylthio)acetamido]penicillanic acid,
6-[α -(4-cyclohexylphenylthio)acetamido]penicillanic acid,
6-[α -(2,4-dichlorophenylthio)acetamido]penicillanic acid,
6-[α -(2,4-diisoamylphenylthio)acetamido]penicillanic acid,
6-[α -(4-benzylphenylthio)acetamido]penicillanic acid,
6-[α -(4-sulfamylphenylthio)acetamido]penicillanic acid,
6-[α -(2-allyloxyphenylthio)acetamido]penicillanic acid,
6-[α -(4-allylphenylthio)acetamido]penicillanic acid,
6-[α -(3-methoxyphenylthio)acetamido]penicillanic acid,
6-[α -(2-iodophenylthio)acetamido]penicillanic acid,
6-[α -(3-diethylaminophenoxy)acetamido]penicillanic acid,
6-[α -(2,5-dichlorophenylthio)acetamido]penicillanic acid,
6-[α -(2-iodophenylthio)acetamido]penicillanic acid,
6-[α -(2-acetamidophenylthio)acetamido]penicillanic acid,
6-[α -(4-diethylaminophenylthio)acetamido]penicillanic acid, and
6-[α -(3-fluorophenylthio)acetamido]penicillanic acid,
respectively, to produce the potassium salts of
6-(α -phenylthioacetamido)thiopenicillanic acid,
6-(α -paranitrophenylthioacetamido)thiopenicillanic acid,
6-(α -parachlorophenylthioacetamido)thiopenicillanic acid,
6-[α -(4-tertairy-butylphenylthio)acetamido]thiopenicillanic acid,
6-(α -ortho-tolylthioacetamido)thiopenicillanic acid,
6-(α -ortho-nitrophenylthioacetamido)thiopenicillanic acid,
6-[α -(3,4,5-trichlorophenylthio)acetamido]thiopenicillanic acid,
6-[α -(3-trifluoromethylphenylthio)acetamido]thiopenicillanic acid,
6-(α -parabromophenylthioacetamido)thiopenicillanic acid,
6-(α -paraphenylphenylthioacetamido)thiopenicillanic acid,
6-[α -(4-methoxyphenylthio)acetamido]thiopenicillanic acid,
6-[α -(4-cyclohexylphenylthio)acetamido]thiopenicillanic acid,
6-[α -(2,4-dichlorophenylthio)acetamido]thiopenicillanic acid,
6-[α -(2,4-diisoamylphenylthio)acetamido]thiopenicillanic acid,
6-[α -(4-benzylphenylthio)acetamido]thiopenicillanic acid,
6-[α -(4-sulfamylphenylthio)acetamido]thiopenicillanic acid,
6-[α -(2-allyloxyphenylthio)acetamido]thiopenicillanic acid,
6-[α -(4-allylphenylthio)acetamido]thiopenicillanic acid,
6-[α -(3-methoxyphenylthio)acetamido]thiopenicillanic acid,
6-[α -(2-iodophenylthio)acetamido]thiopenicillanic acid,
6-[α -(3-diethylaminophenoxy)acetamido]thiopenicillanic acid,
6-[α -(2,5-dichlorophenylthio)acetamido]thiopenicillanic acid,
6-[α -(2-iodophenylthio)acetamido]thiopenicillanic acid,
6-[α -(2-acetamidophenylthio)acetamido]thiopenicillanic acid,
6-[α -(4-diethylaminophenylthio)acetamido]thiopenicillanic acid, and
6-[α -(3-fluorophenylthio)acetamido]thiopenicillanic acid,
respectively, each of which is isolated as its solid, water-soluble potassium salt.

6-[α -(2,4-dichlorophenylthio)acetamido]thiopenicillanic acid,
6-[α -(2,4-diisoamylphenylthio)acetamido]thiopenicillanic acid,
5 6-[α -(4-benzylphenylthio)acetamido]thiopenicillanic acid,
6-[α -(4-sulfamylphenylthio)acetamido]thiopenicillanic acid,
6-[α -(2-allyloxyphenylthio)acetamido]thiopenicillanic acid,
10 6-[α -(4-allylphenylthio)acetamido]thiopenicillanic acid,
6-[α -(4-dimethylaminophenylthio)acetamido]thiopenicillanic acid,
15 6-[α -(2,5-dichlorophenylthio)acetamido]thiopenicillanic acid,
6-[α -(2-iodophenylthio)acetamido]thiopenicillanic acid,
6-[α -(2-acetamidophenylthio)acetamido]thiopenicillanic acid,
20 6-[α -(4-diethylaminophenylthio)acetamido]thiopenicillanic acid, and
6-[α -(3-fluorophenylthio)acetamido]thiopenicillanic acid,
25 respectively, each of which is isolated as its solid, water-soluble potassium salt.

Preparation 49

In the procedure of Preparation 43, the potassium 6-(α -phenylmercaptoacetamido)penicillanic acid is replaced by 0.03 mole of the potassium salt of
30 6-[α -(4-nitrophenyl)acetamido]penicillanic acid,
6-[α -(4-bromophenyl)acetamido]penicillanic acid,
35 6-[α -(4-t-butylphenyl)acetamido]penicillanic acid,
6-[α -(4-trifluoromethylphenyl)acetamido]penicillanic acid,
6-[α -(3-fluorophenyl)acetamido]penicillanic acid,
40 6-[α -(4-sulfamylphenyl)acetamido]penicillanic acid,
6-[α -(2-benzylphenyl)acetamido]penicillanic acid,
6-[α -(3-methoxyphenyl)acetamido]penicillanic acid,
6-[α -(2-iodophenyl)acetamido]penicillanic acid,
6-[α -(3-diethylaminophenoxy)acetamido]penicillanic acid,
45 6-[α -(2,4-diisoamylphenyl)acetamido]penicillanic acid,
respectively, to produce the potassium salts of
6-[α -(4-nitrophenyl)acetamido]thiopenicillanic acid,
6-[α -(4-bromophenyl)acetamido]thiopenicillanic acid,
6-[α -(4-t-butylphenyl)acetamido]thiopenicillanic acid,
50 6-[α -(4-trifluoromethylphenyl)acetamido]thiopenicillanic acid,
6-[α -(3-fluorophenyl)acetamido]thiopenicillanic acid,
6-[α -(4-sulfamylphenyl)acetamido]thiopenicillanic acid,
6-[α -(2-benzylphenyl)acetamido]thiopenicillanic acid,
6-[α -(3-methoxyphenyl)acetamido]thiopenicillanic acid,
6-[α -(2-iodophenyl)acetamido]thiopenicillanic acid,
6-[α -(3-diethylaminophenoxy)acetamido]thiopenicillanic acid,
65 6-[α -(2,4-diisoamylphenyl)acetamido]thiopenicillanic acid,
respectively, each of which is isolated as its solid, water-soluble potassium salt.

Preparation 50

In the procedure of Preparation 43, the potassium 6-(α -phenylmercaptoacetamido)penicillanic acid is replaced by 0.03 mole of the potassium salt of
70 6-[α -phenylacetamido]penicillanic acid,
6-[α -paranitrophenylacetamido]penicillanic acid,
6-[α -parachlorophenylacetamido]penicillanic acid,
6-[α -(4-tertairy-butylphenyl)acetamido]penicillanic acid,
75 6-[α -ortho-tolylacetamido]penicillanic acid,

6-(α -ortho-nitrophenylacetamido)penicillanic acid,
 6-[α -(3,4,5-trichlorophenyl)acetamido]penicillanic acid,
 6-[α -(3-trifluoromethylphenyl)acetamido]penicillanic acid,
 6-(α -paragromophenylacetamido)penicillanic acid,
 6-(α -paraphenylphenylacetamido)penicillanic acid,
 6-[α -(4-methoxyphenyl)acetamido]penicillanic acid,
 6-[α -(4-cyclohexylphenyl)acetamido]penicillanic acid,
 6-[α -(2,4-dichlorophenyl)acetamido]penicillanic acid,
 6-[α -(2,4-diisoamylphenyl)acetamido]penicillanic acid,
 6-[α -(4-benzylphenyl)acetamido]penicillanic acid,
 6-[α -(4-sulfamylphenyl)acetamido]penicillanic acid,
 6-[α -(2-allyloxyphenyl)acetamido]penicillanic acid,
 6-[α -(4-allylphenyl)acetamido]penicillanic acid,
 6-[α -(4-dimethylaminophenyl)acetamido]penicillanic acid,
 6-[α -(2,5-dichlorophenyl)acetamido]penicillanic acid,
 6-[α -(2-iodophenyl)acetamido]penicillanic acid,
 6-[α -(2-acetamidophenyl)acetamido]penicillanic acid,
 6-[α -(4-diethylaminophenyl)acetamido]penicillanic acid,
 6-[α -(3-fluorophenyl)acetamido]penicillanic acid,
 respectively, to produce the potassium salts of
 6-(α -phenylacetamido)thiopenicillanic acid,
 6-(α -paranitrophenylacetamido)thiopenicillanic acid,
 6-(α -parachlorophenylacetamido)thiopenicillanic acid,
 6-[α -(4-tertiary-butylphenyl)acetamido]thiopenicillanic acid,
 6-(α -ortho-tolylacetamido)thiopenicillanic acid,
 6-(α -ortho-nitrophenylacetamido)thiopenicillanic acid,
 6-[α -(3,4,5-trichlorophenyl)acetamido]thiopenicillanic acid,
 6-[α -(3-trifluoromethylphenyl)acetamido]thiopenicillanic acid,
 6-(α -parabromophenylacetamido)thiopenicillanic acid,
 6-(α -paraphenylphenylacetamido)thiopenicillanic acid,
 6-[α -(4-methoxyphenyl)acetamido]thiopenicillanic acid,
 6-[α -(4-cyclohexylphenyl)acetamido]thiopenicillanic acid,
 6-[α -(2,4-dichlorophenyl)acetamido]thiopenicillanic acid,
 6-[α -(2,4-diisoamylphenyl)acetamido]thiopenicillanic acid,
 6-[α -(4-benzylphenyl)acetamido]thiopenicillanic acid,
 6-[α -(4-sulfamylphenyl)acetamido]thiopenicillanic acid,
 6-[α -(2-allyloxyphenyl)acetamido]thiopenicillanic acid,
 6-[α -(4-allylphenyl)acetamido]thiopenicillanic acid,
 6-[α -(4-dimethylaminophenyl)acetamido]thiopenicillanic acid,
 6-[α -(2,5-dichlorophenyl)acetamido]thiopenicillanic acid,
 6-[α -(2-iodophenyl)acetamido]thiopenicillanic acid,
 6-[α -(2-acetamidophenyl)acetamido]thiopenicillanic acid,
 6-[α -(4-diethylaminophenyl)acetamido]thiopenicillanic acid,
 6-[α -(3-fluorophenyl)acetamido]thiopenicillanic acid,
 respectively, each of which is isolated as its solid, water-soluble potassium salt.

PREPARATION OF STARTING MATERIALS— PENICILLIN THIOESTERS

Use is also made in the present invention of thioesters of the above thioacids. These thioesters are prepared simply by substituting a mercaptan, e.g. ethyl mercaptan, benzyl mercaptan, for the sodium hydrosulfide used in each case above to make the thioacid.

Two examples of the preparation of such thioesters are as follows:

Preparation 51.—Benzylthiol ester of 6-phthalimidopenicillanic acid

To a slurry of 33.63 g. (0.1 mole) of 6-phthalimidopenicillanic acid in 700 ml. of CH_2Cl_2 was added 21 ml. 75

of triethylamine (TEA) and the resulting solution was evaporated to dryness under reduced pressure at 25° C. The resulting oil was redissolved in 400 ml. of CH_2Cl_2 and stirred and cooled at -10° C. while 10.7 g. (0.1 mole) of ethyl chloroformate was added dropwise. Fifteen minutes after the addition was complete 12.1 g. (0.1 mole) of benzylmercaptan was added all at once and stirring continued for one and one-half hours with the ice bath removed. The resulting solution was then washed with 5% NaHCO_3 (3 x 100 ml. portions) and finally with water (2 x 200 ml. portions) and dried briefly over anhydrous Na_2SO_4 . The filtered solution was evaporated to dryness at 25° C. (water pump) and the residue dissolved in 100 ml. of dry ether, scratched and cooled. There was collected 20 g. of crystalline benzylthiol ester of 6-phthalimidopenicillanic acid melting at 150-151° C.

Analysis.—Calculated for: C, 61.2%; H, 4.45%; N, 6.20%; S, 14.15%. Found: C, 61.1%; H, 4.47%; N, 6.26%; S, 13.70%.

Preparation 52.—Ethylthiol ester of 6-phthalimidopenicillanic acid

25 The same procedure and scale was carried out as with the benzylthiol ester preparation. Ethyl mercaptan (6.6 g.; 0.1 mole) was used and the product crystallized from ether-Skellysolve B to give 17 g.; M.P. 113-115°.

Analysis.—Calculated for: C, 55.4%; H, 4.65%; S, 16.4%. Found: C, 56.3%; H, 4.68%; S, 14.85%.

We claim:

1. A compound of the formula

in which R^2 represents the side chain of a penicillin.

2. A member selected from the group consisting of the 40 compounds of the formulae

11. A compound of the formula

12. A compound of the formula

13. A compound of the formula
